[57] **ABSTRACT**

A transition or isolation zone for accommodating continuous free flow of a tier of articles between two distinct and isolated atmospheres. The transition zone includes a series of alternate inlet and outlet compartments for a non-reactive gas wherein the compartments contain inlet and outlet openings interconnecting with each other and the indicated atmospheres. The cross sections of the openings are complementary to the cross section of the tier of articles to provide a restricted orifice-size clearance therebetween, whereby the orifice phenomena can be employed by correlation of pressures to control the flow of gas and conversely to substantially completely isolate the indicated atmospheres without any measurable cross-migration therebetween.

1. Field of the Invention

This invention relates to gas barriers for interconnecting and isolating two distinct atmospheres, and more particularly to a gas barrier to prevent the cross infiltration of contaminating atmospheres into a reactive atmosphere. In general the gas barrier of this invention has particular application in continuous processing systems for interconnecting two distinct and separate atmospheres, wherein cross-migration between such atmospheres is for all measurable purposes completely eliminated.

2. Description of the Prior Art

In various processing operations involving reactive atmospheres, it is desirable to minimize and preferably to eliminate the adulteration of such atmospheres by infiltration or injection therein of other non-compatible gasses which may either dilute the processing atmospheres, introduce degrading impurities therein, or alter the chemical composition thereof. To this effect, the maintainence of the integrity of reactive atmospheres assumes increased importance in multichamber processing systems utilizing a series of interconnected processing chambers through which a continuous throughput of workpieces is transported. The importance of effecting an operable isolation of atmospheres in such atmospheres becomes readily apparent upon consideration of systems such as described in U.S. Pat. No. 3,179,392 utilizing hydrogen and oxygen at elevated temperatures in sequential processing chambers of high temperature furnaces to prevent explosive mixtures of the gases from forming.

Another continuous system for processing a continuous flow of workpieces in two successive and distinct stages utilizing different atmospheres whose integrity is preferably maintained is described in U.S. Pat. No. 3,086,764.

The desirability of maintaining the integrity of a processing atmosphere is equally applicable to systems such as described in U.S. Pats. Nos. 2,916,398 and 2,897,091 involving coating operations, such as gas plating, in which a workpiece enters a

processing atmosphere from an ambient atmosphere whose entry is to be prevented into the processing atmosphere.

Another area of particular interest in the application of this invention is the continuous multistage processing of semiconductor devices as proposed in U.S. Pat. No. 3,314,393 and French Pats. Nos. 1,498,045 and 1,511,289. It can be readily appreciated that in such processing systems, where contamination in processing atmospheres even of the order of parts by million can seriously affect the integrity of a semiconductor device, the isolation and preservation of such processing atmospheres from contaminating and non-compatible impurities becomes increasingly critical, and thus requires the preclusion and at most a substantial minimization of infiltration or cross-migration of atmospheres between each of sequential processing stages of a continuous system.

Various techniques for isolating and maintaining the integrity of a processing atmosphere in various systems have been proposed heretofore. Among such techniques is the use of air barriers, mechanical seals, air locks, liquid seals, gas curtains and the like as described in various ones of U.S. Pats. Nos. 2,701,901, 2,856,312, 2,916,398, 3,179,392, 3,314,393 and 3,340,176. However, the main effect of the seal configurations described has been to minimize if not eliminate leakage to and from processing atmospheres; and although a number of such sealing techniques have been implemented in production systems their use has been limited in application to processing systems tolerating substantial fluctuation in processing atmospheres. Moreover, none of such techniques have found any practical application or use in systems processing semiconductor devices, particularly in continuous systems wherein the semiconductor device is sequentially transported in a continuous mode from one processing chamber of zone to another and wherein each zone is provided with its own distinct and controlled environment.

Another attempt to resolve the problem of isolating sequential processing chambers of a continuous system comprehended the introduction and removal of workpieces through a series of isolating chambers connected by low throughput apertures in the form of narrow slots with attempts to control the leak between such chambers involving the use of controlled and steep pressure gradients. However the disadvantages of such systems are adequately set out in U.S. Pat. No. 2,972,330 among which disadvantages is included the continued "excessive leak" and need for pumping requirements which become excessive or so small as to materially interfere with the passage of the substrate.

A further approach to maintain the integrity of semiconductor processing atmospheres in a continuous system comprehends the high velocity flow of the atmosphere intermediate an open end of a reactor tube and an exhaust portion separating the processing station from the other section of the tube. Typical techniques employing such approaches are described in the aforesaid U.S. Pat. No. 3,314,393 and French Pat. No. 1,498,045. In such systems, reliance is placed on the high velocity gas flow to provide sufficient force to prevent ingress of adjacent atmospheres. However, in actual practice, particularly in semiconductor processing where impurities are measured in parts per million or billion, it is known that regardless of the flow (and pressure) of one gas into a second gas, diffusion causes sufficient inmigration of minor quantities of the second gas up-stream of the first gas which can seriously affect the integrity of the first gas. In fact, regardless of the extent of the flow of the first gas (even approaching infinity) such inmigration of the second gas continuously occurs.

SUMMARY OF THE INVENTION

It has now been discovered in accordance with this invention that substantially complete isolation (for all measurable purposes) can be obtained between two distinct and separate atmospheres of a continuous processing system by use of a transition or isolation chamber comprised of a series of alternate inlet and outlet compartments for a non-reactive gas,

and interconnected with each other and to adjacent atmospheres by openings having a cross section complementary to the cross section of a moving tier of workpieces so as to define restricted orifice-sized clearances therebetween. A non-reactive gas is introduced into the inlet compartments at a pressure sufficiently above the pressure of adjacent outlet compartments, so as to cause positive flow of the non-reactive gasses out of the inlet compartments into any adjacent outlet compartments and/or atmospheres. In general, for preferred embodiments of the invention, pressure and volume of the gasses in the systems are controlled so as to form gas flows in each of the processing chambers of the system of a magnitude providing a substantially uniform gas pattern of substantially constant concentration by suitable inlets and outlets of the processing atmospheres.

Of particular significance in the application of this invention to the continuous processing of semiconductor devices is to enable a continuous and uninterrupted throughput of the devices through a plurality of processing steps in contrast to present day batch type processes. In such batch type processes, a semiconductor material or device is placed in a chamber where various environmental conditions are sequentially created to produce the desired result. Where a plurality of processing operations are to be performed in such a chamber, a plurality of distinct processing environments must be sequentially formed and removed, with purging of the chamber intermediate the introduction of subsequent new processing environments. After process completion, the chamber environment is returned to ambient conditions, and the material or device removed from the chamber.

In contrast with the prior art, the present invention enables the use of a continuous processing technique wherein a semiconductor material or device is transported in a continuous mode from one processing environment to another through the transition or isolation zones of this invention, whereby each processing zone can be provided with its own distinct and controlled environment by use of suitable flow and process control techniques. In this manner multiple processing zones can be formed in series to provide multiple processing capabilities where the environmental conditions in each processing zone can be held constant.

With such a continuous system, a plurality of stable environments can be considered constant relative to processing times. Further each semiconductor material can be assured of being processed in a substantially identical manner. Also, more than one single process can be executed on a traveling array or tier of semiconductor materials or substrates in one material handling step. In addition and of particular significance a continuous processing line, incorporating this invention, can be provided for successive processing of material with a plurality of individual and constant environments, which reduces the usual deleterious effects associated with environmental cycling.

Accordingly, it is an object of this invention to provide a novel means for maintaining the integrity of a processing atmosphere during a continuous throughput of workpieces therethrough from and into externally distinct atmospheres.

Another object of this invention is to provide a novel means of ingress and egress for a continuous transport of workpieces through a reactive chamber which forms an effective barrier against entry of external atmospheres into the reactive atmosphere.

A further object of this invention is to provide a novel transitional or isolation compartment between two distinct and separate processing atmospheres to effectively prevent cross-migration therebetween during a continuous transport of workpieces therethrough.

A still further object of this invention is to provide an interconnecting transition or isolation section between two reactive atmospheres of a continuous multistage processing system which prevents cross-migration of such atmospheres during a continuous throughput of workpieces through such stages.

It is also an object of this invention to provide a novel method and apparatus for oxidation of semiconductor material.

Another object of this invention is to provide a continuous method and apparatus for processing of semiconductor substrates which substantially eliminates environmental cycling.

The foregoing and other objects, features and advantages of the invention will be apparent from the following more particular description of the embodiment of the invention, as illustrated in the accompanying drawings.

BRIEF DESCRIPTION OF THE DRAWINGS

FIGS. 1 and 2 are, respectively, perspective and elevational views of an embodiment of this invention defining a buffer pass-through for a continuous work flow between two distinct atmospheres maintained in substantially complete isolation from each other to prevent cross-migration of such atmospheres;

FIG. 3 is a perspective view of another embodiment of this invention;

FIG. 4 is a sectional view taken along line 4—4 of FIG. 3;

FIG. 5 is a schematic view in perspective illustrating a feed mechanism for a work throughput in a multistage continuous semiconductor processing system;

FIGS. 6 to 7 are perspective views of various carriers for supporting semiconductor wafers in transport through a series of processing stations formed within an open-ended tube;

FIG. 8 is an elevational view in cross section of an open-ended processing tube illustrating an embodiment of this invention for processing semiconductor wafers in accordance with a series of processing operations;

FIGS. 9 and 10 are views taken along lines 9—9 and 10—10, respectively, of FIG. 8;

FIGS. 11 and 12 illustrate various inlet nozzle configurations employed for introducing processing atmospheres in the various chambers of the processing tube of FIG. 8;

FIGS. 13 and 14 are views taken along lines 13—13 and 14—14 of FIGS. 11 and 12, respectively;

FIG. 15 is a cross-sectional view of a buffer or isolation unit employed in the processing tube of FIG. 8 for illustrating gas flow and pressure relationships therein;

FIG. 16 is a cross-sectional view showing the use of the buffer or isolation unit embodiment of FIG. 2 in a processing tube for illustrating gas flow and pressure relationships therein; and

FIG. 17 is an elevational view in cross section of an open-ended processing tube illustrating another embodiment of this invention for processing semiconductor wafers in accordance with another series of processing operations;

FIGS. 18 to 44 are elevational views in cross section of open-ended processing tubes illustrating additional embodiments of this invention of processing semiconductor wafers.

DESCRIPTION OF THE PREFERRED EMBODIMENTS

Referring to the drawings, one embodiment of the invention is shown in FIGS. 1 and 2, illustrating the use of a transition or isolation unit generally indicated at 1 as a buffer feed unit interconnecting two atmospheres A1 and A2 in their respective environments 2 and 3, through which a sheet 4 of material to be treated is transported in a continuous mode, as from suitable supply and take-up reel units not shown. The atmospheres A1 and A2 may constitute any of the environmental or reactive atmospheres, as in the above indicated patents, required for a multistage processing unit of a continuous system; or one of the atmospheres, such as A1, may constitute an ambient atmosphere from which the sheet 4 enters into a reactive atmosphere such as A2.

It is to be understood that where atmospheres A1 and A2 constitute distinct reactive atmospheres of a continuous multistage processing system, into which the sheet 4 enters from and exits into, an ambient atmosphere, additional and similar transition or isolation units may be provided as buffer

units at the entry of the sheet 4 into the first reactive atmosphere, such as A1, from ambient atmospheres, and also at the exit of sheet 4 from the second atmosphere, such as A2, into ambient atmospheres.

Similarly, where a continuous processing system employs only a single reactive atmosphere into which a continuous tier of workpieces enters from and exits into ambient atmospheres, two of the transitional or isolation units may be provided, as buffer feed units at, respectively, the entry to and exit from the reactive atmospheres.

As used herein, the term "tier of workpieces" is employed to define and comprehend a continuous flow of material, such as a sheet, filament or sequence of units which form a substantially uninterrupted cross section of the material as it is transported in a continuous flow through the processing system. As for example, where a sequence of individual units is employed, they may be provided with complementary configurations at adjacent end portions, and transported through the system in end-to-end relationship. Thus, in this manner, the units will form a continuum of units and substantially constant cross section.

Alternately, the tier of workpieces may include suitable carriers on which the workpieces may be mounted; as for example planar carriers provided with a recess in which is mounted a substrate to be processed, which example is further described below with another embodiment of this invention.

In the form illustrated in FIGS. 1 and 2, the transition unit 1 may be defined as an isolation chamber interconnecting atmospheres A1 and A2, and subdivided into a plurality of alternate inlet and outlet compartments utilizing a non-reactive gas which is compatible with the work flow and the atmosphere in that it is not reactive with the workpiece or with the atmospheres A1 and A2, as for example in forming corrosive, toxic, or explosive mixtures therebetween.

The compartments of the isolation unit are defined by end walls 5 and baffles 6 with it being understood that end walls 5 may comprise part of any environmental enclosure (shown in phantom) confining either of atmospheres A1 and A2. In the specific configuration shown, end walls 5 and baffles 6 define an inlet compartment 7 disposed adjacent respective atmospheres A1 and A2.

In order to control gas flow between adjacent compartments of the buffer unit 1 and atmospheres A1 and A2, and thus prevent cross-migration between these atmospheres, the end walls 5 and baffles 6 are extended so as to define with the buffer unit bottom wall 10 an opening having a cross section complementary to the cross section of the work flow or sheet 4 so as to define therewith a restricted orifice size clearance therebetween, as for example, of the order of 0.4 sq.cm. This restricted clearance forms a controlled leak of gasses which enables the use of the orifice phenomena in conjunction with gas pressure employed to control the direction of gas flows between compartments and atmospheres.

A non-reactive atmosphere is injected in the inlet compartment 7 by means of a nozzle 11 connected to a suitable controlled and pressurized supply of the gas, not shown.

The non-reactive gas is supplied to the inlet compartment at a pressure substantially higher than the pressures of atmospheres A1 and A2. In turn, the pressures of the atmospheres A1 and A2 and of the non-reactive gas in inlet compartment 7 are higher than the gas pressures in adjacent outlet compartments 8 and 9.

Where the atmospheres A1 and A2 are at the positive pressure levels (e.g., and conversely the pressure in inlet compartment 7 is at a higher positive level), no positive exhaust system

is necessary for withdrawing gasses from outlet compartments 8 and 9 via outlets 12 and 13. The exit of gasses from outlet compartments 8 and 9 can be exhausted by the sole impetus of the gas flows from inlet compartment 7 alone or in conjunction with any adjacent pressurized gas flows either one from atmospheres A1 and A2. However, it is to be understood that, if desired, the withdrawal of gasses from the outlet compartments can be facilitated by use of supplementary exhaust systems such as shown in U.S. Pat. No. 3,314,393 particularly where one of the atmospheres A1 and A2 is at ambient pressures.

In substance, the above defined structural configuration of the transition or buffer feed unit of this invention utilizes the orifice phenomena for control of gas flows, and thus conversely prevents cross-migration of interconnected atmosphere. Basically since for a given feed unit, constant values are presented by the dimensions of the orifice-sized clearances, the cross section of the compartments or chambers, the coefficient of discharge and the density of the flowing gasses, the orifice equation for flow-through the clearances is reduced to

$$F = K \sqrt{\Delta P}$$

where F is the rate of flow in feed per second, K is a derivable constant characteristic of each of the orifice-clearances employed in the buffer feed unit, and P is the pressure differential across the orifice-clearances.

Using the equation above, the control of gas flows in FIG. 2 for preventing cross-migration of atmospheres can be clarified, by reference to the previous qualifications that the pressures in buffer outlet compartments 8 and 9 are lower than the pressure of adjacent atmospheres in environments 2 and 3 and in buffer inlet compartment 7. Thus since the pressure P_3 of atmosphere A2 is higher than the pressure P_9 in outlet compartment 9, the gas from atmosphere A2 into outlet compartment 9 conforms to the equation

$$F_1 = K_1 \sqrt{P_3 - P_9}$$

where P_3 will be selected to provide a positive gas flow from atmosphere A2 into outlet compartment as indicated by the arrow 15.

Similarly the gas flow F_2 between outlet compartment 9 at pressure P_9 and inlet compartment 7 at pressure P_7 will conform to the equation

$$F_2 = K_2 \sqrt{P_7 - P_9}$$

where the pressure P_7 will be maintained at a sufficiently high level above pressures P_9 and P_3 to insure a positive gas flow from inlet compartment 7 to outlet compartment 9 as indicated by the arrow 16.

Also, the gas flow F_3 between inlet compartments 7 at its pressure P_7 and outlet compartment 8 at a pressure P_8 will conform to the equation

$$F_3 = K_3 \sqrt{P_7 - P_8}$$

where the pressure P_7 will be maintained at a level sufficiently below pressure P_7 to insure a positive gas flow from inlet compartment 7 into outlet compartment 8 as indicated by the arrow 17.

Likewise, the gas flow F_4 between atmosphere A1 at a pressure P_2 and the outlet compartment 8 at its pressure P_8 will conform to the equation

$$F_4 = K_4 \sqrt{P_1 - P_8}$$

where the pressure P_1 is at a level below P_7 , and the pressure P_8 will be maintained sufficiently below the pressure P_1 (with correlation to pressure P_7) to insure a positive gas flow from atmosphere A1 into outlet compartment 8 as indicated by the arrow 18.

In general, the relationship of pressures can be summarized in the following table:

TABLE 1

Atmosphere	Pressures		Flow directions		
	Compartments	Atmosphere	Atmosphere	Compartments	Atmosphere
$P_1 \geq P_2$	8 7 9 $P_8 < P_7 > P_9 \leq$	P_2	P_1 —————> 8 ————— 7 —————> 9 —————> P_2		

where flows (7-8) and (7-9) are greater than corresponding adjacent flows (A1-8) and (A2-9).

It is noted that the foregoing isolation or buffer feed units are normally employed for separation of processing atmosphere having some degree of tolerance for each other in minor concentrations. A typical example of such separated reactive atmosphere is an epitaxial film growing atmosphere comprised of hydrogen and a silicon halide separated from an oxidizing atmosphere comprised of hydrogen, silicon halide and carbon dioxide.

In any event, as noted previously, complete elimination of cross-migration between communicating reactive atmospheres is impossible to achieve. However, the concentration of the migrating gasses can be sequentially reduced to a level that its infusion into a second atmosphere can be restricted to tolerable levels. Thus in the embodiment above described, the noted epitaxial film growing atmosphere (e.g., A1 in FIG. 2) upon entry in outlet compartment 8 will be diluted by an order of $10^2 : 1$ (e.g., a 1 percent by volume concentration) from which it will diffuse into inlet compartment 7 (against the flow of inert gas therefrom) wherein it will be again diluted by an order of $10^4 : 1$ (e.g., to a concentration of about 0.01 percent by volume), and then the final mixture (in inlet compartment 7) will be exhausted into outlet compartment 9. In turn, this gas will be further diluted by an order of $10^2 : 1$ by combination with the inflowing atmosphere A2 (e.g., the indicated oxidizing atmosphere comprised of hydrogen, a silicon halide and carbon dioxide) to reduce its concentration to a level of about 10^{-4} percent by volume, which gas mixture is reduced with concentration limits whose diffusion into and against the inflowing atmosphere A2 can be safely tolerated since the first atmosphere A1 is further diluted by an order of $10^2 : 1$ within atmosphere A2 to concentrations measurable only in parts per million. Conversely, as will be readily seen, a similar analysis applies equally to the cross-migration in FIG. 2 of atmosphere A2 into atmosphere A1.

FIG. 3 shows another embodiment of the buffer feed units comprehended within this invention, where increased isolation performance of two atmospheres can be obtained particularly where it is highly critical to minimize all possible forms of cross-migration between the atmospheres, as for example by in-migration or in-diffusion at elevated temperatures, e.g., $1,000^{\circ}\text{C}$.

In the embodiment of FIG. 3, the buffer or isolation feed unit 20 is adapted for transfer to a continuous traveling filament 21 between two isolated temperatures A11 and A12 in their respective environments 22 and 23 (indicated in phantom).

The buffer feed unit 20 is in the configuration of an elongated chamber subdivided by end walls 24 and 25, in conjunction with partitions 26 into a series of alternate inlet and outlet compartments, comprising three inlet compartments 27, 29 and 31 and two outlet compartments 28 and 30 with the two end most inlet compartments 27 and 31 disposed adjacent respective atmospheres A11 and A12. It is to be understood that, as with the preceding embodiment, either of end walls 24 and 25 may form or comprise part of any environmental defining enclosures for atmospheres A11 and A12.

A non-reactive gas, from a suitable source not shown, is introduced into inlet compartments 27, 29 and 31 through respective inlet nozzles 32, 33 and 34 at a pressure level above that of atmospheres A11 and A12, with the inlet compartment 29 pressurized to a level above that in end most inlet compartments 27 and 31. Gasses from outlet compartments 28 and 30 are exhausted by respective discharge outlets 35 and 36.

Each of end walls 24 and 25 are provided with an aperture 37, and baffles 26 are likewise provided with apertures 38. Each of the apertures 37 and 38 define work-passage openings having a cross section substantially complementary to the cross section of filament 21 which define therebetween, as in the preceding embodiment, a restricted orifice-size clearance for control of gas flows in conjunction with the pressures of atmospheres A11 and A12 and that in the alternate inlet and

outlet compartments 27 to 31. As will be noted, each of end walls 24 and 25 is provided with an axially projecting annular flange or extension 40 which defines an elongated passage for increased gas flow control by, conversely, providing a large coefficient of discharge to which the flow rate is directly proportional.

For convenience, the various pressures comprehended in the system are identified and set forth in the following table:

10

TABLE 2

Atmosphere	Compartment Pressure	
15 A11		P _{A11}
Non-reactive	27	P ₂₇
Non-reactive	28	P ₂₈
Non-reactive	29	P ₂₉
Non-reactive	30	P ₃₀
Non-reactive	31	P ₃₁
		P ₁₂

With the above pressures correlated to each other in accordance with the following relationship wherein pressure P₂₉ (in central inlet compartment 29) represents the highest pressure level employed; $P_{A11} \leq P_{27} > P_{28} < P_{29} > P_{30} < P_{31} \leq P_{12}$.

In a preferred application for maximum isolation of atmospheres A11 and A12, the various pressures are correlated in the following relationships:

$$P_{27} \geq P_{A11}$$

$$P_{31} \geq P_{A12}$$

$$P_{29} > P_{27}, P_{31}, P_{A11} \text{ and } P_{A12}$$

$$P_{28} < P_{27} + \frac{1}{2}P_{29}$$

$$P_{30} < P_{31} + \frac{1}{2}P_{29}$$

Using the orifice equation noted above to the gas flows between the various atmospheres and compartments, the gas flow between atmosphere A11 and inlet compartment 27 will conform to the equation

$$F_1 = K_1 \sqrt{P_{27} - P_{A11}}$$

wherein P_{27} , as indicated above, may be equal to or greater than P_{A11} so that gas flow therebetween will be zero or in a positive direction from compartment 27 to atmosphere A11 as indicated by the arrow 41. As will be seen, where atmosphere A11 is a prefixed processing environment with a fixed pressure P_{A11} , the pressure P_{27} , (in compartment 27) will be selected to give the indicated gas flow relationship. Also, as will be seen, in view of the greater coefficient of friction reflecting the elongation of aperture 37 the gas flow rate will be directly affected.

The gas flows F_2 and F_3 between respective pairs of compartments 27 and 28 and compartments 28 and 29 conform to the corresponding equations

$$F_2 = K_2 \sqrt{P_{27} - P_{28}} \quad F_3 = K_3 \sqrt{P_{29} - P_{28}}$$

in respective compartments 27 and 29, wherein both pressures P_{27} and P_{29} are greater than pressure P_{28} in compartment 28 so that gas flow will be in positive directions from compartments 27 and 29 into compartment 28 as indicated by the arrows 42 and 43. Also, in view of the additional requirement that the positive pressure P_{29} in compartment 29 is at a higher level above the positive pressure P_{27} in compartment 27, the gas flow F_3 from compartment 29 into compartment 28 will be greater than the gas flow F_2 from compartment 27 into compartment 28 to thus minimize to non-measurement magnitudes cross-migration of gas between inlet compartments 27 and 29.

The gas flow relationship for gas flows F_2 and F_3 apply similarly to respective gas flows F_5 (between compartments 29 and 30) which conform to the equations

$$F_5 = K_5 \sqrt{P_{31} - P_{30}} \quad F_4 = K_4 \sqrt{P_{29} - P_{30}}$$

wherein the pressures are selected and correlated so that there is a positive gas flow F_5 from compartment 31 into compartment 30, as indicated by the arrow 44, and a positive gas flow

*F*4 from compartment 29 into compartment 30 as indicated by the arrow 45.

Similarly the relationship for gas flow *F*1 applies in like manner to the gas flow *F*6 between compartment 31 and atmosphere *A*12 which conform to the equation

$$F_6 = K_6 \sqrt{P_{31} - P_{A12}}$$

wherein the pressures *P*₃₁ and *P*_{*A*12}, or respectively compartment 31 and atmosphere *A*12, are correlated so that there is zero flow or a positive flow from compartment 31 into atmosphere *A*12.

Also, as indicated previously with the embodiment of FIG. 2, complete elimination of cross-migration between communicating atmospheres is again impossible to achieve. However, the concentration of migrating gasses is sequentially reduced in this embodiment (e.g., FIG. 3) to a level that its infusion into a second atmosphere is restricted to unmeasurable concentrations (e.g., a few parts per million or less).

Thus in the embodiment described in conjunction with FIG. 3, the previously noted epitaxial film growing atmosphere (e.g., all in FIG. 3) will diffuse against a back pressure of compartment 27 wherein it will be diluted by an order of 10² : 1 to a concentration level of about 1 percent by volume wherein the final mixture will be represented as an atmosphere *D*1 which represents the first dilution of atmosphere *A*11. From compartment 27, the atmosphere or gas mixture *D*1 is forced into outlet compartment 28 where it is blended with the inflowing gas from inlet compartment 29 which results in a further dilution of atmosphere *A*11 in the gas mixture *D*1 by an order of 10⁴ : 1 to form a second mixture *D*2 wherein the concentration of atmosphere *A*11 is about 10⁻⁴ percent by volume. This second gas mixture *D*12 will diffuse against the inflowing gasses from inlet compartment 29 wherein the atmosphere *A*11 will be further diluted by an order of 10² : 1 to form a third gas mixture *D*3 wherein *D*3 represents the third dilution of atmosphere *A*11 to a concentration level of less than 10⁻⁴ percent or 1 or less parts per million. In turn, the gas mixture *D*3 (in compartment 29) flows into the outlet compartment 30 wherein it is mixed with the inflowing gasses from inlet compartment 31 to form a fourth mixture *D*4 in which the atmosphere *A*11 is further diluted by an order of 10² : 1 to a concentration of 10⁻² parts per million. Similarly this gas mixture *D*4 (representing the fourth dilution of atmosphere *A*11) diffuses against the inflowing gasses from compartment 31 into this compartment wherein it is again diluted by an order of 10² : 1 to a concentration level of less than 10⁻¹ parts per billion which forms a gas mixture *D*5 in which the concentration limits of *A*11 are at a level, which upon migration of gas mixture *D*5 into atmosphere *A*12 can be safely tolerated since the first atmosphere *A*11 is still further diluted by an order of 10² : 1 within atmosphere *A*12 to concentration of less than 1 part per trillion. Conversely, as can be readily seen, a similar analysis applies equally to the cross-migration in FIG. 3 of atmosphere *A*12 into atmosphere *A*11.

FIGS. 5 to 14 illustrate a specific implementation of the buffer feed units of this invention in the continuous processing of semiconductor elements as more fully described in the following examples

EXAMPLE 1

Thermal Oxidation

This example in conjunction with FIGS. 8 to 15 describes a continuous processing system for thermal oxidation of semiconductor substrates. As shown a continuous tier of wafer carriers 50 having a rectangular configuration are transported in end-to-end relationship by a feed mechanism generally indicated by the numeral 51 into a quartz processing tube 52 disposed within heating coils 53 and 54 normally enclosed in a furnace enclosure 55 of the usual construction.

In its broadest concept the system of this example comprises an environmentally controlled pre-heat station communicating with a confined oxidizing atmosphere with a series of

semiconductor substrates sequentially transported through pre-heat and the oxidizing station. In a particular application, the oxidation station will comprise three distinct oxidizing operations as the semiconductor substrates are sequentially transported through three distinct and demarcated oxidizing atmospheres. Specifically the first oxidizing operation would be oxidation in dry oxygen followed by oxidation of the substrates in an oxygen/water vapor atmosphere and a third oxidation in dry oxygen wherein the three atmospheres are disposed sequentially along the path of the substrate's travel.

In practice, a series of wafers are appropriately supported on a flat carrier which is sequentially passed in end-to-end relationship through a series of consecutive chambers defined by partitions each having an opening of the configuration conforming to the cross section of the carriers so as to provide a restricted clearance, as the identically shaped carriers pass through the openings. The three basic oxidizing chambers are, respectively, a dry oxygen processing chamber, a wet oxidizing chamber, and a second dry oxidizing chamber with the three oxidizing chambers disposed sequentially along the reactive tube intermediate the ends thereof. Disposed within the tube intermediate the first dry oxidation chamber and the restricted opening at the inlet of the tube, is a pre-heat or buffer chamber in which is introduced, at low pressures, either a non-reactive gas or dry oxygen (in view of its compatibility with the processing gasses and the atmosphere externally of the two). The first dry oxidation chamber is positioned immediately adjacent to and upstream the wet oxidation chamber whereas the second dry oxidation chamber is positioned downstream of the wet oxidation chamber which immediately follows the first oxidation chamber. Positioned between the wet oxidation chamber and the second dry oxidation chamber is a transition or isolation chamber constructed in accordance with our teachings above. The isolation of transition chamber functions to demarcate the adjacent processing atmospheres into distinct processing environments whereby each processing section of the tube defined for the oxidation is provided with its own distinct and controlled environment by use of suitable flow and process control techniques. With the continuous oxidation system of this invention, individual and constant environments are provided which reduce the usual deleterious effects associated with environmental cycling as a consequence of batch techniques.

Isolation of the adjacent oxidizing atmospheres by means of the transition chamber or section is accomplished by means of a series of counterflowing gasses which comprise non-reactive gasses or oxygen or other gas which are compatible with the oxidizing atmospheres. Also included within the reactor tube downstream of the second dry oxidation chamber and adjacent the outlet of the tube is a cooldown section in which a non-reactive gas, oxygen or other gas compatible with the oxidation chamber and ambient atmospheres is introduced and maintained. Also included in the system is a suitable heater, e.g., resistance heater, disposed about the reactor tube for heating and maintaining the transported wafers at operating or processing temperatures.

The process involved in the operation of the above system can be defined, in substance, as introducing semiconductor wafers into a preconditioning chamber in which the wafers are pre-heated to operating temperatures in an atmosphere which may be oxygen or any non-reactive gas compatible with ambient atmospheres and the reaction gasses in the system, and while the wafers are maintained at operating temperatures, immediately and sequentially passing them through: (a) a dry oxygen processing atmosphere (at operating temperatures) (b) into a water vapor laden oxygen processing atmosphere maintained at the operating temperatures (c) into a dry oxygen isolation atmosphere and (d) into a second dry oxygen processing atmosphere from which the wafer passes through a cooldown chamber of oxygen or the indicated non-reactive gasses wherein the wafers are cooled to below reactive temperatures, and from which the wafers emerge from the reactor tube into ambient atmospheres.

The foregoing process is characterized in that a series of wafers is continuously passed in linear array through the various chambers with substantially 100 percent separation maintained between the wet oxidation chamber and the final dry oxidation chamber.

Also the process is further characterized in that the various processing and isolating atmospheres are maintained at substantially constant concentration and environment whereby each respective atmosphere concentration level and pressure is non-fluctuating. In essence, the invention processes the semiconductor material sequentially at a common ambient, such as temperature, which eliminates the deleterious effects produced by switching gas flows, etc., for example introducing transients in an otherwise undisturbed system. Secondly, each chamber provides its own environment which is stable over long periods compared with the processing time of the material in that chamber.

Specifically with reference to the drawings, as shown in FIG. 5, a continuous tier of wafer carriers 50 having a rectangular configuration are transported in end-to-end relationship by a feed mechanism generally indicated by the numeral 51 into a quartz processing or reactor tube 52 which may be disposed within water-cooled RF heating coils 53 or normally enclosed in a furnace enclosure of the usual construction.

The carriers 50 may be fabricated of any suitable material, such as quartz or treated graphite, which is compatible with the semiconductor substrates which are to be supported thereon. In general, the material of carriers 50 will generally determine the type of heater coils employed in conjunction with reactor tube 52. In a system employing quartz carriers, the heating coils would generally comprise resistance coils, and conversely, the use of treated graphite in the construction of the carriers can employ either resistance coils or water-cooled induction heater coils in the system. In general, the specific form of heating employed will be dependent on the specific processing involved, and where appropriate, the heating coils can comprise resistance heaters and the like. Conversely, when appropriate, in other processing systems the carriers can be fabricated of other material, such as quartz and the like.

The processing or reactor tube 52 shown is a rectangular configuration having an internal height of about 33 mm. and an internal width of 89 mm. with an overall length of about 78 inches subdivided into appropriate chambers to be described below.

A typical carrier 50 adapted for processing of wafers of 2½ in. diameter is shown in FIG. 6. The particular carrier shown has a generally square configuration having a width which normally spans across the internal width of processing tube 52 to enable the sides of tube 52 to serve as guides during transport of the carrier therethrough; and to this end, carriers 50 were fabricated in a 3.45 square inch configuration. Although a carrier is shown with a square planar configuration, it is to be understood that other configurations may be employed, particularly with respect to opposite end portions in the longitudinal extension of the carriers. Thus, for example, as shown in FIG. 6A, it is preferred that the ends 60 and 61 of the carriers be configured in a construction complementary to adjacent ends 60A and 61A respectively, of abutting carriers so as to define a continuous tier of carriers with a substantially uninterrupted extension during transport through processing tube 52.

Referring to the specific configuration of FIG. 6, the carrier thickness is 0.5 inches for graphite or 0.1875 inches for quartz, having skids or rails 62 of about 0.015 inches depending from the bottom of the carrier to provide an overall height of about 0.515 inches on the graphite carrier and 0.1890 inches on the quartz carrier. Skids 62 are provided to reduce friction as the carriers are pushed in end-to-end fashion in sliding relationship across the bottom of the processing tube 52 to provide a free-flow area of 17.7 square centimeters in the tube.

In addition, the top surface of carrier 50 is recessed at 63 a sufficient depth to seat and maintain therein a semiconductor

waffer 64 such as silicon and the like, for multistage processing through processing tube 52. In the preferred form the top surface of wafer 64 will be substantially flush with the top surface of carrier 50 while seated therein. Although the specific carrier shown in FIG. 6 is provided with a single recess for support of a single wafer, it will be apparent that a carrier 50B can be provided with a multiplicity of recesses 63B (as in FIG. 7) for support of a like number of smaller dimensioned wafers 64B (e.g., of about 1.3 in. diameter) for transport through processing tube 52.

Referring back to FIG. 5, the feed station 51 for carriers 50, each supporting a wafer 64, comprises an endless conveyor 65 which carry the carriers to the drive units 66. The drive units 66 comprise two side-gripping endless belts which contact the carriers 50 on their sides to propel them. Transfer plate 67 is provided with side-guides 67A for feeding the carriers 50 in end-to-end relationship into and through processing tube 52.

The tube 52 shown in FIG. 8 is configured to sequentially process a preconditioned silicon wafer in successive dry, wet and dry oxidation operations, employed to provide corresponding number stratified oxide layers. As is known, the dry oxidations produce slow growth but dense pinhole-free oxides whereas the wet oxidation produces a less dense but rapid growth oxide in relatively thicker dimensions.

Basically the reactor tube 52 is subdivided into a preheat chamber or zone 69, a first dry oxidation chamber 69A, a wet oxidation chamber 69B, an isolation or buffer chamber 92, a second dry oxidation chamber 69C, and an ambient buffer or cooldown chamber 77.

The preheat chamber 69 is about 15 inches in length and is defined by partitions 78 and 79 with the end partition 78 extending toward the bottom of reactor tube 52 a distance providing about 0.25 inch clearance with the top of the tier of carriers 50. Preheat chamber 69 also forms a preliminary barrier with ambient atmosphere and is maintained with either an oxygen or a non-reactive atmosphere of about 0.001 p.s.i.g. by introducing therein, through a circumferential slot 80A of a closed end nozzle 80 a suitably controlled flow of gas such as oxygen, nitrogen, helium, argon, forming gas or other gas which is compatible with ambient atmospheres and oxygen. Generally however, for the instant processing system, the pressure in the preheat buffer chamber may extend from about 0.001 to about 0.005 p.s.i.g. and preferably from about 0.001 to about 0.003 p.s.i.g.

As shown, nozzle 80 is a closed-end structure having a configuration such as shown in FIGS. 12 and 13 with an ID of about 5 mm., and a 250° circumferential slot (e.g., H1) of about 0.55 mm. to laterally eject the environmental gasses toward the entry end of the reaction tube 52 and to prevent direct impingement of the gasses on the wafers 64. The tier of carriers 50 traveling at a rate of 1 inch per minute passes out of the ambient chamber 69 into and through three oxidation chambers 69A, 69B and 69C at a temperature of about 1,100° C. but which generally can extend in the range of 700°-1,150° C. and preferably in the range of 800°-1,100° C.

The reaction chambers 69A, 69B and 69C are employed to oxidize the wafers 64 in corresponding dry, wet, and dry oxygen environments. The first dry oxidation chamber 69A in the system shown in FIG. 8 is about 7 inches in length as defined between flanged partitions 79 and 79A each of which extends to a level of about 0.015 inches above the surface of the traveling tier of carriers 50 to provide an orifice-size clearance therewith and thereby restrict flow of gasses therethrough.

The second dry oxidation chamber 69C in this system is about 4 inches in length and is defined between partitions 96A and 79C, both of which also extend to a level of about 0.015 inches above the surface of the traveling tier of carriers 50 to define the indicated orifice-size clearance therewith and likewise restrict the flow of gasses therethrough.

In general, dry oxygen is circulated through the first oxidation chamber via inlets and outlets 89 and 90, respectively, to provide a gas feed or flow rate of about 2 liters per minute (e.g.,

about 0.113 liters/min./sq. cm. of cross section of the chamber) and a pressure of about 0.003 p.s.i.g. Generally the flow or feed rate may range from about 1 to 10 liters per minute (e.g., about 0.0565 to about 0.565 liters/min./sq. cm. of cross section of the chamber) and the pressure may range from about 0.001 to about 0.05 p.s.i.g.

In similar fashion dry oxygen is circulated through dry oxi-chamber 69C via its inlet and outlet tubes 89 and 90 respectively, to maintain a feed rate and pressure comparable to that employed in the first dry oxi-chamber 69A, e.g., about 2 liters/minute (e.g., about 0.113 liters/min./sq. cm. of cross section of the chamber) and 0.003 p.s.i.g.

In general, the lengths of both dry oxi-chambers 69A and 69C will be determined by the range of oxide thicknesses desired, as correlated directly to the throughput of carriers 50, the temperatures employed, and indirectly correlated to the dimensions of the reactor tube parameters employed which initially determines the range of speeds for the throughput of carriers 50.

The wet oxi-chamber 69B in the system as shown in FIG. 8 is about 40 inches in length with an oxygen/water vapor mixture circulated therethrough via its respective inlet and outlet tubes 89 and 90. The flow of mixture is controlled to provide a rate of about 2 to about 4 liters per minute (e.g., about 0.113 to about 0.226 liters/min./sq. cm. of cross section) which defines a substantially quiescent environment at a pressure in the range of about 0.002 to about 0.005 p.s.i.g. and in a general range of 0.001 to 0.05 p.s.i.g. As will be noted, each of inlet tubes 89 discharge their atmosphere laterally to prevent direct impingement on wafers 64.

In operation, as the tiers of carriers 50 traveling at the indicated rate of 1 inch per minute, emerge from ambient buffer chamber 69, pass at temperature through dry oxi-chamber 69A, the surface of wafers 64 is converted into relatively dense adherent oxide film ranging from about 250 to about 600 angstroms prior to entry into the following wet oxidation chamber 69B. On passage through the wet oxi-chamber 69B, the wafer is further oxidized by an additional thickness of about 3,500 to about 4,500 angstroms of relatively less dense oxide, from which they pass through the isolation chamber 92 and into the dry oxygen chamber 69C for a final oxidation wherein the wafers 64 are further oxidized by a thickness of about 50 to about 150 angstroms.

Following the final oxidation in dry oxi-chamber 69C, the carriers pass into and through the cooldown chamber 77 about 9 inches in length for discharge across a transfer table 98 and between a conveyor 99. As shown, the cooldown chamber 77 is provided with an oxygen or a non-reactive atmosphere via inlet tube 89 with discharge of gasses effected into ambient atmospheres through the restricted openings defined between end partition 78A and the surfaces of carriers 50.

In order to maintain the integrity of the oxidizing atmosphere in the wet oxi-chamber 69B and the oxidizing atmosphere in the second dry oxi-chamber 69C an isolation chamber 92, as described above, is interposed between the two oxi-chambers. In accordance with our above teachings, the isolation chamber 92 is subdivided into a series of alternate outlet and inlet compartments into which oxygen or a non-reactive gas, such as any of those indicated above and compatible with oxygen is respectively withdrawn and introduced. For the particular isolation obtained, the isolation chamber 92 subdivided into an outlet compartment 92A, an inlet compartment 92B, and a second outlet compartment 92C each being 1 inch in length.

The outlet compartment 92A is about 1 inch in length and is defined between the flanged partitions 96 and a baffle 97 in which oxygen or non-reactive atmosphere is maintained at a pressure of about 0.002 p.s.i.g.

A gas mixture is formed in the outlet compartment 92A by the inflowing atmosphere and gasses from respectively wet oxi-chamber 69B and inlet compartment 92B (of isolation chamber 92) with the gases exhausted via an outlet 94 which

exhausts the gasses under the sole impetus of the gas flows into the outlet compartment. In general, the outlet 94 comprises a pair of open-ended outlet tubes of about 15 mm. ID each. However, if desired, and where the requirements of a processing system require it, positive exhaust means may be employed to assist in exhausting gasses. It is also noted that the indicated baffle 97 extends to about 0.020 inches to the top of carriers 50 to define a clearance substantially larger than that defined by the flange 82 of partition 96 with the top of carriers 50.

In general, the pressure in outlet compartment 92A may extend in the range from about 0.001 p.s.i.g. to about 0.005 p.s.i.g. and preferably from about 0.001 to about 0.003 p.s.i.g. However, in all cases, the pressure P_{92A} in outlet compartment 92A will be lower than the pressure P_{69B} in the wet oxi-chamber 69B with a pressure differential P_1 therebetween (e.g., $P_{69B} - P_{92A}$) of at least about 0.001 p.s.i.g. In the preferred construction, baffle 97 extends to within 0.020 inches of the top of carrier 50 to define a restricted clearance with the carriers larger than the corresponding clearance formed under flange 82 of partition 96. As will be understood, since the flow in the orifice equation is directly proportional to the orifice area, the flow (under like pressure conditions) will be greater in a larger orifice than in a smaller orifice.

The inlet compartment 92B is defined between baffle 97 and second like baffle 97A wherein both define like clearances with the top of wafer carriers 50. Generally as shown in FIG. 15, the pressure differentials P_1 and P_2 (e.g., $P_{92B} - P_{92A}$) are coordinated with each other and with other pressure differentials (as described below) in the remaining compartments and the chambers of the reaction tube 52 so that there will be (a) a positive flow F_1 from the wet oxi-chamber 69B into the outlet compartment 92A, (b) a positive gas flow F_2 from inlet compartment 92B into outlet compartment 92A, and (c) wherein gas flow F_2 is greater than gas flow F_1 . A non-reactive gas or oxygen (generally the same as employed in the pre-heat chamber 69A of the tube) is introduced through the inlet nozzle 95 having a general configuration such as shown in FIGS. 11 and 14. In the specific embodiment described, these inlet nozzles have an ID (e.g., ID 2) of about 5 mm. with two diametrically opposed circumferential slots having a width of about 9 mm. (e.g., H2). Generally these slots are positioned so as to laterally discharge the non-reactive gas towards the distal ends of the reactor tube 52. Also, the closed end of the nozzles prevents direct impingement of gasses on the wafers traveling through the zone.

In practice the pressure P_{92B} in inlet compartment 92B is maintained at a level (e.g., about 0.006 p.s.i.g.) substantially higher than the pressures P_{92A} and P_{92C} in respectively, outlet compartment 92A and the following outlet compartment 92C defined between baffle 97A and the flanged partition 96A. This outlet compartment 92C is substantially identical with the preceding outlet compartment 92A with the baffle extending to about 0.020 inches of the top surfaces of carriers 50 and with the flanged partition 82 extending to within about 0.015 inches of the top surfaces of carriers 50. Generally the pressure in inlet compartment 92B will be maintained in the range of about 0.004 to about 0.1 p.s.i.g., and preferably from about 0.004 to about 0.01 p.s.i.g. However, as indicated, the pressure in inlet compartment 92B will be maintained at a level substantially higher than the pressure in either of outlet compartments 92A and 92C. Conversely, the pressure in inlet compartment 92B will not only be substantially higher than the pressure in either of outlet compartments 92A and 92C, but also at a level higher than the pressure in wet oxi-chamber 69B and the dry oxi-chamber 69C where the relationship is graphically shown in FIG. 15.

As more fully described above, in order to control gas flow between adjacent compartments of the isolation chamber 92 and the atmospheres in wet oxi-chamber 69B and dry oxi-chamber 69C and thus prevent cross-migration between these two atmospheres, the end walls or partitions 96 and 96A and

baffles 97 and 97A are extended so as to define with the top surfaces of carriers 50 openings having a cross section complementary to the cross section of the carriers so as to define therewith a restricted orifice-size clearance therebetween as, for example, of the order of 0.34 sq. centimeters and 0.45 sq. centimeters, respectively. These restricted clearances form a controlled leak of gasses which enables the use of the orifice phenomena in conjunction with the gas pressures employed to control the direction of gas flows between compartments and processing atmospheres.

In addition, the flanges on the partitions 96 and 96A form an elongated tubular passage which overlaps the juncture line of adjoining carriers and thus insures against any interstitial leaks between such carriers or by depressions therebetween as may be caused by rounded top edges of adjacent ends. Although each of the aforescribed partitions is shown as a continuum of the reaction tube 52, in practice each of such partitions (as well as the baffles) is welded to the reaction tube by conventional glass working techniques. However, it is noted that where flanges are provided on the various partitions they are preferably and conventionally formed as continuums thereof.

As indicated, oxygen or a non-reactive atmosphere is injected in the inlet compartment 92B by means of the nozzle 95 connected to a suitably controlled and pressurized source of gas (not shown). The non-reactive gas is applied to the inlet compartment at a pressure substantially higher than the corresponding pressures of the oxidizing atmospheres in wet oxi-chamber 69B and dry oxi-chamber 69C. In turn, the pressures P69B, P69C and P92B in the wet oxi-chamber 69B, the dry oxi-chamber 69C and inlet compartment, respectively, are higher than the gas pressures P92A and P92C in respective adjacent outlet compartments 92A and 92C.

Where the pressures P69B and P69C are at positive pressure levels (e.g., and conversely the pressure P92B in inlet compartment 92B is at a still higher pressure level) no positive exhaust system is necessary for withdrawing gasses from outlet

pressures in isolation outlet compartments 92A and 92C are lower than the pressure of adjacent atmospheres in chambers 69B and 69C and in inlet compartment 96B. Thus since the pressure P69B of atmosphere A69B in wet oxi-chamber 69B is higher than the pressure P92A in outlet compartment 92A, the gas flow from atmosphere A69B into outlet compartment 92A conforms to the equation

$$F_1 = K_1 \sqrt{P69B - P92A} = K_1 \sqrt{\Delta P_1}$$

where ΔP_1 will be selected to provide a positive gas flow from atmosphere A69B into outlet compartment as indicated by the arrow F1.

Similarly the gas flow F2 between outlet compartment 92A at pressure P92A and inlet compartment 92B at pressure P92B will conform to the equation

$$F_2 = K_2 \sqrt{P92B - P92A} = K_2 \sqrt{\Delta P_2}$$

where the pressure P92B will be maintained at a sufficiently high level above pressures P92A and P69B to insure a positive gas flow from inlet compartment 92B to outlet compartment 92A as indicated by the arrow F2.

Also, the gas flow F3 between inlet compartment 92B at its pressure P92B and outlet compartment 92C at a pressure P92C will conform to the equation

$$F_3 = K_3 \sqrt{P92B - P92C} = K_3 \sqrt{\Delta P_3}$$

where the pressure P92B-P92C will be maintained at a level sufficiently below pressure P92B to insure a positive gas flow from inlet compartment 92B into outlet compartment 92C as indicated by the arrow F3.

Likewise, the gas flow F4 between atmosphere A69C in dry oxi-chamber 69C at a pressure P69C and the outlet compartment 92C at its pressure P92C will conform to the equation

$$F_4 = K_4 \sqrt{P69C - P92C} = K_4 \sqrt{\Delta P_4}$$

where the pressure P69C-P92C is at a level below pressure P92B and the pressure P92C will be maintained sufficiently below the pressure P69C (with correlation to pressure P92B) to insure a positive gas flow from atmosphere A69C into outlet compartment 92C as indicated by the arrow F4.

In general, the relationship of pressures and flows can be summarized in the following table:

TABLE 3

Pressures					Flow directions		
Atmosphere	Compartments			Atmosphere	Compartments	Atmosphere	
	Outlet	Inlet	Outlet				
A69B	92A	92B	92C	A69B	92A → 92B → 92C	→ A69C	
P69B ≥	92A <<	92B >>	92C ≤	P69C	where flows (92B → 92A) and (92B → 92C) are greater than corresponding adjacent flows (A69C → 92A)		

compartments 92A and 92C via outlets 94 and 94A. The gasses from the outlet compartments 92A and 92C can be exhausted by the sole impetus of the gas flows from inlet compartment 92B alone or in conjunction with the adjacent pressurized gas flows in either one of the atmospheres in wet oxi-chamber 69B and dry oxi-chamber 69C. However, it is to be understood that, if desired, the withdrawal of gasses from the outlet compartments can be facilitated by use of supplementary exhaust systems such as shown in U.S. Pat. No. 3,314,393.

In substance, the above defined structural configuration of the transition or isolation chamber 92 in this invention utilizes the orifice phenomena for control of gas flows, and thus conversely prevents cross-migration of interconnected atmosphere. Basically, since for a given reactor tube 52 constant values are presented by the dimensions of the orifice-sized clearances, the cross section of the compartments or chambers, the coefficient of discharge and the density of the flowing gasses, the orifice equation for flow through the clearances is reduced to

$$F = K \sqrt{\Delta P}$$

where F is the rate of flow in feet per second, K is a derivable constant characteristic of each of the orifice clearances employed in the buffer feed unit, and P is the pressure differential across the orifice-sized clearances.

Using the equation above, the control of gas flows in FIG. 15 for preventing cross-migration of atmospheres can be clarified, by reference to the previous qualifications that the

50 The foregoing isolation is normally employed for separation of processing atmosphere having some degree of tolerance for each other in minor concentrations.

In any event, and as noted previously, complete elimination of cross-migration between communicating reactive atmospheres is impossible to achieve. However, the concentration of the migrating gasses can be sequentially reduced to a level that its infusion into a second atmosphere can be restricted to tolerable levels. Thus in the embodiment above described, the noted wet oxi-film growing atmosphere (e.g., A69B in FIG. 15) upon entry in outlet compartment 92A will be diluted by an order of $10^2 : 1$ (e.g., a 1 percent by volume) from which it will diffuse into inlet compartment 92B (against the flow of gas therefrom) wherein it will be again diluted by an order of $10^4 : 1$ (e.g., about 0.0001 percent by volume), and then the final mixture (in inlet compartment 92B) will be exhausted into outlet compartment 92C. In turn, this gas will be further diluted by an order of $10^9 : 1$ by combination with the inflowing atmosphere A69C (e.g., the dry oxidizing atmosphere) to reduce its concentration to a level of about 10^{-4} percent by volume, which gas mixture is reduced within concentration limits whose diffusion into and against the inflowing atmosphere A69C can be safely tolerated since the first atmosphere A69B is further diluted by an order of $10^1 : 1$ within atmosphere to A69C to concentrations measurable only in parts per million. Conversely, as will be readily seen, a similar analysis applies equally to the cross-migration in FIG. 15 of atmosphere A69C into atmosphere A69B.

To illustrate the operation of the above described system as shown in FIG. 8, the following table is set forth to illustrate the environments and results of a specific operating system for processing of surface pre-conditioned silicon wafers supported on carriers traveling through the system at a rate of 1 inch per minute, with wet oxidation atmosphere comprised by volume of 1 percent oxygen and 99 percent water vapor or 0.92 mole fraction of water in oxygen. For the dry oxidation in chambers 69A and 69C, substantially 100 percent oxygen was employed.

TABLE 4

Chamber or compartment	Function	Atmosphere	Gas feed liters per min.	Temp., °C.	Film thickness, Å.
69	Pre-heat	O ₂	2	1,100	-----
69A	Dry oxidation	O ₂	4	1,100	600
69B	Wet oxidation	O ₂ +H ₂ O ¹	1	1,100	4,500
92A	Isolation	O ₂	-----	1,100	-----
92B	do	O ₂	4	1,100	-----
92C	do	O ₂	-----	1,100	-----
69C	Dry oxidation	O ₂	1	1,100	150
77	Output buffer	O ₂	2	-----	-----

¹ In general the atmosphere for wet oxidation can comprise, by volume, from about 1 to about 99% water vapor in oxygen, and preferably from about 40 to about 60% water vapor in oxygen.

EXAMPLE II

Silicon Oxide Deposition

This example, in conjunction with FIGS. 5 to 7, 9 to 16 and 17 describes a continuous processing system for depositing a silicon dioxide film on semiconductor substrates.

In its broadest concept, the system of this example comprises an environmentally controlled preheat station communicating with an environmentally controlled cooldown station, with a series of semiconductor substrates sequentially transported through the preheat, film deposition, and cooldown stations. In a particular application, the film deposition station comprises the formation of a glass coating on the surface of the substrates. For example, the film deposition station includes an atmosphere containing a metal halide of a glass forming metal taken from the groups III, IV and V of the periodic table, e.g., a silicon halide such as silicon tetrachloride, in combination with hydrogen and a third component which may be either oxygen or carbon dioxide.

In practice, a series of wafers which are appropriately supported on a flat carrier are sequentially passed in end-to-end relationship through a series of consecutive chambers defined by partitions each having an opening of a configuration conforming to the cross section of the carriers so as to provide a restricted clearance as the identically shaped carriers pass through the openings. The three chambers (e.g., preheat, processing and cooldown) are disposed within a reactor tube intermediate the ends thereof. Disposed within the tube adjacent the restricted opening at the inlet of the tube, is an ambient buffer chamber in which is introduced, at low pressures, a non-reactive gas such as nitrogen, helium, argon, forming gas and the like. Positioned within the tube between the ambient buffer chamber and the preheat station is a transition or isolation chamber constructed as described above.

Conversely, disposed adjacent the outlet of the reactor tube is a similar ambient buffer chamber separated from the cooldown station by an interposed second isolation chamber identical to the previously indicated one and also constructed as described above.

The isolation or transition chambers function to demarcate adjacent atmospheres into distinct and isolated environments whereby each environment is provided with its own distinct and controlled environment by the use of suitable flow and process control techniques.

With the continuous film deposition system of this invention, individual and constant environments are isolated from deleterious atmospheres which reduce the usual detrimental effects associated with environmental cycling associated with batch techniques.

Isolation of the processing atmospheres, by the indicated isolation chambers is accomplished, within the isolation chambers, by means of a series of counter-flowing gasses which comprise non-reactive gasses such as nitrogen, argon, helium and the like. Also included in this system is a suitable heater, e.g., a resistance heater or an inductance heater, disposed about the reactor tube for heating and maintaining the transported wafers at operating or processing temperatures.

The process involved in the operation of the above system can be defined, in substance, as introducing semiconductor

wafers through an isolation chamber into a preconditioning chamber in which the wafers are pre-heated to operating temperatures in an atmosphere of a non-reactive gas, as indicated above, which is compatible with ambient atmospheres and the reaction gasses in the system, and while the wafers are maintained at operating temperatures, immediately and sequentially passing them through the processing chamber containing a film-forming gas from which the wafers pass through a cooldown chamber of the indicated non-reactive gasses wherein the wafers are cooled to below reactive temperatures and from which the wafers pass through a second isolation chamber into an ambient buffer chamber from which they emerge, from the reactor tube into ambient atmospheres.

The foregoing process is characterized in that a series of semiconductor wafers are continuously passed in linear array through the processing chambers with substantially 100 percent separation maintained between the preheat and cooldown chambers on the one hand, and external ambient atmospheres on the other hand.

Also the process is further characterized in that the various processing and isolating atmospheres are maintained at substantially constant concentration and environment whereby each respective atmosphere concentration level and pressure is non-fluctuating. In essence, the invention processes the semiconductor material sequentially at common ambients, such as temperature, which eliminates the deleterious effects produced by switching gas flows, etc. and temperature recoveries which are noted for examples and which introduce transients in an otherwise undisturbed system. Secondly, each chamber provides its own environment which is stable over long periods compared with the processing time of the material in that chamber.

Also with reference to the drawings, as shown in FIG. 5, again a continuous tier of graphite wafer carriers 50 having a rectangular configuration are transported in end-to-end relationship by a feed mechanism generally indicated by the numeral 51 into a quartz processing or reactor tube 52 disposed within RF heating coils 54 optionally enclosed in a furnace enclosure 55 of the usual construction.

The carriers 50 are fabricated of any suitable material, such as quartz or graphite, which is compatible with the semiconductor substrates which are to be supported thereon. In general, the material of carriers 50 will generally determine the type of heater coils employed in conjunction with reactor tube 52. In a system employing quartz carriers, the heating coils would generally comprise resistance coils, and conversely, the use of graphite in the construction of the carriers permits the use of either resistance coils or induction heater coils in the system.

The processing or reactor tube 52 shown is of a rectangular configuration having an internal height of about 33 mm. and an internal width of 89 mm. with an overall length of about 78 inches subdivided into appropriate chambers to be described below.

A typical carrier 50 adapted for processing of wafers of 1½-inch diameter is shown in FIG. 17. The particular carrier shown has a generally square configuration having a width which normally spans across the internal width of processing tube 52 to enable the sides of tube 3 to assist as guides during transport of the carrier therethrough; and to this end, carriers 50 were fabricated in a 3.45 square inch configuration. Although a carrier is shown with a square planar configuration, it is to be understood that other configurations may be employed, particularly with respect to opposite end portions in the longitudinal extension of the carriers. Thus, for example, as shown in FIG. 6A, it is preferred that the ends 60 and 61 of the carriers be configured in a construction complementary to adjacent ends 60A and 61A respectively, of abutting carriers so as to define a continuous tier of carriers with a substantially uninterrupted extension during transport through processing tube 52.

Referring to the specific configuration of FIG. 6, the carrier thickness is 0.5 inches having skids or rails 62 of about 0.015 inches depending from the bottom of the carrier to provide an overall height of about 0.515 inches. Such a dimensioned carrier provides a free-flow cross section of 17.7 sq. cm. in the unbaffled portions of the tube. Skids 62 are provided to reduce friction as the carriers are pushed in end-to-end fashion in sliding relationship across the bottom of the processing tube 52.

In addition, the top surface of carriers 50 is recessed at 63 a sufficient depth to seat and maintain therein a semiconductor wafer 64 of silicon and the like, for multistage processing through processing tube 52. In the preferred form, the top surface of wafer 64 will be substantially flush with the top surface of carrier 50 while seated therein. Although the specific carrier shown in FIG. 6 is provided with a single recess for support of a single wafer, it will be apparent that a carrier 50B can be provided with a multiplicity of recesses 63B (as in FIG. 7) for support of a like number of smaller dimensioned wafers 64B (e.g., of about 1.30 inch diameter) for transport through processing tube 52.

Referring back to FIG. 5, the feed station 51 for carriers 50, each supporting a wafer 64, comprises an endless conveyor 65 which carry the carriers to the drive units 66. The drive units 66 comprise two side-gripping endless belts which contact the carriers 50 on their sides to propel them. Transfer plate 67 is provided with side-guides 67A for feeding the carriers 50 in end-to-end relationship into and through processing tube 52.

Basically, the reactor tube is subdivided into an ambient buffer chamber or zone 69, an isolation chamber 70, a preheat chamber 71, a film deposition chamber 71A, a cooldown chamber 71B, a second isolation chamber 73, and a second ambient buffer chamber 77.

The buffer zone 69, of about 5 inches in length, is defined by partitions 78 and 79 with partition 78 extending toward the bottom of reactor tube 52 a distance providing about 0.25 inches clearance with the top of a tier of carriers 50. Buffer zone 69 forms a preliminary barrier with ambient atmospheres and is maintained with a non-reactive atmosphere of about 0.003 p.s.i.g. by introducing therein through a circumferential slot 80A of a closed end nozzle 80 (of about 5 mm. ID) a suitably controlled flow of gas such as nitrogen, helium, argon, forming gas and the like. Generally however, for the instant processing system, the pressure in the ambient buffer chamber may extend from about 0.0001 to about 0.005 p.s.i.g. and preferably from about 0.001 p.s.i.g. to about 0.003 p.s.i.g. As indicated, nozzle 80 is a closed end structure having a configuration such as shown in FIG. 12 with an ID of about 5 mm., and a 250° circumferential slot (e.g., H1) of about 0.55 mm. to effect a better distribution of gasses in the chamber and to prevent direct impingement of the gasses on the wafers 64.

The tier of carriers 50 traveling at a rate of 1 inch per minute passes out of the ambient buffer chamber 69 into and through the critical isolation chamber 70 defined within the aforesaid partition 79 and the partition 81 with each of partitions 79 and 81 extending downwardly in reaction tube 52 a distance defining a 0.015-inch clearance with the top surfaces of the tier of carriers 50, e.g., to within 0.530 inches of the bottom of reaction tube 52. To provide an increased coefficient of discharge for gas flow through the restricted clearances between the carriers 50 and the partitions 79 and 81, laterally extending flanges 82 are provided at the bottom of each of partitions 79 and 81. In addition, the flanges form an elongated tubular passage which overlaps the juncture line of adjoining carriers and thus insures against any interstitial leaks between such carriers or by depression therebetween as may be caused by rounded top edges of adjacent ends. Although each of the aforescribed partitions is shown as a continuum of the reaction tube 52 in practice, each of such partitions (as well as baffles to be subsequently described) are distinct units welded to the reaction tube by conventional glass working techniques. However, it is noted that where flanges are provided on the various partitions they are preferably and conveniently formed thereon as continuums thereof.

Isolation chamber 70 forms a buffer feed zone between the ambient buffer chamber 69 and the preheat chamber 71 to maintain the integrity of the reactive atmosphere therein. To provide the degree of isolation accorded by the invention, the isolation chamber is subdivided into a series of alternate inlet and outlet compartments into which a non-reactive gas, such as indicated above, is respectively introduced and withdrawn. For the particular isolation obtained, the isolation chamber is subdivided into an inlet compartment 70A, and outlet compartment 70B, a second inlet compartment 70C, a second outlet compartment 70D, and a third inlet compartment 70E, each about 1 inch in length.

The inlet compartment 70A of about 1 inch in length is defined between the flanged partition 79 and a baffle 85 into which a non-reactive atmosphere is maintained at a pressure of about 0.003 p.s.i.g. by introducing therein a non-reactive gas (such as nitrogen, argon, helium, forming gas and the like) through a double slotted closed end nozzle 86 of 5 mm. ID having a general configuration such as shown in FIG. 11. Generally, this pressure may extend from about 0.002 p.s.i.g. to about 0.05 p.s.i.g. However, in all cases, the pressure P70A (see FIG. 16) in inlet compartment 70A will be greater than the pressure P69 in buffer chamber 69 and with a pressure differential $\Delta P1$ therebetween of at least 0.001 p.s.i.g. In the specific embodiment described, these nozzles have an ID of about 5 mm. with two diametrically opposed 135° circumferential slots having a width of about 9 mm. (e.g., H2). Generally these slots are positioned so as to laterally discharge the non-reactive gas toward the distal ends of the reaction tube 52. Also the closed end of the nozzles prevents direct impingement of gasses on the wafers traveling through the zone. In a preferred construction, baffle 85 extends to within 0.020 inches of the top of carriers 50 to define a restricted clearance with the carriers larger than the corresponding clearance formed by partition 79. As will be understood, since the flow in the orifice equation is directly proportional to the orifice area, the flow (under like conditions) will be greater in a larger orifice than that in a smaller orifice. The significance of this becomes evident upon consideration that the broad pressure range in the succeeding outlet compartment 70B is of the order of about 0.001 to about 0.03 p.s.i.g. and preferably from about 0.001 to about 0.003 p.s.i.g. with a pressure differential $\Delta P2$ of at least 0.001 p.s.i.g.

Generally as shown in FIG. 16, the pressure differentials $\Delta P1$ and $\Delta P2$ are coordinated with each other and with other pressure differentials (as below described) in the remaining compartments and chambers of the reaction tube 52 so that there will be (a) a positive flow of gas F2 from inlet compartment 70A to outlet compartment 70B, (b) zero flow or a posi-

tive gas flow $F1$ from inlet compartment 70A to the ambient buffer chamber 69, and (c) wherein gas flow $F2$ is greater than gas flow $F1$. Also, as shown in FIG. 16, the relationship of the pressure differentials $\Delta P1$ and $\Delta P2$ are maintained by providing a pressure $P70A$ (in inlet compartment 70A at a level (a) equal to or greater than the pressure $P69$ (in ambient buffer chamber 69) and (b) greater than the pressure $P70B$ (in outlet compartment 70B).

The outlet compartment 70B (of isolation chamber 70) is about 1 inch in length and is defined by the above indicated baffle 85 (0.02 inches clearance) and baffle 87 extending in reaction tube 52 to within about 0.030 inches of the top of flowing tier of carriers 50. A pressure $P70B$ of about 0.002 p.s.i.g. is maintained in outlet compartment 70B by suitable exhausting via the outlet tube 88 which exhausts the gas under the sole impetus of flows into outlet compartment 70B. In general, the outlet tube is open-ended and of about 14 mm. ID. However, as indicated above, positive exhaust means may be employed to assist the exhausting of gasses if desired and where the requirements of a processing system require it.

Also, it is noted that the increased clearance of baffle 87 relative to carriers 50 provides an increased orifice area through which, as indicated above, the rate of flow is directly proportional.

A second like baffle 87A downstream in reaction tube 52 defines with the preceding baffle 87 a second inlet compartment 80C of about 1 inch in length. Baffle 87A is for all practical purposes, substantially identical to baffle 87 so that both define correspondingly like clearances related to the traveling tier of carriers 50. A non-reactive gas (generally the same as employed in preceding sections of the tube) is introduced through an inlet nozzle 86A, having the same general configuration as nozzle 86 to maintain a pressure $P70C$ substantially higher than pressures $P69$ and $P70A$ in respectively, buffer chamber 69 and inlet compartment 70A, as for example, about 0.006 p.s.i.g. Generally, pressure $P70C$ will be maintained in the range of about 0.004 to about 0.1 p.s.i.g., and preferably from about 0.004 to about 0.01 p.s.i.g. However, as indicated, pressure $P70C$ will be maintained at a level substantially higher than pressure $P69$ and $P70A$. Conversely, this pressure $P70C$ will be substantially higher than the pressure $P70B$ so that a positive gas flow $F3$ will exist from inlet compartment 70C into outlet compartment 70B through the restricted orifice-type clearance defined by baffle 87 relative to the surface of the carriers 50.

The second outlet compartment 70D of about 1 inch in length, is defined by baffles 87A and 85A with the latter baffle 85A being dimensioned substantially identical to the aforescribed baffle 85 with a corresponding like clearance with the carriers 50. In general, the gasses in outlet compartment 70D are withdrawn therefrom via outlet tube 88A to maintain a pressure $P70D$ substantially lower, e.g., about 0.004 p.s.i.g. than pressure $P70C$ in the preceding inlet compartment 70C. For all practical purposes, the pressure $P70D$ in outlet compartment 70D may be equal to the pressure $P70B$ in the previous outlet compartment 70B, but in general this pressure level may extend in the same general range, e.g., about 0.001 to about 0.03 p.s.i.g., and preferably about 0.001 to about 0.003 p.s.i.g. As can be seen, in compliance with the orifice equation, the correlation of pressures in respective inlet and outlet compartments 70B and 70D, in conjunction with the restricted orifice-type clearance of baffle 87A the flow of gas $F4$ will be from inlet compartment 70C into outlet compartment 70D.

The configuration of isolation chamber 70 is completed by the additional inlet compartment 70E defined between baffle 85A and the flanged partition 81. In general, the clearance of flange 82 of partition 81 with the surfaces of carriers 50 will be of the same order as that of the corresponding flange on partition 79. Similarly the pressure $P70E$, in inlet compartment 70E will be in the same ranges specified for pressure $P70A$ in the first inlet compartment 70A and normally both pressure $P70A$ and $P70E$ will be at the same level so that a symmetrical

distribution of pressures will be maintained in isolation chamber 70 as follows

$P69 < P70A > P70B << P70C >> P70D < P70E > P71$
where

5 $P70A = P70E$ and
 $P70B = P70D$

The pressure $P70E$ in inlet compartment 70E is maintained by appropriate control of the injection of the non-reactive gas 10 into the compartment via the inlet nozzle 86B having the same general configuration of previously noted inlet nozzles 86 and 86A shown in more detail in FIGS. 11 and 14. As will be noted, for convenience and simplicity, the non-reactive gas employed in each of inlet compartments 70A, 70C and 70E may be identical. However, as will be obvious, if desired or for 15 whatever purpose required different non-reactive gasses may be employed in these various inlet compartments of isolation chamber 70.

As the tier of carriers 50 emerges from the last inlet compartment 70E of isolation chamber 70, they enter into the 20 non-reactive preheat chamber 71 disposed within the heating coil 53 for heating the supported wafers 64 to processing temperatures, e.g., about 800° C. for silicon, with it being understood that the temperatures may extend from a preferred range of about 750° to about 900° C. to a general range of 25 about 600° to about 1,300° C.

In this process for a carrier travel rate of about 1 30 inch/minute through the preheat chamber 71, this chamber has a length of about 25 inches as defined between flanged partitions 81 and 91 each extending to a level of about 0.015 35 inches above the surface of carriers 50 to form a restricted orifice-size opening such as that previously indicated above. It is noted that the length of preheat chamber 71 is not necessarily restricted to the specific dimensions indicated therefor. In 40 practice, the length of the preheat chamber can be readily varied, but as a general rule it will be correlated to the rate of carrier travel and the temperature required to bring the semiconductor wafers to processing temperatures. Conversely, where the length of preheat chamber 71 is prefixed, it will 45 be readily seen that the wafers can be brought to processing temperature by suitable adjustments in the rate of carrier travel and/or in the temperature generated via the heating coil 53 which for varying temperature profiles, may be sectionalized and individual units separately controlled.

Normally the environment of preheat chamber 71 will be 50 selected so as to be compatible with the film-forming atmosphere in the succeeding processing chamber 71A defined between partitions 91 and 91A. For example where the film-forming gas is employed in conjunction with an inert carrier gas, the gasses employed in preheat chamber 71 may comprise the same gasses used for the carrier gas in processing chamber 71A. Similarly where hydrogen constitutes part of the film-forming gas (as in U.S. Pat. No. 3,331,716) in processing chamber 71A, the gas employed for the atmospheres in preheat chamber 71 may be hydrogen. In a specific application, utilizing a mixture of gaseous silicon tetrachloride, hydrogen and oxygen, hydrogen was employed for the atmosphere in preheat chamber 71 in the general range of about 0.001 to 60 about 0.005 p.s.i.g. and preferably from about 0.002 to about 0.005 p.s.i.g. However the pressure $P71$ will be maintained at a level below the pressure $P70E$ in the preceding inlet compartment 70E (of the isolation chamber 70) and coordinated therewith so that there will be either a zero flow $F6$ between 65 inlet compartment 70E and preheat chamber 71 or a positive flow $F6$ from inlet compartment 70E into preheat chamber 71.

The indicated pressure and environment in preheat chamber 71 is obtained by introducing and withdrawing hydrogen via 70 respective inlet and outlet tubes 89 and 90 at a controlled rate which will also provide a substantially quiescent preheat atmosphere having a feed rate from inlet tube 89 to outlet tube 90 of about 4 liters per minute (e.g., about 0.226 liters/minute/sq. cm. of cross section), and normally from about 1 to about 20 liters per minute (e.g., about 0.565 to

about 1.13 liters/minute/sq. cm. of cross section of the chamber).

The construction of inlet and outlet tubes 89 and 90 are similar to the corresponding inlet and outlet tubes previously described. Specifically, the inlet tube 89 will be substantially identical and will have the general configurations shown in FIGS. 12 and 13. However, as shown in FIG. 17, the discharge of hydrogen from the orifice of inlet tube 89 will normally be directed laterally against partition 81 to effect a better distribution of hydrogen in preheat chamber 71, and as previously indicated, to prevent direct impingement of the hydrogen on the wafers 64.

After the preheating stage, the moving tier of carriers 50 emerges from the preheat chamber 71 and passes through the reaction chamber 71A of about 8 inches in length in which is maintained a substantially quiescent environment of hydrogen and a film growing gas flowing from its inlet tube 89 to outlet tube 90 at a feed rate not greater than about 20 liters per minute (e.g. about 1.13 liters/minute/sq. cm. of cross-section), and preferably from about 8 to about 12 liters per minute at pressures not exceeding 0.05 p.s.i.g. and preferably 0.001 to 0.005 p.s.i.g. In general, the rate of flow will be sufficient to maintain a substantially constant proportional concentration of the hydrogen and film growing gas. Various film growing atmospheres may be employed in processing chamber 71A. This feed rate of atmosphere is equivalent to about 0.45 to about 0.66 liters/minute/sq. cm. of cross-section of the chamber.

For example, the film forming atmosphere may contain a metal halide of a glass-forming metal taken from the groups III, IV and V of the periodic table, either alone or in conjunction with ozone as in U.S. Pat. No. 3,228,812. Alternatively, an organic siloxane may be employed in conjunction with an inert carrier gas, such as nitrogen, within the film deposition chamber 71A with an optional step of oxidation (e.g. within cool-down chamber 71B) included at the end of the film deposition to eliminate any silicon carbide that may have formed during film deposition.

Also the film forming atmosphere may comprise an inert gas plus water vapor and a volatilized and hydrolizable halide of a glass-forming metal selected from the groups III, IV and V of the periodic table.

In the preferred embodiment as used in the specific example set out below, the film-forming atmosphere can comprise a three component mixture wherein the first component is hydrogen, the second component may be either oxygen or carbon dioxide, and the third component may be either an organic silicate, a silicon halide or an alkoxy-silane. A typical mixture of this film-forming atmosphere will comprise, by volume, about 92 to about 99 percent hydrogen, about 0.92 to about 1.2 percent silicon tetrachloride, and about 0.4 to about 0.6 percent oxygen.

Where the film-forming atmosphere comprises ozone, a vaporous halide of a glass-forming metal taken from the groups III, IV AND V of the periodic table, substantially any metal halide may be employed therefrom and the metal selected may be determined, in part at least, by the specific film characteristics desired. In operation, the reacting materials, such as silicon tetrachloride and ozone are preferably introduced into the reaction zone in the dilute vapor phase. Since the ozone is formed in commercial ozonizers, a resultant mixture of oxygen and ozone will result and which mixture may be introduced directly into the processing chamber 71A. The silicon metal halide may be diluted by merely passing argon or other inert gasses into contact therewith, such as bubbling argon gas through the liquid silicon chloride. It is noted that with the employment of oxygen and ozone in the processing chamber 71A, and the reliance on ozonolysis for effecting the film deposition, the atmospheres employed in the preheat chamber 71 will be the non-reactive gasses such as nitrogen, helium, argon and the like, and preferably will consist of the same carrier gas employed in processing or film deposition chamber 71A.

Similarly, the preheat chamber 71 will also employ an inert gas such as nitrogen, helium and argon when the film-forming atmosphere (in processing chamber 71A) comprises an inert atmosphere, water vapor and a volatized hydrolyzable halide 5 of a glass-forming metal selected from groups III, IV and V of the periodic table as outlined in U.S. Pat. No. 3,316,661. A relatively large number of materials may be used to produce glass or glass-like films. For example, halides of group IV metals may be used, as well as halides of such metals in the IIIrd group such as boron, aluminum, gallium and indium. Of the group V metals, halides of phosphorous, arsenic and tin may also be employed. Mixtures of these indicated materials 10 may also be employed. However, it is to be understood that the term "halide" is employed herein in a generic sense to include not only halogen salts of metal but other halogen-bearing compounds, such as covalent compounds exemplified by silicon and germanium tetrachloride or tetrabromide. In 15 operation, the general outlines for parameter control set forth in the indicated U.S. Pat. No. 3,316,661 may be employed.

Similarly, a non-reactive atmosphere, such as nitrogen, helium, argon and the like will be employed in the preheating chamber 71 where the deposition of a silicon oxide film is obtained by pyrolytic decomposition of organic siloxanes or 20 reduction of a gaseous semiconductor compound in the proximity of a semiconductor body (such as set forth in U.S. Pat. No. 3,089,793). In general, the same control of process parameters set forth and outlined in this patent are applicable for control of the film-forming operation effective in 25 processing chamber 71A of the reactor tube 52.

In general, the semiconductor substrate would be transported into vapors of an organic siloxane compound at a temperature below the melting point of the semiconductor but above that at which the compound decomposes, so that an 30 inert adherent coating of silicon dioxide is formed on the substrate surface. The siloxanes comprise a large group of organic derivatives of silicon from which silicon dioxide can be obtained by thermal decomposition. The substances may be considered to be derived from the silicon halides, such as silicon tetrachloride through replacement of the halogen by oxygen groups having the general composition Si—O—R where R can be alkyl, aryl, alkaryl, aralkyl, or mixtures thereof. Examples 35 of such compounds include tetraepoxysilane, ethyltriepoxysilane, amyltriepoxysilane, vinyltriepoxysilane, phenyltriepoxysilane, dimethyltriepoxysilane, diphenyltriepoxysilane, dimethyl-dimepoxysilane, ethylsilicate, methylsilicate and the like.

It is noted herein that it is to be understood that the term "semiconductor" material as utilized herein is considered generic to germanium, silicon, germanium-silicon alloy, indium-antimonide, gallium-antimonide, aluminum-antimonide, indium-arsenide, gallium-arsenide, gallium-phosphorous alloys and indium-phosphorous alloys and the like, and is employed to distinguish these semiconductors from metallic oxide semiconductors such as copper oxide and selenium.

As indicated above, the preferred method involves the use 55 of a three component mixture from which the silicon dioxide is deposited on the surface of a semiconductor substrate, wherein the first component comprises hydrogen, the second component comprises either oxygen or carbon dioxide and the third component comprises a thermally decomposable compound from which silicon oxide is obtained by thermal decomposition, such as for example, methylsilicate, ethylsilicate, alkoxy-silanes, and silicon halides, wherein the mixture of the 60 components is formed externally of the processing chamber 71A and introduced therein via its inlet nozzle 79. The silicon compound may be a silicon-hydrogen compound which is oxidized by the oxygen to result in the formation of silicon oxide. The oxygen may also be added in the form of a compound, for 65 example, carbon dioxide, which has an oxidizing effect on the silicon-hydrogen compound. Preferably the silicon compound is a silicon-halogen compound, such as silicon tetrachloride. In the processing chamber 71A, hydrogen reacts with the oxygen containing compound to form water, which in turn, reacts with the silicon-halogen compound to produce silicon 70

dioxide. Optimally, oxygen is preferably added in the form of the gas itself since this reacts with hydrogen to form water vapor at the processing temperatures which results in the formation of silicon dioxide on the surfaces of the semiconductor substrates.

After passage of the substrates through the film deposition chamber 71A, the carrier supported substrates enter the cool-down chamber 71B (defined between partitions 91A and 79A which is provided with a flow of a non-reactive atmosphere via its inlet nozzle 89 and outlet nozzle 90. In general, the atmosphere of cool-down chamber 71B will normally be comprised of inert atmospheres such as nitrogen, helium, argon and the like, where such gasses are employed as carrier gasses in film deposition chamber 71A. Conversely where hydrogen is employed as a component of the film-forming atmosphere in processing chamber 71A, hydrogen may also be employed as the atmosphere within cool-down chamber 71B.

After passage through the cool-down chamber 71B of about 25 inches in length, the carriers 50 (with the wafers supported thereon cooled to below reactive temperatures) enter and pass through a second isolation chamber 73 which (although defined between partitions 79A and 81A) is, for all practical purposes, identical to the previously described isolation chamber 70. Since these two isolation chambers 70 and 73 are identical, and since the correlation of the pressures in the various inlet compartments 73A, 73C and 73E and outlet compartments 73B and 73D are identical to the pressures in the corresponding inlet and outlet compartments of isolation chamber 70, no extended description is necessary. If required, such details may be easily ascertained by reference to the above description of corresponding portions of isolation chamber 70. In general, the pressure P71B in cool-down chamber 71B will be correlated to the pressure P73A in inlet compartment 73A (of isolation chamber 73) so that there will be zero flow therebetween or a positive flow from inlet compartment 73A into cool-down chamber 71B.

The basic function of isolation chamber 73 is for the use of non-reactive gasses to effect critical isolation between film deposition chamber 71A and external ambient atmospheres.

As the carriers 50 emerge from the isolation chamber 73 they pass into and through an outlet buffer chamber 77 (defined between partitions 81A and 78A) to discharge across a transfer table 98 between conveyor belt 99. As shown, the outlet buffer chamber 77 is about 5 inches in length and is provided with a non-reactive atmosphere via its inlet nozzle 89 with discharge of gasses effected into ambient atmosphere through the restricted openings defined by end partition 78A and the surface of carriers 50.

In order to maintain the integrity of the atmospheres in the respective preheat, processing and cool-down chambers 71, 71A and 71B, isolation chambers 70 and 73 are interposed between these chambers and ambient atmospheres in accordance with our aforesaid description thereof. As described above, one of these isolation chambers is interposed between the preheat chamber 71 and ambient atmospheres (including inlet buffer chamber 69) and a second isolation chamber 73 is interposed between the cool-down chamber 71B and external ambient atmospheres (including outlet buffer chamber 77). Each of the isolation chambers 70 and 73 is subdivided into a series of alternate inlet and outlet compartments, comprising three inlet compartments and two outlet compartments with the two end-most inlet compartments disposed adjacent the ambient buffer chambers and a corresponding one of the preheat and cool-down chambers 71 and 71B.

In operation, with reference to isolation chamber 70, a non-reactive gas, from a suitable source not shown, is introduced into inlet compartments 70A, 70C and 70E through respective inlet nozzles 86, 86A and 86B at a pressure level above that of the atmospheres in adjoining chambers, e.g. inlet buffer chamber 69 and preheat chamber 71 associated with isolation chamber 70, and outlet buffer chamber 77 and cool-down chamber 71B associated with isolation chamber 73, with the inlet compartment 70C pressurized to a level above that in the

end-most inlet compartments 70A and 70E. Gasses from outlet compartments 70B and 70D are exhausted by respective discharge outlets 88.

With the pressures in the processing chambers and the various inlet compartments at higher pressure levels than that in the outlet compartments 70B and 70D, no positive exhaust system is necessary for withdrawing gasses from outlet compartments 70B and 70D via outlets 88. The exit of gasses from the outlet compartments 70B and 70D can be exhausted by the sole impetus of the gas flows from inlet compartments 70A, 70C and 70E, alone or in conjunction with the adjacent pressurized gas flow in either one of the processing chambers adjacent the isolation chamber. However, it is to be understood that, if desired, the withdrawal of gasses from the outlet compartments can be facilitated by the use of supplementary exhaust systems such as shown in U.S. Pat. No. 3,314,393.

In substance, the above defined structural configuration of the isolation chamber utilizes the orifice phenomena for control of gas flows and thus conversely prevents cross-migration of interconnected atmospheres. Basically, since for a given feed unit constant values are presented by the dimensions of the orifice-size clearances, the cross-sections of the compartments or chambers, the coefficient of discharge and the density of the flowing gasses, the orifice equation for flow through the clearances is reduced to

$$F = K \sqrt{\Delta P}$$

where F is the rate of flow in feed per second, K is a derivable constant characteristic of each of the orifice clearances employed from the buffer feed unit, and ΔP is the pressure differential across the orifice clearances.

For convenience, the various pressures comprehended in the various compartments of the isolation chambers (and in respective inlet buffer and preheat chambers 69 and 71) are identified and set forth in the following table.

TABLE 5

	Atmosphere	Chamber or Compartment	Pressure
45	A69	69	P69
Non-reactive	70A	P70A	
Non-reactive	70B	P70B	
Non-reactive	70C	P70C	
Non-reactive	70D	P70D	
Non-reactive	70E	P70E	
471	71	P71	

with the above pressures correlated to each other in accordance with the following relationship wherein pressure P70C (in central inlet compartment 70C) represents the highest pressure level employed; $P69 \leq P70A > P70B < P70C > P70D < P70E \geq P71$, where P69 and P71 are the respective pressures in inlet buffer chamber 69 and preheat chamber 71.

In a preferred application for maximum isolation of the atmospheres in inlet buffer chamber 69 and preheat chamber 71, for example, the various pressures are correlated in the following relationships:

$$P70A \geq P69$$

$$P70E \geq P71$$

$$P70C > P69 \text{ and } P71 \text{ and } P70E$$

$$P70B < P70A + \frac{1}{2} P70C$$

$$P70D < P70E + \frac{1}{2} P70C$$

Using the orifice equation noted above to the gas flow between atmosphere A69 and inlet compartment A70 will conform to the equation

$$F = K1 P70A - P69 = K1 P1$$

wherein P70A, as indicated above, may be equal to or greater than P69 so that gas flow therebetween will be zero or in a positive direction from compartment 70A to atmosphere A69 (in inlet buffer chamber 69) as indicated by the arrow F1.

The gas flows F_2 and F_3 between respective pairs of compartments 70A and 70B and compartments 70B and 70C conform to the corresponding equations

$$F_2 = K_2 \sqrt{P_{70A} - P_{70B}} \quad F_3 = K_3 \sqrt{P_{70C} - P_{70B}}$$

$$F_2 = K_2 \sqrt{\Delta P_2} \quad F_3 = K_3 \sqrt{\Delta P_3}$$

wherein both pressures P_{70A} and P_{70C} in respective compartments 70A and 70C are greater than pressure P_{70B} in outlet compartment 70B so that gas flow will be in positive directions from compartments 70A and 70C into compartment 70B as indicated by the arrows F_2 and F_3 . Also, in view of the additional requirement that the positive pressure P_{70C} in compartment 70C is at a higher level above the positive pressure P_{70A} in compartment 70A, the gas flow F_3 from compartment 70C into compartment 70B will be greater than the gas flow F_2 from compartment 70A into compartment 70B to thus minimize (to non-measurable magnitudes) cross-migration of gasses between inlet compartments 70A and 70C.

The gas flow relationship for gas flows F_2 and F_3 apply similarly to respective gas flows F_5 (between compartments 70E and 70D) and F_4 (between compartments 70C and 70D) which conform to the equations

$$F_5 = K_5 \sqrt{P_{70E} - P_{70D}} \quad F_4 = K_4 \sqrt{P_{70C} - P_{70D}}$$

$$F_5 = K_5 \sqrt{\Delta P_5} \quad F_4 = K_4 \sqrt{\Delta P_4}$$

wherein the pressures are selected and correlated so that there is a positive gas flow F_5 from compartment 70E into compartment 70D as indicated by the arrow F_5 , and a positive gas flow F_4 from compartment 70C into compartment 70D as indicated by the arrow F_4 .

further diluted by an order of $10^4 : 1$ to form a third gas mixture D_3 wherein D_3 represents the third dilution of atmosphere A69 to a concentration level of less than 10^{-5} percent. In turn, the gas mixture D_3 (in compartment 70C) flows into the outlet compartment 70D wherein it is mixed with the inflowing gasses from inlet compartment 70E to form a fourth mixture D_4 in which the atmosphere A69 is further diluted by an order of $10^6 : 1$ to a concentration of 10^{-5} percent. Similarly this gas mixture D_4 (representing the fourth dilution of atmosphere A69) diffuses against the inflowing gasses from compartment 70E into this compartment wherein it is again diluted by an order of $10^2 : 1$ to a concentration level of 10^{-7} percent which forms a gas mixture D_5 in which the concentration limits of A69 are at a level which, upon migration of gas mixture D_5 into atmosphere A71 (of preheat chamber 71, can be safely tolerated since therein the first atmosphere A69 is still further diluted by an order of $10^4 : 1$ within atmosphere A71 to concentration of about 10^{-8} percent. Conversely, as can be readily seen a similar analysis applies equally to the cross-migration in FIG. 16 of atmosphere A71 into atmosphere A69.

To illustrate the operation of the above described system of this example, the following table is set forth to illustrate the environments and results of a specific operating system for processing of surface preconditioned silicon wafers supported on the carriers traveling through the system at a rate of 1 inch per minute and utilizing an atmosphere comprised of hydrogen containing 0.5 vol. percent silicon tetrachloride and 1.0 vol. percent oxygen for silicon oxide deposition.

30

TABLE 6

Chamber or compartment	Function	Atmosphere	Gas feed liters per min.	Temp., °C.	Film thickness, A.
69	Inlet buffer chamber	N_2	4	Ambient	
70A	Isolation	N_2	2		
70B	do	N_2	4		
70C	do	N_2			
70D	do				
70E	do	H_2	10		
71	Preheat	H_2	2	800	
71A	Silicon oxide deposition	$H_2 + SiCl_4 + O_2$	10	800	+6,400
71B	Cool-down	H_2	2	800	
73A	Isolation	N_2	2		
73B	do				
73C	do	N_2	4		
73D	do				
73E	do	N_2	2	150	
77	Output buffer chamber	N_2	4	100	

Similarly the relationship for gas flow F_1 applies in like manner to the gas flow F_6 between compartment 70E and preheat chamber 71 which conform to the equation

$$F_6 = K_6 \sqrt{P_{70E} - P_{71}} = K_6 \sqrt{\Delta P_6}$$

wherein the pressures P_{70E} and P_{71} , or respectively compartment 70E and preheat chamber 71, are correlated so that there is zero flow or a positive flow from compartment 70E into preheat chamber 71. Also, as indicated above, complete elimination of cross-migration between communicating atmospheres is practically impossible to achieve. However the concentration of migrating gasses is sequentially reduced to a level that its infusion into a second atmosphere is restricted to unmeasurable concentrations e.g. parts per billion or less.

Thus in the embodiment described in conjunction with FIG. 16, the atmosphere A69 (in inlet buffer chamber 69 will diffuse against a back pressure of compartment 70A wherein it will be diluted by an order of $10^2 : 1$ to a concentration level of about 1 percent by volume wherein the final mixture will be represented as an atmosphere D_1 which represents the first dilution of atmosphere A69. From compartment 70A the atmosphere or gas mixture D_1 is forced into outlet compartment 70B where it is blended with the inflowing gas from inlet compartment 70C which results in a further dilution of atmosphere A69 in the gas mixture D_1 by an order of $10 : 1$ to form a second mixture D_2 wherein the concentration of atmosphere A69 is about 0.1 percent by volume. This second gas mixture D_2 will diffuse against the inflowing gasses from inlet compartment 70C wherein the atmosphere A69 will be

50

EXAMPLE III

Epitaxial Deposition

This example, in conjunction with FIGS. 9-16 and 18, describes a continuous processing system for epitaxial deposition of material on a semiconductor substrate.

55 This example comprehends a continuous epitaxial deposition system, which, in its broadest concept, comprises an environmentally controlled preheat station communicating with a reactive atmosphere containing an epitaxial film growing atmosphere, which optionally may also include a conductivity-type determining impurity. This reactive atmosphere in turn communicates with an environmentally controlled cool-down station with a series of semiconductor substrates sequentially transported through a preheat, reactive atmosphere and cool-down stations.

60 In one application, the epitaxial deposition may be effected by means of a flowing atmosphere which may be comprised of the gaseous mixture of hydrogen and a halide compound of the appropriate semiconductor material (for example, silicon tetrachloride) which passes over the semiconductor substrates (as for example, silicon wafers) at pre-determined temperatures for a period of time sufficient to grow an epitaxial layer of the source material in the atmosphere. For example, the epitaxial film growing atmosphere may normally be comprised of a decomposable vapor source of the same semiconductor material forming the composition of the substrate on which

70

75

the film is grown. The terms "thermally decomposable", "thermal decomposition" and the associated deposit of a product of decomposition, as used herein, are intended to be generic to the mechanisms of heat-cracking, as for example, the decomposition of silicon tetrachloride and the liberation of silicon atoms through the action of heat alone and the mechanism of high temperature reactions wherein the high temperature causes interaction between various materials with liberation of specific materials or atoms, as for example, in the reduction of silicon tetrachloride or trichlorsilane by hydrogen. Optionally, as indicated above, the epitaxial film growing atmosphere may also include a conductivity-type determining impurity which may be selected from groups IIIB and VB (e.g. arsine, phosphine, stibine, diborane and the like). As will be understood, where a conductivity-type determining impurity is included in the epitaxial film growing atmosphere, the epitaxial film matrix will be grown on the substrate containing the active impurity.

In practice, a series of wafers which are appropriately supported on flat carriers and are sequentially passed in end-to-end relationship through a series of consecutive chambers defined by partitions each having an opening of a configuration conforming to the cross-section of the carrier so as to provide restricted clearances as the identically shaped carriers pass through the openings. The various chambers for the epitaxial growth operations are disposed within a reactive tube intermediate the ends thereof. Disposed within the tube adjacent the restricted opening at the inlet of the tube is an ambient buffer chamber in which is introduced, at low positive pressures, a protective atmosphere which may comprise any gas which does not involve a positive modifying reaction with the substrates and which herein is properly defined as "non-reactive gas" and which includes hydrogen, nitrogen, helium, argon, forming gas and the like. Positioned within the reactive tube, between the ambient buffer chamber and a preheat station is a transition or isolation chamber constructed in accordance with the teachings above. Located within the reactor tube, downstream from and adjacent to the preheat station is the epitaxial growth chamber provided with the epitaxial film growing atmosphere, as indicated above, and which, to some extent, controls the configuration of the remaining portions of the tube.

Also the reactor tube is provided with a cool-down section which is separated from a second ambient buffer (disposed at the outlet of the reactor tube) by a second isolation chamber identical to the previously indicated one and also constructed in accordance with our teachings above. Upon completion of the process, the substrates emerge into ambient atmospheres for further handling in accordance with processing and/or handling techniques. In this system, the reactive atmospheres associated with the substrates during their change sensitive condition, are protected from deleterious atmospheres, including ambient atmospheres, by appropriate location of the two isolation sections to provide substantially complete segregation or isolation of the reactive atmospheres from the indicated deleterious atmospheres. These isolation or transition sections or chambers function to demarcate adjacent atmospheres and to distinct and isolated environments, whereby each environment is provided with its own distinct and controlled environment by the use of suitable flow and process control techniques.

With the continuous epitaxial growth system of this invention, individual and constant environments are isolated from deleterious atmospheres which reduce the usual detrimental effects associated with environmental cycling associated with batch techniques.

Isolation of the processing atmospheres by indicated isolation chambers is accomplished with the isolation chambers by means of a series of counter-flowing gasses which comprise suitable protective atmospheres which are not adversely reactive with the substrate (e.g., non-reactive gasses such as hydrogen, nitrogen, argon, helium, forming gasses and the like). Also included in the continuous system of this invention

are suitable heating means, such as induction heaters disposed about appropriate sections of the reactive tube for heating and maintaining the transported wafers at operating or processing temperatures.

- 5 The process involved in the operation of the above system can be defined in substance as introducing semiconductor wafers into a buffer chamber and through an isolation chamber into a pre-conditioning chamber in which the wafers are preheated to operating or deposition temperatures in a protective atmosphere of a non-reactive gas as defined herein, which is compatible with ambient atmospheres and the reactive gasses in the system, and while the wafers are maintained at operating temperatures, immediately and sequentially passing them through the processing chamber containing a reactive gas comprised of a decomposable vapor source of a semiconductor material from which the wafers pass through a cool-down chamber of the indicated non-reactive gasses wherein the wafers are cooled below sensitive reactive temperatures with the second isolation chamber interposed between atmospheres containing the change sensitive substrate and ambient atmospheres with final discharge of the substrates from the reactor tube, and into ambient atmospheres.
- 10 20 The foregoing process is characterized in that a series of semiconductor wafers are continuously passed in linear array through the processing chambers with substantially 100 percent separation maintained between substrate modifying atmospheres and adverse atmospheres.
- 25 30 Also the process is further characterized in that the various processing and isolating atmospheres are maintained at a substantially constant concentration and environment whereby each respective atmosphere concentration level and pressure is non-fluctuating. In essence, the invention processes the 35 semiconductor materials sequentially at common ambients, such as temperatures and environment which eliminates the deleterious effects produced by switching gas flows, temperature recovery, etc., which are noted as examples and which introduce transients, in an otherwise undisturbed system.
- 40 45 50 Secondly, each chamber provides its own environment which is stable over a long period compared with the processing time of the material in that chamber.

In the same fashion as shown in preceding examples, a continuous tier of wafer carriers 50, having a rectangular configuration, are transported in end-to-end relationship by a feed mechanism generally indicated by the numeral 51 into a quartz processing tube 52 disposed within heating coils 53 which may be optionally enclosed in a furnace enclosure 55 of the usual construction.

55 60 65 Since the specific process involves epitaxial deposition on a semiconductor wafer, the carriers 50 therefore are fabricated of a suitable susceptor material, such as graphite, carbon and the like, for coupling with the field of coil 53 with corresponding conduction and radiation heating of the supported wafers 64. The heating coil 53 is a water cooled induction coil for coupling RF energy into the carriers to provide the desired heating of the wafers to processing temperatures. However, as will be understood, the specific form of heating employed will be dependent on the specific processing involved and, where appropriate, the heating coils can comprise resistance heaters and the like. Conversely, when appropriate, in other processing systems the carriers can be fabricated of other materials such as quartz and the like.

65 The processing tube shown here is also of rectangular configuration having an internal height of about 33 mm. and an internal width of 89 mm. with an overall length of about 78 inches subdivided into appropriate chambers to be described below. The carriers 50 illustrated in FIG. 6 are employed for processing a wafer having 2½-inch diameter with it being understood that other variation in carrier and wafers aforesubdiscussed in conjunction with the preceding examples may also be employed where desired or required. As in the previous embodiments, the carriers 50 were fabricated in a 3.45 inch square configuration, with a thickness of about 0.5

inches with skids or rails 62 of about 0.015 inches depending, from the bottom of the carrier to provide an overall height of 0.515 inches to provide a free flow cross-sectional area in the tube of about 17.7 sq. cm.

As in the previous examples, the top surfaces of carriers 50 in this example are recessed at 63 to a sufficient depth to seat and maintain therein a semiconductor wafer 64 of silicon and the like for processing through tube 52. In general, the top surface of the wafers will be substantially flush with the top surface of carriers 50 while seated therein.

A typical feed station for this example may be similar in construction to that shown in FIG. 5, which comprises an endless conveyor 65 which carries the carriers to the drive units 66 which comprise two side gripping endless belts which contact the carriers on their sides to propel them in end-to-end relationship through processing tube 52. A transfer plate 67 is provided with side-guides 67A for feeding the carriers 50 in end-to-end relationship through processing tube 52.

The tube 52, as shown in FIG. 18, is subdivided into an ambient buffer chamber or zone 69, a critical isolation or buffer feed chamber 70, a preheat chamber 71, a deposition chamber 71A, a cool-down chamber 71B, a second critical isolation or buffer feed chamber 73, and an ambient output buffer chamber 77.

The input buffer zone 69, of about 5 inches in length, is defined by partitions 78 and 79 with partition 78 extending toward the bottom of the reactor tube 52, a distance providing about 0.25 inches clearance with the top of a tier of carriers 50. Buffer zone 69 forms a preliminary barrier with ambient atmosphere and is maintained with a non-reactive protective atmosphere of about 0.001 p.s.i.g., by introducing therein to a circumferential slot 81 of a closed end nozzle 80, a suitably controlled flow of gas such as nitrogen, helium, argon, forming gas and the like. Generally however, for this processing system the pressure in the ambient input buffer chamber may extend from about 0.0001 to about 0.005 p.s.i.g., and preferably from about 0.001 p.s.i.g. to about 0.003 p.s.i.g. As indicated, nozzle 80 is a closed end structure having configurations such as shown in FIG. 12 with an ID of about 5 mm. and a 240° circumferential slot (e.g. H1) of about 0.55 mm. to laterally eject the non-reactive gas toward the entry end of the reaction tube 52, and to prevent direct impingement of the gasses on the wafer 64.

The tier of carriers 50 traveling at a rate of 1 inch per minute passes out of the ambient buffer chamber 69 into and through the critical isolation chamber 70 defined within the aforesaid partition 79 and partition 81 having the same structural configuration of the preceding examples and accordingly the component features are indicated by the same reference numerals.

Also, as in the preceding examples, the isolation chamber is subdivided into a series of alternate inlet and outlet compartments into which protective gasses are introduced and withdrawn. For the particular isolation obtained, the isolation chamber is subdivided into an inlet compartment 70A, an outlet compartment 70B, a second inlet compartment 70C, a second outlet compartment 70D, and a third inlet compartment 70E, each about 1 inch in length.

This five compartmented isolation chamber 70 has a structural configuration identical to the isolation chambers of the preceding examples, with a protective atmosphere maintained in inlet compartment 70A at a pressure of about 0.003 p.s.i.g. by introducing therein an inert gas (such as nitrogen, argon, helium and the like) through a double slotted end nozzle 86 of 5 mm. ID having a general configuration such as shown in FIG. 11. Generally, this pressure may extend from about 0.002 p.s.i.g. to about 0.05 p.s.i.g., with the same relationships maintained between pressure piece 70A (inlet compartment 70A), and pressure P69 (in input buffer chamber 69) as indicated in the preceding examples.

Similarly, as in the preceding examples, the same pressures relationship will be maintained between the pressure P70A and (in compartment 70A), and pressure P70B (in compart-

ment 70B), with a pressure of about 0.002 p.s.i.g. maintained in the outlet compartment 70B by suitable exhausting via the outlet tube 88 which exhausts the gas under the sole impetus of flows into outlet compartment 70B. However, as indicated above, positive exhaust means may be employed to assist the exhausting of gasses if desired, and where the requirements of the processing require it.

A protective atmosphere (generally the same as employed in the preceding inlet compartment of the tube), is introduced through the inlet nozzle 86A having the same general configuration as nozzle 86 to maintain a pressure P70C substantially higher than the pressures P69 and P70A in, respectively, buffer chamber 69 in inlet compartment 70A as, for example, about 0.006 p.s.i.g. Generally the pressure P70C will be maintained in the range of about 0.004 to about 0.1 p.s.i.g. and preferably from about 0.004 to about 0.01 p.s.i.g. However, as in the preceding examples, the indicated pressure P70C will be maintained at a level substantially higher than pressures P69 and P70A. Conversely this pressure P70C will be substantially higher than the pressure P70B so that a positive gas flow F3 will exist from inlet compartment 70C into outlet compartment 70B through the restricted orifice type clearance defined by baffle 87 relative to the surface of the carrier 50.

The second outlet compartment 70D of about 1 inch in length is defined by baffles 87A and 85A with the latter baffle 85A being in dimension substantially identical to the aforescribed baffle 85 with a corresponding-like clearance with the carriers 50. In general, the gasses in outlet compartment 70D are withdrawn therefore via outlet tube 88A to maintain the pressure P70D substantially lower, e.g. about 0.004 p.s.i.g. than pressure P70C in the preceding inlet compartment 70C. For all practical purposes the pressure 70D in outlet compartment 70D may be equal to the pressure P70B in the previous outlet compartment 70B, but in general, this pressure level may extend to the same general range, e.g. about 0.001 to about 0.003 p.s.i.g., and preferably from 0.001 to about 0.003 p.s.i.g. As previously indicated, in compliance with the orifice equation, the correlation of pressures in respective inlet and outlet compartments 70B and 70D, in conjunction with the restrictive orifice-type clearances of baffle 87A, the flow of gas F4 will be from inlet compartment 70C into outlet compartment 70D.

The configuration of isolation chamber 70 is completed by the additional inlet compartment 70E, in the same manner described for the previous embodiments. In like manner, the pressure P70E, inlet compartment 70E, will be in the same general range as specified above, normally both pressures P70A and P70E will be at the same level so that a symmetrical distribution of pressures will be maintained in isolation chamber 70 as follows

$$P69 \leq P70A > P70B << P70C >> P70D < P70E \geq P71$$

where $P70E = P70A$ and $P70B = P70D$

The pressure P70E in inlet compartment 70E is maintained by appropriate control of the injection of a protective atmosphere into a compartment via the inlet nozzle 86B having the same general configuration of previously noted inlet nozzles 86 and 86A shown in FIGS. 11 and 14. The protective atmosphere provided in inlet compartment 70E may constitute any of the inert gasses employed in the preceding inlet compartments 70A and 70C, but may also include non-reactive gasses, such as forming gas, and preferably hydrogen.

As the tier of carriers 50 emerges from the last inlet compartment 70E of isolation chamber 70 they enter into a non-reactive preheat chamber 71 disposed within the heating coil 53 for heating the supported wafers 64 to processing temperatures, e.g. about 1,200° C. for silicon, with it being understood that a temperature may extend from a preferred range of 1,050° C. to about 1,250° C. to a general range of about 950° C. to about 1,350° C. Conversely, these temperatures for germanium will be in a general range of about 600° C. to about 920° C. and preferably from about 890° C. to about 910° C.

In this embodiment, for a carrier travel of about 1.0 inches per minute through the preheat chamber 71, this chamber has

a length of about 12 inches as defined between flanges partitions 81 and 91, each extending to a level of about 0.015 above the surface of carriers 50 to form restricted orifice-sized clearances such as that previously indicated above. It is to be understood that the length of the preheat chamber 71 is not necessarily restricted to the specific dimensions indicated therefor. In practice, the length of the preheat chamber can be readily varied, but as a general rule, they will be correlated to the rate of carrier travel and the temperatures generated as required to bring the semiconductor wafers to processing temperatures. Conversely, where the length of preheat chamber 71 is prefixed, it will be readily seen that the wafers can be brought to processing temperatures by suitable adjustment in the rate of carrier travel and/or in the temperatures generated via the induction coil 53. Since the preheated wafers are to be subjected to an epitaxial vapor deposition step in the immediately following chamber 71A, a hydrogen environment is normally maintained in preheat chambers 71 at a pressure P71 in the general range of about 0.001 to about 0.05 p.s.i.g. and preferably to about 0.002 to about 0.005 p.s.i.g. However the pressure P71 will be maintained at a level below the pressure in the preceding inlet compartment 70E and coordinated therewith so that there will be either a zero flow F6 between inlet compartment 70E and preheat chamber 71 or a positive flow of F4 from inlet compartment 70E into preheat chamber 71.

The indicated pressure environment in preheat chamber 71 is maintained by introducing and withdrawing hydrogen via respective inlet and outlet tubes 89 and 90, at a controlled rate which will also provide a substantially quiescent preheat atmosphere having a flow rate, from inlet tube 89 to outlet tube 90 not greater than about 20 liters per minute (e.g. about 1.13 liters/minute/sq. cm. of cross-section), and preferably about 3 to about 12 liters per minute (e.g. about 0.170 to about 1.13 liters/minute/sq. cm. of cross-sectional are of the chamber). The construction of inlet and outlet tubes 89 and 90 are similar in construction to the corresponding inlet and outlet tubes previously described and shown in FIGS. 12 and 13. In general, as shown in FIG. 18, the discharge of hydrogen from the orifice of inlet tube 89 will normally be directed laterally against partition 81 to effect a better distribution of hydrogen in preheat chamber 71, and as previously indicated to prevent direct impingement of the hydrogen on the wafer 64.

After the preheating process, the moving tier of carriers 50 emerge from the preheat chamber 71 (approximately 21 inches in length) and pass through the reaction chamber 71A (approximately 8 inches in length) in which is maintained an environment of hydrogen and an epitaxial film growing gas source flowing from inlet tube 89 to outlet tube 90 at a feed rate not greater than about 25 liters per minute (e.g. 1.41 liters/minute/sq. cm. of cross-section) and preferably from about 6 to about 12 liters per minute (e.g. from about 0.339 to about 0.68 liters/minute/sq. cm. of cross-section of the chamber). In general, the rate of flow will be sufficient to maintain a substantially constant proportional concentration of the hydrogen and epitaxial film growing gas source at a pressure in the general range of 0.001 to 0.5 p.s.i.g. and preferably 0.002 to 0.005 p.s.i.g. Typically the film growing gas may comprise a semiconductor halide. However, the epitaxial film growing atmosphere may comprise any of the conventional epitaxial source materials such as the various halide compounds, silicon tetrachloride, trichlorsilane, germanium tetrachloride, germanium iodide, silicon bromide and the like, or the epitaxial source material may be a hydride of silicon or germanium such as silane or germane. In general, the epitaxial deposition may be effected by reduction, or from pyrolytic decomposition of source materials. Conversely, as will be appreciated, where doped epitaxial layers are desired, suitable impurities, as for example, hydride compounds such as phosphine, diborane, arsine, and the like may be included in the processing environment of reaction chamber 71A in suitably controlled amounts to obtain grown or epitaxial layers having the desired impurity concentration or doping levels.

In practice, controlled proportions of hydrogen and the epitaxial film growing gas (including a dopant if desired) from suitable sources are pre-mixed externally of the system and circulated through the epitaxial growth chamber 71A via its 5 inlet tube 89 and outlet tube 90 to provide the above indicated rate of flow and to maintain a pressure P71A at substantially the same level as the pressure P71 in preheat chamber 71. Generally however, the pressure may range from about 0.001 to about 0.05 p.s.i.g. and preferably from about 0.002 to about 0.005 p.s.i.g. As will be noted in FIG. 18, to prevent direct 10 impingement of the gas on the substrate 64, the discharge orifice is directed laterally against partition 91 which also facilitates a more even distribution of the gasses in epitaxial chamber 71A.

15 It is noted herein that it is to be understood that the term "semiconductor" material as utilized herein is considered generic to germanium, silicon and germanium-silicon alloys indium antimonide, gallium antimonide, aluminum antimonide, indium arsenide, gallium arsenide, gallium phosphorous alloys and indium phosphorous alloys, and the like, and is employed to distinguish these semiconductors from metallic oxide semiconductors such as copper, oxide and selenium.

The preferred method herein involves the use of a three 25 component mixture in which a doped epitaxial film is deposited on the surface of a semiconductor substrate, wherein the first component comprises hydrogen, the second component comprises silicon tetrachloride and the third component comprises a conductivity-type determining impurity. 30 The epitaxial film is obtained by the reduction of the silicon tetrachloride by hydrogen, and with the liberated silicon epitaxially deposited on the heated exposed surfaces of the substrate. The film produced on the exposed surface of the substrate is single crystalline material having the same orientation as the substrate. The formation of the film may be characterized as a hydrogen reduction of a decomposable compound of the semiconductor material.

35 Although as indicated, silicon tetrachloride is a preferred compound for use with silicon substrates, in general, the halides of both silicon and germanium, respectively, can be used 40 for such film growth. The indicated preferred epitaxial film forming atmospheres will normally comprise by volume about 0.5 percent silicon tetrachloride and about 0.05 percent arsine in hydrogen flowing at a feed rate of 10 liters per minute (e.g. 45 0.565 liters/minute/sq. cm. of cross-section).

50 After passage of the substrates through the reaction chamber 71A, the carrier supported substrates enter into cool-down chamber 71B, defined between partition 91A and 79A which is provided with a protective atmosphere via its inlet nozzle 89 and outlet nozzle 90. In general, the atmosphere of cool-down chamber 71B will normally be comprised of inert gasses such as nitrogen, helium, argon and the like. However, forming gas and preferably hydrogen may also be used.

55 After passage through the cool-down chamber 71B of about 29 inches in length, the carriers 50 (with the wafers 64 supported thereon cooled to below reactive temperatures), enter and pass through a second isolation chamber 73 which 60 (although defined between partitions 79A and 81A) is, for all practical purposes, identical to the previously described isolation chamber 70. Since these two isolation chambers 70 and 73 are identical, and since correlation of the pressures in the various inlet compartments 73A, 73C and 73E and outlet compartments 73B and 73D are identical to the pressures in the corresponding inlet and outlet compartments of isolation chamber 70, no extended description is necessary. If required, such details may be easily ascertained by reference to the above description of corresponding portions of isolation chamber 70.

65 In general, the protective atmospheres employed in the inlet compartment 73A (of isolation chamber 73) may include not only the inert gasses such as helium, argon, nitrogen and the like, but may also include forming gas and preferably hydrogen. Also the protective atmospheres in inlet compartment 70

ment 73C and 73E will normally be comprised of the inert gases such a nitrogen, hydrogen, argon, and the like. In general, the pressure P71B in cool-down chamber 71B will be correlated to the pressure P73A in inlet compartment 73A (of isolation chamber 73) so that there will be zero flow therebetween or positive flow from inlet compartment 73A into cool-down chamber 71B.

The basic function of isolation chamber 73 is for the use of protective atmospheres to effect critical isolation between the reaction chamber 71A and external ambient atmospheres.

As the carriers 50 emerge from the isolation chamber 73, they pass into and through an ambient outlet buffer chamber 77 (defined between partitions 81A and 78A) to discharge across a transfer table 98 between conveyor belts 99.

As shown, the outlet buffer chamber 77 is about 5 inches in length and is provided with a protective atmosphere such as the indicated inert gases, via its inlet nozzle 89 with discharge of gasses effected into ambient atmosphere through the restricted openings defined by end partition 78A and a service of carriers 50.

The foregoing system may be summarized as maintaining the integrity of the atmospheres in respective preheat, processing and cool-down chambers 71, 71A and 71B by the interpositioning of isolation chambers 70 and 73, between these chambers and ambient atmospheres in accordance with the more extended description above. As described above, one of these isolation chambers is interposed between the preheat chamber 71 and ambient atmospheres (including inlet buffer chamber 69), and a second isolation chamber 73 is interposed between the cool-down chamber 71B at external ambient atmospheres (including outlet buffer chamber 77). Each of the isolation chambers 70 and 73 is subdivided into a series of alternate inlet and outlet compartments (comprising three inlet compartments and two outlet compartments), with the two end-most inlet compartments disposed adjacent the ambient buffer chambers and a corresponding one of the preheat and cool-down chambers 71 and 71B.

The gas pressures and flow relationships in the isolation chambers 70 and 73 of this example are identical to those previously described with the foregoing examples. For example, in operation a non-reactive gas, from a suitable source not shown, is introduced into inlet compartments 70A, 70C and 70E through respective inlet nozzles 86, 86A and 86B at a pressure level above that of the atmospheres in adjoining chambers (e.g. inlet buffer chamber 69 and preheat chamber 71, associated with isolation chamber 70, and outlet buffer chamber 77 and cool-down chamber 71B associated with isolation chamber 73). The inlet compartment 70C is pressurized to a level above that in the end-most inlet compartments 70A and 70E. Gasses from the outlet compartments 70B and 70D are exhausted by respective discharge outlets 88.

With the pressure in the processing chambers and the various inlet compartments at higher pressure levels than that in the outlet compartments 70B and 70D, no positive exhaust system is necessary for withdrawing gasses from outlet compartments 70B and 70D via outlets 88. The exit of gasses from the outlet compartments 70B and 70D can be exhausted by the sole impetus of the gas flows from inlet compartments 70A, 70C and 70E, alone or in conjunction with the adjacent pressurized gas flows in either one of the processing chambers.

In substance, the above defined structural configuration of the isolation chamber utilizes the orifice phenomena for control of gas flows, and thus conversely prevents cross-migration of interconnected atmospheres. Basically, since for a given feed unit, constant values are presented by the dimensions of the orifice-size clearances, the cross-sections of the compartments or chambers, the coefficient of discharge and the density of the flowing gasses, the orifice equation for flow through the clearances is reduced to

$$F = K \sqrt{\Delta P}$$

where F is the rate of flow in feet per second, K is a derivable constant characteristic of each of the orifice clearances em-

ployed in the buffer feed unit, and ΔP is the pressure differential across the orifice clearances.

For convenience, the various pressures comprehended in the various compartments of the isolation chambers (and in respective inlet buffer and preheat chambers 69 and 71 are, with reference to FIG. 16, identified and set forth in the following table:

TABLE 7

10

	Atmosphere	Chamber or Compartment	Pressure
15	A69	69	P69
	Non-reactive	70A	P70A
	Non-reactive	70B	P70B
	Non-reactive	70C	P70C
	Non-reactive	70D	P70D
	Non-reactive	70E	P70E
20	A71	71	P71

with the above pressures correlated to each other in accordance with the following relationship wherein pressure P70C (in central inlet compartment 70C) represents the highest pressure level employed; P69 P70A P70B P70C P70D P70E P71, where P69 and P71 are the respective pressures in inlet buffer chamber 69 and preheat chamber 71.

In a preferred application for maximum isolation of the atmospheres in inlet buffer chamber 69 and preheat chamber 71 for example, the various pressures are correlated in the following relationships:

$$P70A \geq P69$$

$$P70E \geq P71$$

$$P70C > P69, P71, P70A, and P70E$$

$$P70B < P70A + \frac{1}{2}P70C$$

$$P70D < P70E + \frac{1}{2}P70C$$

Using the orifice equation noted above to the gas flow between atmosphere A69 and inlet compartment 70A will conform with reference to FIG. 16, to the equation

$$F = K_1 \sqrt{P70A - P69} = K_1 \sqrt{\Delta P_1}$$

wherein P70A, as indicated above, may be equal to or greater than P69 so that gas flow therebetween will be zero or in a positive direction from compartment 70A to atmosphere A69 (in inlet buffer chamber 69) as indicated by the arrow F1.

The gas flows F2 and F3 between respective pairs of compartments 70A and 70B and compartments 70B and 70C conform to the corresponding equations

$$F2 = K_2 \sqrt{P70A - P70B} \quad F3 = K_3 \sqrt{P70C - P70B}$$

$$F2 = K_2 \sqrt{\Delta P_2} \quad F3 = K_3 \sqrt{\Delta P_3}$$

wherein both pressures P70A and P70C in respective compartments 70A and 70C are greater than pressure P70B in outlet compartment 70B so that gas flow will be in positive directions from compartments 70A and 70C into compartment 70B as indicated by the arrows F2 and F3. Also, in view of the additional requirement that the positive pressure P70C in compartment 70C is at a higher level above the positive pressure P70A in compartment 70A, the gas flow F3 from compartment 70C into compartment 70B will be greater than the gas flow F2 from compartment 70A into compartment 70B to thus minimize (to non-measurable magnitudes) cross-migration of gasses between inlet compartments 70A and 70C.

The gas flow relationship for gas flows F2 and F3 apply similarly to respective gas flows F5 (between compartments 70E and 70D) and F4 (between compartments 70C and 70D) which conform to the equations

$$F5 = K_5 \sqrt{P70E - P70D} \quad F4 = K_4 \sqrt{P70C - P70D}$$

$$F5 = K_5 \sqrt{\Delta P_5} \quad \text{and} \quad F4 = K_4 \sqrt{\Delta P_4}$$

wherein the pressures are selected and correlated so that there is a positive gas flow F5 from compartment 70E into compartment 70D, as indicated by the arrow F5, and a positive gas flow F4 from compartment 70C into compartment 70D as indicated by the arrow F4.

Similarly the relationship for gas flow F1 applies in like

manner to the gas flow F_6 between compartment 70E and preheat chamber 71 which conform to the equation

$$F_6 = K_6 \sqrt{P_{70E} - P_{71}} = K_6 \sqrt{\Delta P_6}$$

wherein the pressures P_{70E} and P_{71} , or respectively compartment 70E and preheat chamber 71, are correlated so that there is zero flow or a positive flow from compartment 70E into preheat chamber 71.

Also, as indicated above, complete elimination of cross-migration between communicating atmospheres is practically impossible to achieve. However, the concentration of migrating gasses is sequentially reduced to a level that its infusion into a second atmosphere is restricted to unmeasurable concentrations, e.g. parts per billion or less.

Thus in the embodiment described in conjunction with FIG. 16, the atmosphere A69 (in inlet buffer chamber 69) will diffuse against a back pressure of compartment 70A wherein it will be diluted by an order of 10^2 : 1 to a concentration level of about 1 percent by volume wherein the final mixture will be represented as an atmosphere D1 which represents the first dilution of atmosphere A69. From compartment 70A, the atmosphere or gas mixture D1 is forced into outlet compartment 70B where it is blended with the inflowing gas from inlet compartment 70C which results in a further dilution of atmosphere A69 in the gas mixture D1 by an order of 10^1 : 1 to form a second mixture D2 wherein the concentration of atmosphere A69 is about 0.1 percent by volume. This second gas mixture D2 will diffuse against the inflowing gasses from inlet compartment 70C wherein the atmosphere A69 will be further diluted by an order of 10^4 : 1 to form a third gas mixture D3 wherein D3 represents the third dilution of atmosphere A69 to a concentration level of less than 10^{-5} percent. In turn, the gas mixture D3 (in compartment 70C) flows into the outlet compartment 70D wherein it is mixed with the inflowing gasses from inlet compartment 70E to form a fourth mixture D4 in which the atmosphere A69 is further diluted by an order of 10^0 : 1 to a concentration of 10^{-6} percent. Similarly this gas mixture D4 (representing the fourth dilution of atmosphere A69) diffuses against the inflowing gasses from compartment 70E into this compartment wherein it is again diluted by an order of 10^2 : 1 to a concentration level of less than 10^{-7} percent which forms a gas mixture D5 in which the concentration limits of A69 are at a level, which upon migration of gas mixture D5 into atmosphere A71 (of preheat chamber 71) can be safely tolerated since therein the first atmosphere A69 is still further diluted by an order of 10^1 : 1 within atmosphere A71 to concentration of less than 10^{-8} percent. Conversely, as can be readily seen, a similar analysis applies equally to the cross-migration in FIG. 16 of atmosphere A71 into atmosphere A69.

To illustrate the operation of the above described system of this example, the following table is set forth to illustrate the environments and results of a specific operating system for processing of surface preconditioned silicon wafers supported on the carriers traveling through the system at a rate of 1 inch per minute and utilizing on an atmosphere of hydrogen containing, by volume, 0.5 percent silicon tetrachloride and 0.05 percent arsine.

EXAMPLE IV

Vapor Etching

5 This example, in conjunction with FIGS. 5-7, 9-14, 16 and 19, describes a continuous processing system for vapor etching of exposed surfaces of semiconductor substrates.

In its broadest concept, the system of this example comprises an environmentally controlled preheat station communicating with an etching atmosphere, which in turn communicates with an environmentally controlled cool-down station, with a series of semiconductor substrates sequentially transported through the preheat, substrate etching and cool-down stations. In general, the etching station comprises the vapor 10 state etching of exposed surface portions of semiconductor substrates, as, for example, for clean-up etching within diffusion windows formed within a silicon dioxide mask coating. For this operation, the etching atmosphere at the etching station will comprise a gas mixture containing hydrogen and a 15 hydrogen halide, such as hydrogen chloride, hydrogen bromide, and the like.

In practice, as in the preceding example, a series of wafers which are appropriately supported on a flat carrier, is sequentially passed in end-to-end relationship through a series of 20

consecutive chambers defined by partitions each having an opening of a configuration conforming to the cross-section of the carriers so as to provide a restricted clearance as the identically shaped carriers pass through the opening. The 25 three chambers (e.g. preheat, processing and cool-down) are disposed within a reactor tube intermediate the ends thereof. Disposed within the tube adjacent the restricted opening at the inlet of the tube is an ambient buffer chamber in which is introduced at low pressure, a non-reactive gas such as nitrogen, helium, argon and the like. Positioned within the 30 tube, between the ambient buffer chamber and a preheat station is a transition or isolation chamber constructed in a configuration as more fully described in the preceding examples.

Conversely, disposed adjacent the outlet end of the reactor 35 tube is a similar ambient output buffer chamber separated from a cool-down station by an interposed second isolation chamber identical to the previously indicated one and also constructed in accordance with the description given above.

The isolation or transition chamber functions to demarcate 40 adjacent atmospheres into distinct and isolated environments whereby each environment is provided with its own distinct and controlled environment by the use of suitable flow and process controlled techniques.

With the continuous vapor etching system of this example, 45 individual and constant environments are isolated from deleterious atmospheres which reduce the usual detrimental effects associated with environmental cycling which characterize batch techniques.

Isolation of the processing atmospheres, by the indicated 50 isolation chambers is accomplished within the isolation chambers by means of a series of counter-flowing gasses which comprise non-reactive gasses such as nitrogen, argon, helium, and the like. Also included into the system is a suitable heater,

e.g. a resistance heater or an induction heater disposed about the reactor tube for heating and maintaining the transport wafers at operating or processing temperatures.

The process involved in the operation of the above system can be defined, in substance, as introducing semiconductor wafers through an isolation chamber into a preconditioning chamber in which the wafers are preheated to operating temperatures in an atmosphere of any one of the non-reactive gasses indicated above, or preferably hydrogen, and while the wafers are maintained at operating temperatures, immediately and sequentially passing them through the processing chamber containing an etching atmosphere from which the wafers pass through to a cool-down chamber provided with a protective atmosphere such as indicated for the preheat station. The wafers are cooled in the cool-down chamber to below reactive temperatures with subsequent passage through a second isolation chamber into an ambient outlet buffer chamber from which they emerge from the reactor tube into ambient atmospheres.

The foregoing process is characterized in that a series of semiconductor wafers are continuously passed in linear array through the processing chambers with substantially 100 percent separation maintained between the preheat and cool-down chambers, on the one hand, and external ambient atmospheres on the other hand.

Also the process is further characterized in that the various processing and the isolating atmospheres are maintained at substantially constant concentration and environment whereby each respective atmosphere concentration level and pressure is non-fluctuating. In essence, the invention processes the semiconductor materials sequentially at common ambients, such as temperature, which eliminates the deleterious effects produced by switching gas flows, etc. and temperature recoveries which are noted for examples, in which introduced transients in otherwise undisturbed system. Secondly, each chamber provides its own environment which is stabled over long periods compared with the processing time of the material in that chamber.

Most specifically, and in the same fashion as shown in the previous examples, FIGS. 5 to 7, a continuous tier of wafer carriers 50 having a rectangular configuration are transported end-to-end relationship by a feed mechanism generally indicated by the numeral 51 into a quartz processing tube 52 disposed within heating coils 53, FIG. 19, which may be optionally enclosed in a furnace enclosure 55, FIG. 5, of the usual construction.

Since RF heater coils 53 are shown and employed in this example, the carriers 50 are fabricated of suitable susceptor material such as graphite, carbon, molybdenum, and the like. However, it is to be understood that for the vapor etching operations, carriers 50 may be constructed of other suitable material compatible with the wafers and with process environments. In general, the materials of carriers 50 will normally determine the type of heater coils employed in conjunction with reactor tube 52. For example, in the system employing quartz carriers, the heating coils can conveniently comprise resistance coils, and conversely, the use of graphite in the construction of the carriers permits the use of either resistance coils or induction heater coils in system.

The processing tube of this example as illustrated in FIG. 19 is also of rectangular configuration having an internal height of about 33 mm., an internal width of 89 mm. and an overall length of about 78 inches subdivided into appropriate chambers to be described below.

The carrier 50, as illustrated in FIG. 6, is employed for processing wafers having 2 1/2-inch diameter, with it being understood that other variations in carrier and wafer aforesubdiscussed in conjunction with Example I may also be employed where desired or required. As in the previous embodiment, the carriers 50 were fabricated in a 3.45 inch square configuration, with a thickness of about 0.5 inches and having skids or rails 62 of about 0.015 inches, depending from the bottom of the carrier, to provide an overall height of 0.515

inches. As in the previous example, the top surface of carrier 50 in this example are recessed at 63 to a sufficient depth to seat and maintain therein a semiconductor wafer 64, as for example, of silicon, germanium and the like for processing through tube 52. In general, the top surfaces of the wafers will be substantially flush with the top surface of the carriers 50 while seated therein.

A typical feed station for this example is similar in construction to that shown in FIG. 5, which comprises an endless conveyor 65 which carries the carriers to the drive unit 66 which comprise two side-gripping endless belts which contact the carriers on their sides to propel them in end-to-end relationships through the processing tube 52. A transfer plate 67 is provided with side-guides 67A for feeding the carriers 50 in end-to-end relationship through the processing tube 52.

Basically, the reactor tube is subdivided into an ambient buffer chamber or zone 69, an isolation chamber 70, a preheat chamber 71, an etching station 71A, a cool-down chamber 71B, a second isolation chamber 73, and a second ambient buffer chamber 77. In general, since chambers 69, 70, 71, 71A, 71B, 73 and 77 of this example (e.g. FIG. 19) are identical to the corresponding chambers of the preceding example (e.g. FIG. 18), no further discussion is believed necessary with regard to these chambers, and reference is merely directed to the preceding discussion thereof, and accordingly, like numerals are employed for corresponding portions of the two examples. In general it is only noted that the overall length of the tube is about 78 inches, and the rate of travel of carriers 50 through the reactor tube is about 1 inch per minute.

The buffer zone 69 is about 5 inches in length and also forms a preliminary barrier with ambient atmospheres and is maintained with protective atmospheres of about 0.001 p.s.i.g. by introducing therein, as in the previous examples, a suitably controlled flow of inert gasses such as nitrogen, helium, argon and the like. Generally however, for the instant processing system, the pressure in the ambient chamber may extend from about 0.001 to about 0.005 p.s.i.g. and preferably from about 0.001 to about 0.003 p.s.i.g.

40 The tier of carriers 50 traveling at the indicated rate of 1 inch per minute passes out of the ambient buffer chamber 69 into and through the critical isolation chamber 70 having the same structural configuration indicated for the processing tube of the previous example.

45 Isolation chamber 70 also forms, in this example, a buffer feed zone between the ambient inlet buffer chamber 69 and the preheat chamber 71 to maintain the integrity of the processing atmosphere therein.

50 Inlet compartments 70A, 70C and 70E of the isolation chamber 70 are provided with protective atmosphere which may comprise any of the inert gasses such as nitrogen, argon, helium and also other non-reactive gasses such as forming gas and the like. In general, the pressure relationships of the preceding example will be maintained within the various compartments of isolation chamber 70 and between the adjacent ambient inlet chamber 69 and the preheat chambers 71 so as to maintain the same flow relationships indicated above.

55 As a tier of carriers 50 emerge from the last inlet compartment 70E of isolation chamber 70, the carriers enter into the preheat chamber 71 disposed within the heating coils 53 for heating the supported wafers 64 to processing temperatures, e.g. about 1,200°C. for silicon with it being understood that the temperatures may extend from a preferred range of about 1,175°-1,250°C. to a general range of about 1,000°-1,300°C. Conversely, these temperatures for germanium will be in a general range of about 350°-900°C., and preferably from about 810° to about 840°C.

60 In this process, for a carrier travel rate of about 1 inch per minute through the preheat chamber 71, this chamber has a length of about 25 inches and is defined between flanged partitions 81 and 91.

65 Normally the environment in preheat chamber 71 will be selected so as to be compatible with the etching atmosphere in the succeeding processing chamber 71A defined between partitions 91 and 91A. For example the protective atmosphere in

preheat chamber 71 may not only comprise any of the indicated inert gasses but in addition, preferably includes hydrogen. In a specific application, utilizing a gas mixture of hydrogen and hydrogen chloride in the etching chamber 71A, hydrogen was, and is, employed for the atmosphere in preheat chamber 71 in a general range of about 0.001 to about 0.05 p.s.i.g. and preferably from about 0.002 to about 0.005 p.s.i.g. It is to be understood that the pressure P71 in preheat chamber 71 will be maintained at a level below the pressure P70E in the preceding inlet compartment 70E (of the isolation chamber 70) and coordinated therewith so that there will be either a zero flow F6 between inlet compartment 70E and preheat chamber 71, or a positive flow F6 from inlet compartment 70E into preheat chamber 71.

After the preheating stage, the moving tier of carriers 50 emerges from the preheat chamber 71 and passes through the reaction chamber 71A of about 4 inches in length in which is maintained a substantially quiescent environment of hydrogen and a hydrogen halide gas flowing from its inlet tube 89 to outlet tube 90 at a feed rate not greater than about 25 liters per minute (e.g. about 1.41 liters/minute/sq. cm. of cross-section) and preferably from about 6 to about 12 liters per minute (e.g. from about 0.339 to about 0.68 liters/minute/sq. cm. of cross-section). In general, the rate of flow will be sufficient to maintain a substantially constant proportional concentration of the hydrogen and the hydrogen halide gas at a pressure in the general range of about 0.001 to about 0.05 and preferably from about 0.002 to 0.005 p.s.i.g.

For example, the etching atmosphere may comprise hydrogen containing from about 2 to about 12 volume percent of a hydrogen halide such as hydrogen chloride, hydrogen bromide, hydrogen fluoride and hydrogen iodide. In the preferred embodiment, as used in the specific example set out below,

is, for all practical purposes, identical to the previously described isolation chamber 70. Since these two isolation chambers 70 and 73 are identical, and since the correlation of the pressures in the various inlet compartments and outlet compartments are identical to the pressures in the corresponding inlet and outlet compartments of the previous examples, no extended description is necessary. If required, such details may be easily ascertained by reference to the above description of corresponding portions of this isolation chamber. In general, the pressure P71B in cool-down chamber 71B will be correlated to the pressure P73A in the inlet compartment 73A (of isolation chamber 73) so that there will be zero flow therebetween, or a positive flow from the inlet compartment 73A into cool-down chamber 71B.

The basic function of isolation chamber 73 is for the use of non-reactive gasses to effect critical isolation between etching chamber 71A and external ambient atmospheres.

As the carriers 50 emerge from the isolation chamber 73, they pass into and through an ambient outlet buffer chamber 77 to discharge across a transfer table 98 between conveyor belts 99. As shown, the outlet buffer chamber 77 is about 5 inches in length and is provided with a protective atmosphere (e.g. inert gasses) with discharge of gasses effected into ambient atmospheres through the restricted openings defined by end partition 78A and the surface of carriers 50.

To illustrate the operation of the above described system, as shown in FIG. 19, the following Table 9 is set forth to illustrate the process parameters of a specific operating system for etching of silicon wafers supported on carriers 50 traveling through the system at a rate of 1 inch per minute, and utilizing an atmosphere of hydrogen containing 6 percent by volume of hydrogen chloride.

the halide of the etching atmosphere is hydrogen chloride. A typical mixture of this etching atmosphere will comprise a flow of from about 6 to about 12 liters/minute of hydrogen containing from about 2 to about 12 volume percent hydrogen chloride.

After passage of the substrates through the etching chamber 71A, the carrier supported substrates enter the cool-down chamber 71B which is provided with a flow of a protective atmosphere at positive pressures and feed rates in the general range of about 0.001 to about 0.05 p.s.i.g. and about 12 to about 20 liters per minute (e.g. about 0.0565 to about 1.13 liters/minute/sq. cm. of cross-section) and preferably from about 0.002 to about 0.005 p.s.i.g. and from about 3 to about 12 liters per minute (e.g. about 0.170 to 0.68 liters/minute/sq. cm. of cross-section).

In general, the atmosphere of cool-down chamber 71B can be comprised of the conventional inert atmospheres such as nitrogen, helium, argon and the like, but preferably will be hydrogen in view of its compatibility with the gas mixture of the processing chambers 71A.

After passage through the cool-down chamber 71B of about 29 inches in length, the carriers 50 (with the wafers 64 supported thereon and cooled below reactive temperatures), enter and pass through a second isolation chamber 73 which

EXAMPLE V

Metal Deposition

55 This example, in conjunction with FIGS. 5-7, 9-14 and 16 and 20 describes the continuous processing system for vapor depositing metals on semiconductor substrates. It is noted in conjunction therewith that the term "plating metal" and/or "vapor deposition of metals" as used herein is restricted to and defines metals having resistivities (ρ) less than about 100 microhms-cm.

In its broadest concept, the system of this example comprises an environmentally controlled preheat station communicating with a confined metal plating atmosphere which, in turn, communicates with an environmentally controlled cool-down station, with a series of semiconductor substrates sequentially transported through preheat, metal deposition and cool-down stations. In a particular application, the metal deposition station comprises the formation of a metal film on the surface of the substrates. For example, the metal deposition station may include an atmosphere containing a halide of a metal having a resistivity less than about 100 microhms/cm., e.g. a molybdenum halide such as molybdenum pentachloride, either alone for pyrolytic decomposition or in conjunction

with hydrogen for chemical reduction of the halide at the surfaces of heated substrates on which the liberated metal deposits.

In practice, a series of wafers which are appropriately supported on flat carriers are sequentially passed in end-to-end relationship through a series of consecutive chambers defined by partitions each having an opening of a configuration conforming to the cross-section of the carriers so as to provide restricted clearance as the identically shaped carriers pass through the openings. The three chambers (e.g. preheat, processing and cool-down) are disposed within the reactor tube intermediate the ends thereof. Disposed within the tube adjacent the restricted opening at the inlet of the tube is an ambient inlet buffer chamber in which is introduced, at low pressures, a protective atmosphere which may comprise any of the inert gasses, such as helium, nitrogen, argon and the like. Positioned within the tube, between the inlet ambient buffer chamber and the preheat chamber is the transition or isolation chamber constructed in accordance with our teachings above.

Conversely, disposed adjacent the outlet of the reactor tube is a similar ambient outlet buffer chamber separated from the cool-down station by an interposed second isolation chamber identical to the previously indicated one and also constructed as described above.

The isolation or transition chambers function to demarcate adjacent atmospheres into distinct and isolated environments whereby each environment is provided with its own distinct and controlled environment by the use of suitable flow and process control techniques.

With the continuous metal deposition system of this invention, individual and constant environments are isolated from deleterious atmospheres which reduce the usual detrimental effects associated with environmental cycling which characterize batch techniques.

Isolation of processing atmospheres by the indicated isolation chambers is accomplished within the isolation chambers by means of a series of counterflowing gasses which can comprise any of the inert gasses, such as nitrogen, argon, helium and the like and also other protective atmospheres, such as forming gas and hydrogen. Also included in this system is a suitable heater e.g. a resistance heater or an inductance heater, disposed about the reactor tube for heating and maintaining the transported wafers at operating or processing temperatures.

The process involved in the operation of the system of this example can be defined, in substance, as introducing semiconductor wafers through an isolation chamber into a preconditioning chamber in which the wafers are preheated to operating temperatures in a protective atmosphere, as indicated above, which is compatible with ambient atmospheres and the reaction gasses in the system; and while the wafers are maintained at operating temperatures, immediately and sequentially passing them through the processing chamber containing the metal depositing atmosphere from which the wafers pass through a cool-down chamber of the indicated protected atmosphere wherein the wafers are cooled to below reactive temperatures and from which the wafers pass through a second isolation chamber into an outlet ambient buffer chamber from which they emerge from the reactor tube into ambient atmospheres.

This process is also characterized in that a series of semiconductor wafers are continuously passed in linear array through the processing chambers with substantially 100 percent separation maintained between the preheat and cool-down chambers on the one hand, and external ambient atmosphere on the other hand.

Also, the process is further characterized in that the various processing and isolating atmospheres are maintained at substantially constant concentration and environment whereby each respective atmosphere concentration level and pressure is non-fluctuating. In essence, the invention processes the semiconductor materials sequentially at common ambients,

such as temperature, which eliminates the deleterious effects produced by switching gas flows, etc. and temperature recoveries, which are noted for examples and which introduced transients in an otherwise undisturbed system. Secondly, each chamber provides its own environment which is stable over long periods compared with the processing time of the material in that chamber.

In the same fashion as shown in the preceding examples, a continuous tier of wafer carriers 50, as in FIG. 5, have a rectangular configuration and are transported in end-to-end relationship by a feed mechanism generally indicated by the number 51 into a quartz processing tube 52 disposed within heating coils 53 (FIG. 20) which may be optionally enclosed in a furnace enclosure 55 of the usual construction.

The carriers 50 may be fabricated of any suitable material, such as quartz or graphite, which is compatible with the semiconductor substrates which are to be supported thereon. In general, the material of carriers 50 will generally determine the type of heater coils 53 employed in conjunction with reactor tube 52. In a system employing quartz carriers, the heating coils 53 would generally comprise resistance heater coils, and conversely, the use of graphite in the construction of the carriers permits the use of resistance heater coils or induction heater coils in the system. In the instant example, the carriers 50 are shown as fabricated of suitable susceptor materials such as graphite, carbon and the like, and the heating coils 53 are high frequency water cooled induction heater coils for RF coupling with the carriers to provide the desired zone heating of the wafers to processing temperatures.

The processing tube shown here is also of rectangular configuration having an internal height of about 33 mm. and an internal width of about 89 mm. with an overall length of about 78 inches subdivided into appropriate chambers to be described below.

The carrier 50, illustrated in FIG. 6 is employed for processing wafers having 2½-inch diameters with it being understood that other variations in carrier and wafers aforesaid discussed in conjunction with Example 1 may also be employed where desired or required. As in the previous embodiment, the carriers 50 were fabricated in a 3.45 inch square configuration with a thickness of about 0.5 inches with skids or rails 62 of about 0.015 inches depending from the bottom of the carrier to provide an overall height of 0.515 inches which defines a free-flow area of 17.7 sq. cm. in the unbaffled portions of the tube.

As above, the top surfaces of the carriers 50 in this example, are recessed at 63 to a sufficient depth to seat and maintain therein a semiconductor wafer 64 of silicon and the like for multi-stage processing through tube 52. In general, the top surface of the wafer would be substantially flush with the top surface of carrier 50 while seated therein.

A typical feed station for this example may be similar in construction to that shown in FIG. 5 which comprises an endless conveyor 65 which propels the carriers to the drive unit 66 which comprise two side-gripping endless belts which contact the carriers on their sides to propel them in end-to-end relationship through processing tube 52. A transfer plate 67 is provided with a side-guide 67A for feeding the carriers in end-to-end relationship through processing tube 52. The tube 52, shown in FIG. 20, is configured to deposit a metal film on preconditioned silicon wafers 64.

Basically, the reactor tube 52 of FIG. 20 is subdivided into an ambient inlet buffer chamber or zone 69, a critical or isolation buffer feed chamber 70, a preheat chamber 71, a metal plating chamber 71A, a cool-down section 71B, a second isolation chamber 73, and a second ambient outlet buffer chamber 77. In general, since chambers 69, 70, 71, 71A, 71B, 73 and 77 are basically identical to the corresponding chambers of the preceding examples, no further discussion is believed necessary with regard to these chambers, and reference is merely directed to the preceding discussions thereof, including the general relationship of gas pressures and flows which are here also applicable. It is only noted that the overall length

of the tube 52 is about 78 inches with the preheat section 71 having a length of about 21 inches and the cool-down section 71B having a length of about 29 inches.

In operation, the tier of carriers 50 (supporting wafers 64) enter and pass through the ambient inlet buffer zone 69 which forms a preliminary barrier with ambient atmospheres by maintaining therein a protective atmosphere of about 0.003 p.s.i.g. by introducing therein through nozzle 80 a suitable controlled flow of gas, such as nitrogen, helium, argon, forming gas and the like. Generally however, for the instant processing system, the pressure in ambient buffer chamber 69 may extend from about 0.001 to about 0.05 p.s.i.g., and preferably from about 0.002 p.s.i.g. to about 0.005 p.s.i.g.

The tier of carriers 50 traveling at a rate of 1 inch per minute passes out of the ambient buffer chamber 69 into and through the critical isolation chamber 70, which isolates the succeeding three chambers (e.g. preheat chamber 71, processing chamber 71A and cool-down chamber 71B) from ambient atmospheres at the inlet of reactor tube 52.

As the tier of carriers 50 emerge from the isolation chamber 70, they enter into the preheat chamber 71 which may be partially or fully disposed within the heating coil 53 for heating the supported wafers 64 to processing temperatures, e.g. about 550°C. for silicon, with it being understood that the temperature may extend from the preferred range of about 300°C. to about 550°C. to a general range of about 250°C. to about 750°C. for metal plating wafer 64 by means of a plating atmosphere comprised of hydrogen and a metal halide such as molybdenum pentachloride. Conversely, these temperatures for plating germanium in a similar atmosphere will be in the same general ranges. As can be seen from the previous discussion of carriers 50, for this specific process utilizing RF induction heating coils 53, the carriers 50 are fabricated of suitable susceptor material such as graphite for coupling with the field of coil 53, with corresponding conduction and radiation heating of the supported wafer 64.

In this example, for a carrier travel rate of about 1 inch per minute through the preheat chamber 71, this chamber has a length of about 21 inches with it being understood that the indicated length is not necessarily restricted to the specific dimensions indicated therefor. In practice, the length of the preheat chamber can be readily varied, but as a general rule, it will be correlated to the rate of carrier travel and the temperature generated as required to bring the semiconductor wafers to processing temperatures. Conversely, with the length of preheat chamber 71 pre-fixed, it will be readily seen that the wafers can be brought to processing temperatures by suitable adjustment in the rate of carrier travel and/or in the temperature generated via the induction coil 53.

Since the preheated wafers are to be subjected to a processing step in the immediately following depositing chamber 71A by a means of an atmosphere containing argon, hydrogen gas and a metal halide, an argon environment is normally maintained in preheat chamber 71 in the general range of about 0.001 to about 0.05 p.s.i.g. and preferably from about 0.002 to about 0.005 p.s.i.g. However, it is pointed out that the pressure P71 (in preheat chamber 71) will be maintained at a level below the pressure in the preceding inlet compartment 70E (of isolation chamber 70) with the pressures coordinated so that there will be either a zero flow F6 between inlet compartment 70E and preheat chamber 71 or a positive flow F6 from inlet compartment 70E into preheat chamber 71, as can be seen on reference to FIG. 16.

The indicated pressures and environment in preheat chamber 71 is obtained by introducing and withdrawing argon, via respective inlet and outlet tubes 89 and 90, at a controlled rate which will also provide a substantially quiescent preheat atmosphere having a flow feed rate of about 2 liters/minute of argon (e.g. about 0.113 liters/minute/sq. cm. of chamber cross-section) from inlet tube 89 to outlet tube 90 with the flow rate not exceeding about 15 liters per minute (e.g. about 0.848 liters/minute/sq. cm. of chamber cross-section), and preferably from about 1.5 to about 12 liters per

minute (e.g. 0.0848 to 0.68 liters/minute/sq. cm. of cross-section).

After the preheating stage, the moving tier of carriers 50 emerge from the preheat chamber 71 and pass through processing chamber 71A in which is maintained a substantially quiescent gaseous environment of argon hydrogen and a metal halide (e.g. molybdenum chloride) flowing from its inlet to the outlet, 89 to 90 respectively, at a feed rate of about 9 to about 25 liters per minute at pressures in the general range of about 0.001 to 0.05 p.s.i.g., and preferably from about 0.002 to about 0.005 p.s.i.g. This flow feed rate is equivalent to a range of about 0.508 to about 1.41 liters/minute/sq. cm. of chamber cross-section. Typically, the metal plating atmosphere may comprise hydrogen and a halide of a metal having a resistivity less than about 100 microhms-cm. at 18°C. As will be understood, various metal plating atmospheres may be employed in processing chamber 71A.

Typically, the plating metal may be deposited on a substrate by pyrolytic decomposition of convention decomposable plating metal compounds such as the carbonyls, nitroxyls, nitrosyls, hydrides, alkyls, halides, and the like which may be vapor deposited on the substrates from heat decomposable compounds thereof. Illustrative compounds of the carbonyl type are nickel, iron, chromium, molybdenum, cobalt. Representative nitroxyls are the nickel and copper nitroxyls. Hydride compounds of these metals are exemplified by antimony hydride, pentahydride, and a metal alkyl may typically be aluminum and magnesium alkyls. Examples of the halide are chromyl chloride, osmium carbonyl, bromide and the like.

For pyrolytic deposition, the metals to be deposited may, in one instance, be introduced in the reactor chamber as gaseous metal carbonyls or vaporized solutions thereof, after a preliminary preheating thereof to temperatures approaching decomposition temperatures. The preheated metallic compounds upon contact with the heated substrates, in the reaction chamber, decompose at the surface of the substrates to liberate metal which is deposited thereon. Each heat decomposable metal plating compound from which the metal is to be plated has a temperature at which decomposition takes place. For example, the decomposition may take place slowly at a lower temperature, or while the vapors are being raised in temperature through some particular range. Thus nickel carbonyl completely decomposes at a temperature in the range of 375°F. to 400°F. whereas nickel carbonyl may start to decompose slowly at about 175°F. with the decomposition continuing during the time of heating from 200°F. to 380°F. In the general, a large number of the metal carbonyls and hydrides may be effectively and efficiently decomposed at a temperature in the range of 350°F. to 450°F.

In the preferred embodiment, as used in the specific example set out below, the metal plating atmosphere comprises a three component gaseous mixture wherein the first component is hydrogen and the second component is argon and the third component is a halide of a plating metal having a resistivity less about 100 microhms-cm., as for example, tungsten pentachloride and specifically, molybdenum pentachloride. A typical mixture of this metal plating atmosphere will comprise a feed of 6 liters/minute H₂ and 3 liters/minute Ar and about 6 volume percent of molybdenum pentachloride per 9 liter volume. In the process, the metal plating atmosphere (e.g. molybdenum pentachloride, argon and hydrogen) may be preheated externally of reactor tube 52, and injected therein via the inlet nozzle 89 (of processing chamber 71A) wherein upon contact with the heated wafers 64, the metal halide is reduced by hydrogen with liberation of the metal (e.g. molybdenum) at the surface of wafer 64 whereat the liberated metal is deposited.

After the passage of the substrates through the metal plating chamber 71A, the carrier-supported substrates enter the cool-down chambers 71B which is provided with a flow of a protective atmosphere which may be comprised of inert atmosphere such as nitrogen, helium or argon and preferably argon, whereas in the instant example, the argon has also been em-

ployed in a processing chamber 71A.

After passing through the cool-down chamber 71B of about 29 inches in length, the carriers 50 (with the wafers supported thereon cooled to below reactive temperatures) enter and pass through a second isolation chamber 73 which is, for all practical purposes, identical to the previously described isolation chamber 70. The basic function of isolation chambers 73 is, in conjunction with the flow of protective gasses therein, to effect critical isolation between the metal plating chamber 71A and external ambient atmospheres at the outlet of reactor tube 52.

As the carriers 50 emerge from the isolation chamber 73 they pass into and through an ambient outlet buffer chamber 77 to discharge across a transfer table 98 between conveyor belts 99 as shown, the outlet buffer chamber 77 is about 5 inches in length and is provided with a protective atmosphere via its inlet nozzle 89 with discharge of gasses effected into ambient atmospheres through the restricted openings defined by end partition 78A and the surface of carriers 50.

In order to maintain the integrity of the atmospheres in the respective preheat, processing and cool-down chambers 71, 71A, and 71B, isolation chambers 70 and 73 are interposed between each chamber and an ambient atmosphere in accordance with our teachings above. As described above, one of these isolation chambers is interposed between the preheat chamber 71 and ambient atmospheres (including inlet buffer chamber 69), and a second isolation chamber 73 is interposed between the cool-down chamber 71B and external ambient atmospheres (including outlet buffer chamber 77). Each of the isolation chambers 70 and 73 is subdivided into a series of alternate inlet and outlet compartments, comprising three inlet compartments and two outlet compartments, with two end-most compartments disposed adjacent to the ambient buffer chambers and the corresponding one of the preheat and cool-down chambers 71 and 71B.

To illustrate the operation of the above described system of this example, the following Table 10 is set forth to illustrate the environment and the results of a specific operating system for processing of surface preconditioned silicon wafers supported on the carriers traveling through the system at the rate of 1 inch per minute. For the specific example set out below the metal deposition atmosphere comprised a 6 liter/minute flow of hydrogen combined with a 3 liter/minute flow of argon containing by volume, 6 percent molybdenum pentachloride ($MoCl_5$).

EXAMPLE VI

Silicon Nitride Deposition

This example, in conjunction with FIGS. 5-7, 9-14, 16 and 21 describes the continuous processing system for forming a nitride film on exposed surfaces of semiconductor substrates.

In the same fashion shown in the preceding examples, a continuous tier of wafer carriers 50 having a rectangular configuration are transported in end-to-end relationship by feed mechanism generally indicated by the numeral 51 into a quartz processing tube 52 disposed within heating coil 53

which may be optionally enclosed in a furnace enclosure 55 of the usual construction.

In the instant example, a wafer of 2 1/2-inch diameter was employed with the carrier illustrated in FIG. 6. However, it is to be understood that the other variations in carrier and wafer aforesubjected may also be employed where desired or required. Also, since an RF heater coil 53 is shown and employed in this example, the carriers 50 are fabricated of suitable susceptible material such as graphite, carbon, molybdenum and the like. However, it is to be understood that the carriers 50 may be constructed of other suitable materials compatible with the wafers and with process environments. In general, the material of carriers 50 will normally determine the type of heater coils employed in conjunction with reactor tube 52. For example, in a system employing quartz wafer carriers, the heating coils can conveniently comprise resistance coils and conversely, the use of graphite in the construction of the carrier permits the use of resistance heater coils or induction heater coils in the system.

The processing of this example as illustrated in the FIG. 21, is also of rectangular configuration having an internal height of about 33 mm., and internal width of 89 mm. and an overall length of about 78 inches subdivided into appropriate chambers to be described below.

The carriers 50, as in the previous embodiments, were fabricated in a 3.45 inch square configuration, with a thickness of about 0.5 inches and having skids or rails 62 of about 0.015 inches, depending from the bottom of the carriers, to provide an overall height of 0.515 inches defining a free-flow area of 17.7 sq. cm. in the unbaffled portions of the tube. Likewise, the top surfaces of carriers 50 are recessed at 63 to a sufficient depth to seat and maintain therein a semiconductor wafer 64 (as for example of silicon, germanium and the like) for processing through tube 52. In general, the top surfaces of the wafers will be substantially flush with the top surfaces of the carriers 50 while seated therein.

A typical feed station for this example is similar in construction to that shown in FIG. 5, which comprises an endless conveyor 65 which carries the carriers to the drive unit 66 which comprise two side-gripping endless belts which contact the carriers on their sides to propel them in end-to-end relationship through the processing tube 52. A transfer plate 67 is provided with side-guides 67A for feeding the carriers 50 in end-to-end relationship through the processing tube 52.

Basically, the reactor tube 52 is subdivided into an ambient inlet buffer chamber or zone 69, an isolation chamber 70, a preheat chamber 71, a nitriding chamber 71A, a cool-down chamber 71B, a second isolation chamber 73 and an ambient outlet buffer chamber 77. In general, since chamber 69, 70, 71, 71A, 71B, 73 and 77 of this example (e.g. FIG. 2) are identical to the corresponding chamber of the preceding examples (e.g. FIG. 20 etc.) no further discussion is believed necessary with regard to these chambers with reference merely directed to the preceding discussion thereof, and accordingly like numerals are employed for corresponding por-

tions of this example as in the preceding examples. In general, it is only noted that the overall length of the tube is about 78 inches and the rate of travel of carriers 50 through the reactor tube 52 is about 1 inch per minute. The inlet buffer zone 69 is about 5 inches in length and also forms a preliminary barrier with ambient atmospheres. The inlet buffer chamber 69 has a protective atmosphere of about 0.003 p.s.i.g. by introducing therein, as in the previous examples, a suitably controlled flow of inert gas such as nitrogen, helium, argon, forming gas and the like. Generally however, for the instant processing system, the pressure in the ambient inlet chamber 69 may extend from about 0.001 to about 0.05 p.s.i.g. and preferably from about 0.002 to about 0.005 p.s.i.g.

The tier of carriers 50 traveling at the indicated rate of 1 inch per minute, passes out of the ambient inlet buffer chamber 69 into and through the critical isolation chamber 70 having the same structural configuration indicated for the processing tube of the previous example.

Isolation chamber 70 also forms, in this example, substantially 100 percent separation between the ambient inlet buffer chamber 69 and the preheat chamber 71 to maintain the integrity of the processing atmosphere therein.

Inlet compartments 70A, 70C and 70E of the isolation chamber 70 are provided with protective atmospheres which may comprise any of the inert gasses such as nitrogen, argon, helium and also other non-reactive gasses such as forming gas and the like. In general, the pressure relationships of the preceding examples will be maintained within the various compartments of isolation chamber 70 and between the adjacent ambient inlet chamber 69 and the preheat chamber 71 so as to maintain the same flow relationships indicated above.

As the tier of carriers 50 emerge from the last inlet compartment 70E of isolation chamber 70, the carriers enter into the preheat chamber 71 disposed within the heating coil 53 for heating the supported wafers 64 to processing temperatures, e.g., about 850° C. for silicon, with it being understood that the temperatures may extend from the preferred range of about 800° C. to about 1,100° C. to a general range of about 700° C. to about 1,125° C. Conversely, these temperatures for germanium will be in the general range of about 700° C. to about 940° C. and preferably from about 750° C. to about 850° C.

In this process, utilizing silicon wafers in conjunction with a carrier travel rate of about 1 inch per minute through the preheat chamber 71, this chamber has a length of about 19 inches and is defined between the flanged partitions 81 and 91.

Normally, the environment of preheat chamber 71 will be selected so as to be compatible with the nitriding atmosphere in the succeeding reaction chamber 71A defined between partitions 91 and 91A. For example, the protective atmosphere in preheat chamber 71 may also comprise any of the above indicated inert gasses. In the preferred application, since a nitriding atmosphere is employed in the succeeding chamber 71A, the protective gas in preheat chamber 71 may conveniently be nitrogen in the general range of about 0.001 to about 0.05 p.s.i.g.; and preferably from about 0.002 to about 0.005 p.s.i.g., flowing via the chamber's inlet and outlet, 89 and 90, respectively, at a flow rate of about 4 liters/minute (e.g., 0.226 liters/minute/sq. cm. of chamber cross section) out of which may extend in the general range of about 2 to about 10 liters per minute (e.g. 0.113 to 0.565 liters/minute/sq. cm. of cross section) and preferably from about 3 to about 7 liters per minute (e.g., about 0.170 to about 0.369 liters/minute/sq. cm. of chamber cross section). As will be understood from the discussions above, the pressure P71 in preheat chamber 71 will be maintained at a level below the pressure P70E in the preceding inlet compartment 70E (of isolation chamber 70), and coordinated therewith so that there will be either a zero flow F6 between inlet compartment 70E and preheat chamber 71, or a positive flow F6 from inlet compartment 70E into preheat chamber 71, as per FIG. 16.

After the preheating stage, the moving tier of carriers 50 emerge from the preheat chamber 71 and pass through the

nitriding chamber 71A of about 10 inches in length in which is maintained a substantially quiescent environment of a nitriding atmosphere which, in a specific application, is comprised of silane, ammonia in conjunction with hydrogen as a carrier therefor. This reactive atmosphere is maintained in a continuous flow from the chamber's inlet tube 89 and outlet tube 90 at a feed rate not greater than about 20 liters per minute (e.g., 1.13 liters/minute/sq. cm. of chamber cross section), and preferably from about 5 to about 15 liters per minute (e.g., 0.282 to about 0.848 liters/minute/sq. cm. of chamber cross section). In general, the rate of flow will be sufficient to maintain a substantially constant proportional concentration of the reactive gas components in chamber 71A at pressures in the general range of 0.001 to 0.05 p.s.i.g. and preferably from about 0.002 to 0.005 p.s.i.g. A typical composition of the above indicated nitriding atmosphere may comprise, by volume, from about 0.005 to about 0.05 percent silane and from about 0.05 to about 0.05 percent ammonia, in 10 liters of hydrogen. A specific mixture of this nitriding atmosphere, as used in the specific example set out below comprised, by volume 0.02 percent silane, 0.2 percent ammonia in 10 liters of hydrogen.

With the specific nitriding atmosphere indicated, a silicon nitride film is deposited on the surfaces of the substrates by the reaction of silane and ammonia in the presence of excess nitrogen which suppresses premature decomposition of silane. The reaction preferably occurs at the surfaces of the substrates which are heated to a temperature in the general range of 700° C. to about 1,125° C. and preferably from about 800° C. to about 1,100° C. Although a specific processing atmosphere has been indicated, it is to be understood that various nitriding atmospheres may be employed in processing chamber 71A.

For example, the nitriding atmosphere may comprise an inert carrier gas (preferably nitrogen), ammonia and a silicon halide, such as silicon tetrachloride. In operation, this atmosphere is introduced into processing chamber 71A below reactive temperatures (e.g., between the silicon halide and the ammonia), with the reaction between the silicon halide and the ammonia taking place at the heated surfaces of the substrates to form silicon nitride which deposits on the substrates.

Also, the nitriding atmospheres may be comprised of silane, ammonia and oxygen to deposit amorphous films of silicon nitride/silicon oxide mixtures on the substrates. These composite film-forming atmospheres may be mixed and preheated externally of the reactor tube 52 at temperatures below that which the reaction between the silane and ammonia and oxygen is initiated followed by injection of the mixture into processing chamber 71A wherein the substrates are heated to processing temperature. In general, the wafers or substrate 64 are heated to a temperature sufficient to initiate the reaction between silane, ammonia and oxygen which is presumed to involve the decomposition of silane and subsequent nitridation and oxidation of the liberated silicon.

Another nitriding atmosphere which can be used in this embodiment comprises a three component mixture of silane, ammonia and nitric oxide from which silicon oxynitride films may be deposited on a substrate by an initiated reaction between the silane, ammonia and nitric oxide at elevated temperatures. Similarly the components may be premixed and preheated externally in the reactor tube 52 to below reactive temperatures, introducing the reactive gasses into the reaction chamber 71A wherein the reaction therebetween is effected at the surfaces of the heated substrates to cause deposition of a silicon oxynitride film thereon.

After passage of the substrates through the nitriding chamber 71A, the carrier supported substrates enter and pass through a cooldown chamber 71B which is provided with a flow of a protective atmosphere which can be comprised of the conventional inert atmosphere such as nitrogen, helium, argon and the like, and may also include hydrogen where the gas is common with a component employed in the nitriding atmosphere of processing chamber 71A.

After passage through the cooldown chamber 71B of about 8 inches in length, the carriers 50 (with the wafers 64 supported thereon and cooled below reactive temperatures) enter and pass through a second isolation chamber 73 which is, for all practical purposes, identical to the previously described isolation chamber 70.

Since these two isolation chambers 70 and 73 are identical, and since the correlation of pressures in the various inlet compartments and outlet compartments are identical to the pressures in the corresponding inlet and outlet compartments of the previous examples, no extended description is necessary. If required, such details may be easily ascertained by reference to the above description of corresponding portions of this isolation chamber. In general, the pressure P71B in cooldown chamber 71B will be correlated to the pressure P73A in the inlet compartment 73A (of isolation chamber 73) so that there will be zero flow therebetween, or a positive flow from the inlet compartment 73A into cooldown chamber 71B.

The basic function of isolation chamber 73 is for use of non-reactive or protective gasses to effect critical isolation between nitriding chamber 71A and external ambient atmospheres.

As the carriers 50 emerge from the isolation chamber 73, they pass into and through an ambient outlet buffer chamber 77 to discharge across the transfer table 98 between conveyor belts 99. As shown, the outlet buffer chamber is about 5 inches in length and is provided with a protective atmosphere (e.g., inert gasses) with discharge of the gasses effected into ambient atmospheres through the restricted openings defined by end partition 78A and the surfaces of carriers 50.

To illustrate the operation of the above described system, as shown in FIG. 21, the following Table 11 is set forth to illustrate the process parameters of a specific operating system for depositing a silicon nitride film on silicon wafers supported on carriers 50 traveling through the system at a rate of 1 inch per minute. For the specific example set out below the silicon nitride forming atmosphere comprised a hydrogen feed of 10 liters/minute containing, by volume, 0.02 percent silane and 0.2 percent ammonia.

EXAMPLE VII

Sequential Vapor Etching and Silicon Oxide Deposition

This example, in conjunction with FIGS. 5-7, 9-17 and 22 describes a continuous multistage processing system for sequentially vapor etching semiconductor wafers and depositing silicon oxide film from a vapor state, onto the substrates without exposure of the substrates to ambient intermediate the processing operations.

In the same manner described in the preceding examples, a continuous tier of wafer carriers 50 having a rectangular configuration are transported end-to-end relationship by feed mechanism generally indicated by the numeral 51 into a quartz processing tube 52 disposed within heating coils 53 and 54 which may be optionally enclosed in a furnace enclosure 55 of the usual construction.

Since RF heater coils 53 and 54 are also shown and employed in this example, the carriers 50 are fabricated of suitable susceptor materials such as graphite, carbon, molybdenum and the like. However it is to be understood that carriers 50

5 may also be constructed of other suitable materials compatible with the wafers and with process environments. In general, the materials of carriers 50 will normally determine the type of heater coils employed in conjunction with reactor tube 52. Thus, in a system employing quartz carriers, the heating coils 10 can conveniently comprise resistance coils, and conversely, the use of graphite in the construction of the carriers permits the use of either resistance coils or induction heater coils in the system.

15 The carriers 50 employed in this example also have the configuration shown in FIG. 6 and are employed for processing the wafers having 2½-inch diameter with it being noted that other variations in carrier and wafer aforesubscribed in conjunction with the previous examples may also be employed 20 where desired or required. Again, as in the previous embodiments, the carriers 50 were fabricated in a 3.45 inch square configuration with a thickness of about 0.5 inches with skids or rails 62 of about 0.015 inches depending from the bottom of the carrier to provide an overall height of 0.515 inches 25 which defines a free-flow cross-sectional area of 17.7 sq. cm. in the unbaffled portion of the tube.

Also the top surfaces of carriers 50 in this example are recessed at 63 to a sufficient depth to seat and maintain therein a semiconductor wafer 64 of silicon and the like for 30 multistage processing through tube 52. In general, the top surface of the wafers will be substantially flush with the top surface of carriers 50 while seated therein.

The feed station shown in FIG. 5 may be also employed in 35 this example, and comprises an endless conveyor 65 which carries the carriers through the drive units 66 which comprises two side-gripping endless belts which contact the carriers on their sides to propel them in end-to-end relationship through processing tube 52. A transfer plate 67 is provided with side-guides 67A for feeding the carriers 50 in end-to-end relationship through the processing tube 52.

60 The tube 52 shown in FIG. 22 is configured to sequentially process a pre-conditioned silicon wafer 64 by vapor etching thereof followed by vapor state deposition of silicon oxide film on the substrates.

65 Basically the reactor tube 52 of FIG. 22 is subdivided into an ambient inlet buffer chamber or zone 69, a critical isolation chamber 70, a preheat chamber 71, a vapor etch chamber 71A, a secondary three-compartmented isolation chamber 92, an oxidation chamber 93, a post cooldown chamber 93A, a critical isolation chamber 73, and an ambient outlet buffer chamber 77.

70 The buffer zone 69 of about 5 inches in length is defined by partitions 78 and 79 with partition 78 extending toward the bottom of reactor tube 52 a distance providing about 0.25 inches clearance with the top of a tier of carriers 50. Buffer zone 69 forms a preliminary barrier with ambient atmospheres

and is maintained with a non-reactive atmosphere of about 0.05 p.s.i.g., by introducing therein through a circumferential slot 80A of a closed end nozzle 80 (of about 5 mm. ID) a suitably controlled flow of an inert gas such as nitrogen, helium, argon, forming gas and the like. Generally however, for the processing system of this example, the pressure in an ambient buffer chamber 69 may extend from about 0 to about 0.003 p.s.i.g., and preferably from about 0.001 p.s.i.g. to about 0.005 p.s.i.g. As indicated, nozzle 80 is a closed end structure having the configuration shown in FIG. 12.

The tier of carriers 50 traveling at a rate of 1.0 inches per minute passes out of the ambient buffer chamber 69 into and through the critical isolation chamber 70 having the same structural configuration indicated therefore in the previous examples; and, accordingly, like component features are indicated by the same reference numerals.

Also, as in the preceding examples, the isolation chamber 70 is subdivided into a series of alternate inlet and outlet compartments, into which protective gasses are introduced and withdrawn. For the particular isolation obtained, the isolation chamber 70 is subdivided into an inlet compartment 70A, an outlet compartment 70B, a second inlet compartment 70C, a second outlet compartment 70D, and a third inlet compartment 70E, each about 1 inch in length. In general, the pressure relationships of the preceding examples will also be maintained within the various compartments of isolation chamber 70 and between the adjacent ambient inlet chamber 69 and the preheat chamber 71, so as to maintain the same flow relationships indicated above therefor.

As a tier of carriers 50 emerge from the last inlet compartment 70E of isolation chamber 70, the carriers enter into the preheat chamber 71, disposed within the heating coil 53 for heating the supported wafers 64 to processing temperatures, e.g., about 1,200° C. for silicon with it being understood that the temperature may extend from the preferred range of about 1,175° to about 1,250° C., to a general range of about 1,000° to about 1,300° C. Conversely, these temperatures for germanium will be in the general range of about 350° C. to about 900° C. and preferably from about 810° to about 840° C.

In this example, for a carrier travel rate of 1.0 inches per minute through the preheat chamber 71, this chamber has a length of about 22 inches and is defined between the flanged partitions 81 and 91.

Normally, the environment in preheat chamber 71 will be selected, as indicated in Example 4, so as to be compatible with the etching atmosphere in the succeeding processing chamber 71A defined between partitions 91 and 96. For example, the protective atmosphere in preheat chamber 71 may not only comprise any of the indicated inert gasses but also preferentially includes hydrogen. In a specific application, utilizing a gas mixture of hydrogen and hydrogen chloride in the etching chamber 71A, hydrogen is conveniently employed for the atmosphere in preheat chamber 71 in the general range of about 0.001 to about 0.05 p.s.i.g. and preferably from about 0.002 to about 0.005 p.s.i.g. It is to be understood that the pressure P71 in preheat chamber 71 will be maintained at a level below the pressure P70E in the preceding inlet compartment 70E (of isolation chamber 70), and coordinated therewith so that there will be either a zero flow F6 between inlet compartment 70E and preheat chamber 71, or a positive flow F6 from inlet compartment 70E into preheat chamber 71.

After the preheating stage, the moving tier of carriers 50 emerge from the preheat chamber 71 and pass through the reaction chamber 71A of about 4 inches in length in which is maintained a substantially quiescent environment of hydrogen and a hydrogen halide gas flowing from its inlet tube 89 to its outlet tube 90 at a feed rate not greater than about 8 liters per minute (e.g., 0.45 liters/minute/sq. cm. of free-flow cross section) and preferably from about 6 to about 12 liters per minute (e.g., about 0.339 to about 0.68 liters/minute/sq. cm. of free-flow cross section).

For example, the etching atmosphere may comprise hydrogen containing from about 2 to about 12 percent by

volume of a hydrogen halide such as hydrogen chloride, hydrogen bromide, hydrogen fluoride and hydrogen iodide. In the preferred embodiment, as used in the specific example set out below, the halide of the etching atmosphere is hydrogen chloride. A typical mixture of this etching atmosphere will comprise from about 6 to about 12 liters/minute of hydrogen containing from about 2 to about 12 volume per cent hydrogen chloride.

After passage through the etching chamber 71A, the carriers 50 enter and pass through a secondary three-compartmented isolation chamber 92 having, with exception of dimensional variations noted, the configuration previously described in conjunction with FIG. 2. As the wafers pass through the three-compartmented isolation chamber 92, they are concurrently passed out of heating coil 53 whereupon the wafers are cooled for oxide deposition in chamber 93, e.g., the silicon wafers are cooled within a general range of about 600° to about 1,300° C.; and preferably within about 750° to about 900° C.

In the processing system embodied in FIG. 22, the three-compartmented isolation chamber 92 forms a buffer-separating unit between the etching chamber 71A and the oxide deposition chamber 93 to maintain the basic integrity of the processing atmospheres therein. To provide the degree of isolation desired between the two reactive chambers (e.g., 71A and 93), the isolation chamber 92 is subdivided into a series of alternate outlet and inlet compartments into which a non-reactive gas, such as any of those indicated above, is respectively withdrawn and introduced. For the particular isolation obtained, the isolation chamber 92 is subdivided into an outlet compartment 92A, an inlet compartment 92B, and a second outlet compartment 92C.

The outlet compartment 92A is about 2½ inches in length and is defined between flanged partitions 96 and a baffle 97 in which a non-reactive atmosphere is maintained at a pressure of about 0.001 p.s.i.g.

A gas mixture is formed in the outlet compartment 92A by the in-flowing atmosphere and gas from respectively etching chamber 71A and inlet compartment 92B (of isolation chamber 92) with the gasses exhausted via an outlet 94 which exhausts the gasses under the sole impetus of the gas flows into the outlet compartment. However, as previously indicated, positive exhaust means may be employed to assist in exhausting the gasses if desired and where the requirements of a processing system require it. It is also noted that the indicated baffle 97 extends to about 0.020 inches of the top of carriers 50 to define a clearance substantially larger than that defined by the flange 82 of partition 96. In general, the pressure in outlet compartment 92A may extend in the range from about 0 p.s.i.g. to about 0.003 p.s.i.g., and preferably from about 0 to about 0.002 p.s.i.g. However, in all cases, the pressure P92A in outlet compartment 92A will be lower than the pressure P71A in etching chamber 71A with a pressure differential therebetween, $\Delta P1$, of at least 0.001 p.s.i.g.

In the preferred construction, baffle 97 extends to within 0.20 inches of the top of carriers 50 to define a restricted clearance with the carriers larger than the corresponding clearance formed under the flange 82 of partition 96. As will be understood, since the flow in the orifice equation is directly proportional to the orifice area, the flow (under like conditions) will be greater in a larger orifice than that in a smaller orifice. The significance of this becomes evident upon consideration that the broad pressure range in the succeeding inlet compartment 92B of 1 inch is of the order of about 0.002 p.s.i.g. to about 0.01 p.s.i.g. and preferably from about 0.002 to about 0.02 p.s.i.g. with a pressure differential $\Delta P2A$ of at least 0.002 p.s.i.g. Generally, as shown in FIG. 15, the pressure differentials $\Delta P1$ and $\Delta P2$ are coordinated with each other and with other pressure differentials (as described below), in the remaining compartments and chambers of the reaction tube 52, so that there will be a positive flow from the etching chamber 71A into the outlet compartment 92A.

The inlet compartment 92B, aforeindicated, is defined between the baffle 97 and a second like baffle 97A, wherein

both define like clearances with the top of wafer carriers 50. A non-reactive gas (the same as employed in the preceding isolation chamber 70 of the tube) is introduced through the inlet nozzle 95, having the same general configuration as the previously described inlet nozzle 86, to maintain a pressure substantially higher than the pressures in the outlet compartment 92A and in the following outlet compartment 2½ inch 92C, as for example, about 0.005 p.s.i.g.

Generally the pressure in the inlet compartment 92B will be maintained in the range of about 0.002 to about 0.01 p.s.i.g., and preferably from about 0.002 to about 0.02 p.s.i.g. However, as indicated, the pressure in inlet compartment 92B will be maintained at a level substantially higher than the pressures in either of outlet 92A and 92C. Conversely, the pressure will also be at a level higher than the pressures in etching chamber 71A and the oxide deposition chamber 93, wherein the relationship is graphically shown in FIG. 15.

As the carriers 50 emerge from separation chamber 92, they enter and pass through an oxide deposition chamber 93 which is about 8 inches in length and is defined between flanged partition 96A and flanged partition 91 of the post-cool chamber 93A. Concurrently the wafers pass within heating coil 54 which maintains processing temperatures.

The oxidation chamber 93 comprises a section of processing tube 52 wherein the substrates or wafers 64 are subjected to an atmosphere in which a volatile silicon compound is being thermally decomposed with reduction by

wafers transported through the oxidation chamber 93 at a throughput of about 0.5 to about 3 inches per minute, oxide films of about 2,000 to about 7,000 Å. thick are generated.

Upon emerging from the deposition chamber 93, the carrier supported wafers 64 pass through the post-cool chamber 93A of about 18 inches in length and similar in construction to the preheat chamber 71. Here the wafers are cooled below critical or reactive temperatures, e.g., to about or below 400° C.

After cooling, the wafers pass through the isolation chamber 73 similar in construction and function to those previously discussed in greater detail with respect to isolation chamber 70 of the present and preceding examples. However, during passage through the isolation chamber 73, the carriers and wafers are allowed to further cool toward ambient temperature as they emerge into outlet buffer chamber 77 for final exiting across a transfer table onto a conveyor for removal from the system.

To illustrate the operation of the above described system, as shown in FIG. 22, the following Table 12 is set forth to illustrate the environment and the results of a specific operating system for processing of surface preconditioned silicon wafers supported on carriers traveling through the system at a rate of 1 inch per minute. For the specific example set out below the vapor etch atmosphere comprised of hydrogen containing, by volume, 6 percent hydrogen, and the silicon oxide depositing atmosphere comprised hydrogen containing, by volume, 1.0 percent oxygen and 0.5 percent silicon tetrachloride.

hydrogen at a temperature below the melting point of the substrate, and reacted with oxygen to form a silicon oxide layer which is deposited as a film on the substrate. Although various atmospheres for the formation of a silicon oxide film may be employed, as shown in FIG. 22 a preferred gas is one composed of hydrogen and silicon-bearing compounds (as for example, silicon tetrachloride) in combination with oxygen or carbon dioxide. A typical composition of hydrogen/oxygen/silicon-bearing compounds would be comprised, by volume, of about 92 to 99 percent hydrogen, about 0.4 to 0.6 percent oxygen and about 0.9 to 1.2 percent silicon tetrachloride. Where a gas composition comprised of hydrogen/carbon dioxide/silicon-bearing compound is employed as an oxide depositing environment, a typical composition will comprise, by volume, from about 0.92 to about 1.2 percent silicon tetrachloride, about 92 to about 99 percent hydrogen and from about 2.0 to about 8.0 percent carbon dioxide.

In general, the temperature in the oxide depositing chamber 93 and, in particular, the temperature of the carrier supported substrates 64 will be maintained in a range from about 750° to about 900° C. whereby a film of a silicon oxide compound is deposited on the substrate from the silicon oxide forming environment flowing through the oxidation chamber 93 at an optional feed rate of about 5 to 10 liters per minute (e.g., about 0.282 to about 0.565 liters/minute/sq. cm. of free-flow cross section) by introduction of the atmosphere via the inlet tube 89 and exhausting of the gasses via outlet tube 90. With the

EXAMPLE VIII

50 Sequential Epitaxial and Silicon Oxide Film Depositions

This example, in conjunction with FIGS. 5, 7, 9-17 and 23 describes a continuous processing system for sequentially depositing an epitaxial film and a silicon oxide layer on semiconductor substrates.

In the same fashion described in the preceding examples, a continuous tier of wafer carriers 50 having a rectangular configuration are transported in end-to-end relationship by a feed mechanism generally indicated by the numeral 51 into a quartz processing tube 52 disposed within heating coils 53 and 54 which may be optionally enclosed in a furnace enclosure 55 of the usual construction.

Since the processing system of this example employs an epitaxial deposition on a semiconductor substrate or wafer, the carriers 50 are fabricated of a suitable susceptor material, such as graphite, carbon, and the like; and the heating coils 53 and 54 are high-frequency water-cooled induction heater section for HF coupling with the carriers to provide the desired zone heating of the wafers through processing temperatures.

The processing tube 52 shown here is also of rectangular configuration having an internal height of about 33 mm. and an internal width of 89 mm. with an overall length of about 78 inches subdivided into appropriate chambers to be described below.

The carriers 50 illustrated in FIG. 6 are employed for processing of wafers having 2½-inch diameter with it being understood that other variations in carriers and wafers aforesubussed in conjunction with the preceding examples may also be employed where desired or required. As in the previous embodiments, the carriers 50 were fabricated in a 3.45-inch square configuration with a thickness of about 0.5 inches and having skids or rails 62 of about 0.015 inches depending from the bottom of the carriers to provide an overall height of 0.515 inches defining a free-flow cross section of 17.7 square inches in the unbaffled portions of the tube.

As in the previous examples, the top surfaces of carriers 50 of this example are also recessed at 63 to a sufficient depth to seat and maintain therein a semiconductor wafer 64, of silicon and the like, for multistage processing through the tube 52. In general, the top surfaces of the wafers will be substantially flush with the top surface of carriers 50 while seated therein.

The feed station shown in FIG. 5 may also be employed in this example, and comprises an endless conveyor 65 which carries the carriers between the drive unit 66 which comprises two side-gripping endless belts which contact the carriers on their sides to propel them in end-to-end relationship through processing tube 52. A transfer plate 67 is provided with side-guides 67A for feeding the carriers 50 in end-to-end relationship through the processing tube 52.

The tube 52 shown in FIG. 23 is configured to sequentially process a pre-conditioned silicon wafer 64 by deposition of an epitaxial film followed by vapor state deposition of a silicon oxide film on the substrates.

Basically the reactor tube of FIG. 23 is subdivided into an ambient inlet buffer chamber or zone 69, a critical isolation chamber 70, a preheat chamber 71, an epitaxial film deposition chamber 71A, a secondary three-compartmented isolation chamber 92, an oxide deposition chamber 93, a post-cool chamber 93A, a critical isolation chamber 73 and an ambient outlet buffer chamber 77.

The buffer zone or chamber 69, of about 5 inches in length, is defined between partitions 78 and 79, with partition 78 extending toward the bottom of the reactor tube 52 a distance providing about 0.25 inch clearance with the top of a tier of carriers 50. Buffer zone 69 forms a preliminary barrier against ambient atmospheres and it is maintained with a non-reactive protective atmosphere of about 0.05 p.s.i.g. by introducing therein through a circumferential slot 80A of a closed end nozzle 80 (of about 5 mm. ID), a suitably controlled flow of an inert gas such as nitrogen, helium, argon, forming gas and the like. Generally however, for this processing system, the pressure in ambient buffer chamber 69, as above, may extend from about 0 to about 0.003 p.s.i.g. and preferably from about 0.001 to about 0.005 p.s.i.g. As indicated, nozzle 80 is a closed end construction having the configuration shown and described in reference to FIG. 12.

The tier of carriers 50 traveling at a rate of 1.0 inch per minute passes out of the ambient buffer chamber 69 into and through the critical isolation chamber 70 having the same structural configuration indicated therefor in the previous examples; and accordingly, like component features are indicated by the same reference numerals.

Also, as in the preceding examples, the isolation chamber 70 is subdivided into a series of alternate inlet and outlet compartments into which protective gasses are introduced and withdrawn. For the particular isolation obtained, the isolation chamber 70 is subdivided into an inlet compartment 70A, an outlet compartment 70B, a second inlet compartment 70C, a second outlet compartment 70D, and a third inlet compartment 70E, each about 1 inch in length. In general, the pressure relationships of the preceding examples are also maintained within and between the various compartments of isolation chamber 70, and between the adjacent ambient inlet chamber 69 and the preheat chamber 71, so as to maintain the same flow and pressure relationships indicated above therefor.

As the tier of carriers 50 emerge from the last compartment 70E of isolation chamber 70, the carriers enter into a non-

reactive preheat chamber 71 disposed within the heating coil 53 for heating the supported wafers 64 to processing temperatures, e.g., about 1,200° C. for silicon, with it being understood that the temperature may extend from a preferred range of about 1,150° C. to about 1,250° C., to a general range of about 950° C. to about 1,350° C. Conversely, these temperatures for germanium will be in the general range of about 600° to about 920° C., and preferably from about 890° C to about 910° C.

10 In this example, for a carrier travel rate of 1.0 inches per minute through the preheat chamber 71, this chamber has a length of about 18 inches and is defined between the flanged partitions 81 and 91.

15 Normally, the environment in preheat chamber 71 will be selected so as to be compatible with the epitaxial atmosphere in the succeeding processing chamber 71A defined between partitions 91 and 96. For example, the protective atmosphere in preheat chamber 71 may not only comprise any of the indicated inert gasses but also preferentially includes hydrogen.

20 In a specific application, utilizing an epitaxial gas mixture of hydrogen and a silicon halide in the epitaxial chamber 71A, hydrogen is conveniently employed for the atmosphere in preheat chamber 71 in a general range of about 0.001 to about 0.05 p.s.i.g. and preferably from about 0.002 to about 0.005 p.s.i.g. It is to be understood that the pressure P71 in preheat chamber 71 will be maintained at a level below the pressure P70E in the preceding inlet compartment 70E (of isolation chamber 70) and coordinated therewith so that there will be

25 either a zero flow F6, between the inlet compartment 70E and preheat chamber 71, or a positive flow F6 from inlet compartment 70E into preheat chamber 71.

30 After the preheating stage, the moving tier of carriers 50 emerge from the preheat chamber 71 and pass through the reaction chamber 71A, of about 8 inches in length, in which is maintained a substantially quiescent environment of hydrogen and an epitaxial film growing gas source flowing therethrough, via inlet tube 89 to outlet tube 90, at a feed rate not greater than about 15 liters per minute (e.g., about 0.848

35 liters/minute/sq. cm. of free-flow cross section) and preferably from about 5 to about 10 liters per minute (e.g., about 0.282 to about 0.565 liters/minute/sq. cm. of free-flow cross section). In general, the rate of flow will be sufficient to maintain

40 a substantially constant proportional concentration of the hydrogen and an epitaxial film growing gas source. In general, the epitaxial film growing atmosphere may comprise any of the composition indicated therefor above. As will be understood, the epitaxial film growing atmosphere may include

45 conductivity type determining impurities. In the preferred embodiment, as used in the specific example set out below, the epitaxial film forming atmosphere may comprise hydrogen at a feed rate of 10 liters per minute containing from about 0.1 to about 1.0 percent by volume, silicon tetrachloride in combination

50 with from about 0.01 to about 0.5 percent by volume of arsine as a conductivity type determining impurity. In the specific epitaxial film-forming atmosphere employed in this example, the composition of the atmosphere comprised hydrogen containing 0.5 volume percent silicon tetrachloride

55 and 0.05 volume percent arsine. In operation, the epitaxial film forming gas composition was premixed externally of the system and circulated through the epitaxial growth chamber 71A via its inlet tube 89 and outlet tube 90 to provide the above indicated rate of flow and to maintain a pressure P70A

60 at substantially the same level as the pressure P71 in preheat chamber 71. Generally however, the pressure may range from about 0.001 to about 0.01 p.s.i.g. and preferably from about 0.001 to about 0.003 p.s.i.g.

65 After passage through the epi-chamber 71A, the carriers 50 enter and pass through a secondary three-compartmented isolation chamber 92 having the configuration previously described in conjunction with the preceding example. As in the preceding example, the carrier-supported wafers pass out of heating coil 53 permitting the wafers 64 to cool to suitable

70 processing temperatures for deposition of a silicon oxide film

on the wafers, e.g., the wafers 64 may be cooled within a general range of about 600° to about 1,300° C., and preferably in the range of 750° to 900° C.

Since the three-compartmented chamber 92 is identical to the corresponding chamber of the preceding example, and since the correlation of pressures in the various inlet and outlet compartments 73A through 73C are identical to the pressures in the corresponding inlet and outlet compartments of the preceding example, no extended description is necessary. If required, such details may easily be ascertained by reference to the foregoing example of corresponding portions of isolation chamber 73. In effect, as shown in FIG. 23, the three-compartmented isolation chamber 92 forms a buffer separating unit between the epi-chamber 71A and the oxide deposition chamber 93 to maintain the basic integrity of the processing atmospheres therein.

As the carriers 50 emerge from the separation chamber 92, they enter and pass through an oxide deposition chamber 93 which is about 8 inches in length as defined between flanged partition 96A and flanged partition 91 of the post-cool chamber 93A. Concurrently the wafers pass through RF heating coil 54 which maintains the wafers at processing temperatures.

The oxidation chamber 93 comprises a section of processing tube 52 wherein the substrates or wafers 64 are subjected to an atmosphere in which a volatile silicon compound is being thermally decomposed with reduction with hydrogen at a temperature below the melting point of the sub-

through-put of about 0.5 to about 3 inches per minute, oxide films of about 2,000 to about 7,000 Å. thick are generated.

Upon emerging from the oxidation chamber 93, the carrier supported wafers 64 pass through the post-cool chamber 93A of about 10 inches in length and similar construction to the preheat chamber 71. Here the wafers are cooled to below critical or reactive temperatures, e.g., to about or below 400° C.

After cooling, the wafers pass through the isolation chamber 73 similar in construction and function to those previously discussed in greater detail with respect to isolation chamber 70 of the present and preceding examples. However, during passage through the isolation chamber 73 the carriers and wafers are allowed to further cool toward ambient temperatures as they emerge into outlet buffer chamber 77 for final exiting across a transfer table onto a conveyor for removal from the system.

To illustrate the operation of the above described system as shown in FIG. 23, the following Table 13 is set forth to illustrate the environment and the results of a specific operating system for processing of surface preconditioned silicon wafers supported on carriers traveling through the system at a rate of 1 inch per minute. For the specific example set out below the epitaxial atmosphere comprised hydrogen containing, by volume, 0.5 percent silicon tetrachloride and 0.05 percent arsine, and silicon oxide depositing the atmosphere comprised hydrogen containing, by volume, 0.05 percent silicon tetrachloride and 1.0 percent oxygen.

strate, and reacted with oxygen to form a silicon oxide which is deposited as a film on the substrate. Although various atmospheres for the formation of a silicon dioxide film may be employed as indicated above, as shown in FIG. 23, a preferred gas is one composed of hydrogen, silicon-bearing compounds (as for example, silicon tetrachloride) in combination with oxygen or carbon dioxide. A typical composition of hydrogen/oxygen/silicon-bearing compounds would be comprised, by volume, of about 92 to 99 percent hydrogen, about 0.4 to 0.6 percent oxygen and from about 0.9 to 1.2 percent silicon tetrachloride. Where a gas composition comprised of hydrogen/carbon dioxide/silicon-bearing compound is employed as an oxide depositing environment, a typical composition will comprise, by volume, from about 0.92 to 1.2 percent silicon tetrachloride, about 92 to about 99 percent hydrogen and from about 2.0 to about 8.0 percent carbon dioxide.

In general, the temperature in the oxide depositing chamber 93, and in particular the temperature of the carrier supported substrates 64, will be maintained at the optimum range from about 750° to 900° C. whereby a film of a silicon oxide compound is deposited on the substrate from the silicon oxide forming environment flowing through the oxidation chamber 93 at a feed rate of about 5 to about 10 liters per minute (e.g., about 0.282 to about 0.565 liters/minute/sq. cm. of free-flow cross section) by introduction of the atmosphere via the inlet tube 89 and exhausting of the gasses via outlet tube 90. With the wafers transported through the oxide chamber 93 at a

EXAMPLE IX

Sequential Silicon Oxide and Metal Film Depositions

This example, in conjunction with the FIGS. 5, 7, 9-17 and 24 describes a continuous processing system for sequentially depositing a silicon oxide film and a metal film on semiconductor substrates.

In the same fashion described in the preceding examples a continuous tier of wafer carriers 50 having a rectangular configuration are transported in end-to-end relationship by a feed mechanism generally indicated by the numeral 51 into a quartz processing tube 52 disposed within heating coils 53 and 54 which may be optionally enclosed in a furnace enclosure 55 of the usual construction.

Since water-cooled RF heater coils 53 and 54 are also shown and employed in this example, the carriers 50 are fabricated of suitable susceptor materials such as graphite, carbon, molybdenum and the like. However, it is to be understood that carriers 50 may also be constructed of other suitable materials compatible with the wafers and with process environments. In general, the material of carriers 50 will normally determine the type of the heater coils employed in conjunction with reactor tube 52. Thus in a system employing quartz carriers, the heating coils can conveniently comprise resistance coils, and conversely the use of graphite in the construction of the carriers permits the use of either resistance coils or induction heater coils in this system.

The processing tube 52 shown here is also of rectangular configuration having an internal height of about 33 mm. and an internal width of 89 mm. with an overall length of about 78 inches subdivided into appropriate chambers described below.

The carriers 50 illustrated in the FIG. 6 are employed for processing the wafers having 2½-inch diameter with it being understood that other variations in carrier and wafers aforesubjected in conjunction with the preceding examples may also be employed where desired or required. As in the previous embodiments, the carriers 50 were fabricated in a 3.45-inch square configuration, with a thickness of about 0.5 inches and having skids or rails 62 of about 0.015 inches depending from the bottom of the carrier to provide an overall height of 0.515 inches defining a free-flow cross section of 17.7 sq. cm. in the unbaffled portions of the tube.

As in the previous examples, the top surfaces of carriers 50 of this example are also recessed at 63 to a sufficient depth to seat and maintain therein a semiconductor wafer 64 of silicon and the like for multistage processing through the tube 52. In general, the top surfaces of the wafers will be substantially flush with the top surface of carriers 50 while seated therein.

The feed station shown in FIG. 5 may also be employed in this example, and comprises an endless conveyor 65 which carries the carriers between the drive-unit 66 which comprises two side-gripping endless belts which contact the carriers on their sides to propel them in end-to-end relationship through processing tube 52. A transfer plate 67 is provided with side-guides 67A for feeding the carriers 50 in end-to-end relationship through processing tube 52. A transfer plate 67 is provided with side-guides 67A for feeding the carriers 50 in end-to-end relationship through the processing tube 52.

The tube 52 shown in FIG. 24 is configured to sequentially process a pre-conditioned silicon wafer 64 for deposition of a silicon oxide film followed by deposition on the substrate of a metal film having a resistivity less than about 100 microhms-cm. Basically, the reactor tube of FIG. 24 is subdivided into an ambient inlet buffer chamber or zone 69, a critical isolation chamber 70, a preheat chamber 71, an oxide deposition chamber 71A, a secondary three-compartmented isolation chamber 92, a metal plating chamber 93, a post-cool chamber 93A, a critical isolation chamber 73, and an ambient outlet buffer chamber 77.

The buffer zone or chamber 69, of about 5 inches in length, is defined between partitions 78 and 79, with partition 78 extending toward the bottom of reactor tube 52 a distance providing about 0.25 inch clearance with the top of a tier of carriers 50. Buffer zone 69 forms a preliminary barrier against ambient atmospheres and is maintained with a non-reactive protective atmosphere of about 0.05 p.s.i.g. by introducing therein through a circumferential slot 80A of a closed end nozzle 80 (of about 5 mm. ID) a suitably controlled flow of a gas such as nitrogen, helium, argon, forming gas and the like. Generally however, for this processing system, the pressure in ambient buffer chamber 69 as above, may extend from about 0 to about 0.003 p.s.i.g., and preferably from about 0.001 to about 0.005 p.s.i.g. As indicated, nozzle 80 is a closed end structure having the configuration shown and described in reference to FIG. 12.

The tier of carriers 50 traveling at a rate of 1.0 inches per minute passes out of the ambient buffer chamber 69 into and through the critical isolation chamber 70 having the same structural configuration indicated therefor in the previous examples; and accordingly, like component features are indicated by the same reference numerals.

Also as in the preceding examples, the isolation chamber 70 is subdivided into a series of alternate inlet and outlet compartments into which protective gasses are introduced and withdrawn. For the particular isolation obtained, the isolation chamber is subdivided into an inlet compartment 70A, an outlet compartment 70B, a second inlet compartment 70C, a second outlet compartment 70D and a third inlet compartment 70E, each about 1 inch in length. In general, the pressure relationships of the preceding examples are also maintained within and between the various compartments of isolation

chamber 70 and between adjacent ambient inlet chamber 69 and the preheat chamber 71, so as to maintain the same flow and pressure relationship as indicated above therefor.

As the tier of carriers 50 emerges from the last compartment 70E of isolation chamber 70, the carriers enter into a non-reactive preheat chamber 71 disposed within the heating coil 53 for heat-conditioning the supported wafers 64 to processing temperatures, e.g., about 800° C. for silicon, with it being understood that the temperature may extend from a preferred range of about 750° to about 900° C. to a general range of about 600° to about 1,300° C.

In this example, for a carrier travel-rate of 1.0 inch per minute through the preheat chamber 71, this chamber has a length of about 18 inches and is defined between the flanged partitions 81 and 91.

Normally, the environment in preheat chamber 71 will be selected so as to be compatible with the oxide-forming atmosphere in the succeeding processing chamber 71A defined between partitions 91 and 96. For example, the protective atmosphere in preheat chamber 71 may not only comprise any of the indicated inert gasses but also preferentially includes hydrogen. In a specific application, utilizing an oxide-forming mixture comprised of hydrogen, silicon chloride and oxygen in processing chamber 71A, hydrogen is conveniently employed for the atmosphere in preheat chamber 71 in the general range of about 0.001 to about 0.03 p.s.i.g. and preferably from about 0.001 to about 0.003 p.s.i.g. It is to be understood that the pressure P71 in preheat chamber 71, will be maintained at a level below the pressure P70E in the preceding inlet compartment 70E (of isolation chamber 70), and coordinated therewith so that there will be either a zero flow F6 between inlet compartment 70E into preheat chamber 71.

After the pre-heating stage, the moving tier of carriers 50 emerges from the preheat chamber 71 and passes through the reaction chamber 71A of about 8 inches in length in which is maintained a substantially quiescent environment of an atmosphere containing a volatile silicon compound which is being thermally decomposed by reduction with hydrogen, at a temperature below the melting point of the substrate and reacted with oxygen to form a silicon oxide which is deposited as a film on the substrate. Although various atmospheres for the formulation of a silicon dioxide film may be employed, as shown in FIG. 24, a preferred atmosphere is one composed of hydrogen and silicon-bearing compounds (as for example, silicon tetrachloride) in combination with oxygen or carbon dioxide. A typical composition of hydrogen/oxygen/silicon-bearing compounds would be comprised, by volume, of about 92 to 99 percent hydrogen, about 0.4 to 0.6 percent oxygen, and about 0.9 to 1.2 percent silicon tetrachloride. For a gas composition comprised of hydrogen/carbon dioxide/silicon-bearing compounds is employed as an oxide depositing environment, a typical composition will comprise, by volume, from about 0.92 to about 1.2 percent silicon tetrachloride, about 92 to about 99 percent hydrogen, and from about 2.0 to about 8.0 percent carbon dioxide.

In general, the temperature in the oxide-forming chamber 71A and, in particular, the temperature of the carrier supported substrates 64, will be maintained in a range from about 1,150° to 1,250° C. whereby a film of a silicon oxide compound is deposited on the substrate from the silicon-forming environment flowing through the oxide chamber 93 at a feed rate of about 5 to about 10 liters per minute (e.g., about 0.282 to about 0.565 liters/minute/sq. cm. of free-flow cross section) by introduction of the atmosphere via the inlet tube 89 and exhausting of the gasses via outlet tube 90. With the wafers transported through the oxide depositing chamber 93 at a through-put of about 0.5 to about 3 inches per minute, oxide films of about 2,000 to about 7,000 Å. thick are generated.

Upon emerging from the oxide depositing chamber 71A, the carriers 50 enter and pass through a secondary three-compartmented isolation chamber 92 having a configuration previously described above. As in the preceding example, the carrier-supported wafers pass out of heating coil 53 permitting the wafers to cool to suitable processing temperatures for plat-

ing of a metal on the wafers, e.g., the wafers may be cooled within a general range of 250° to 750° C., and preferably from 300° to 550° C.

In the processing system embodied in FIG. 24, the three-compartment isolation chamber 92 forms a buffer separating unit between the oxide depositing chamber 71A and the metal plating chamber 93 to maintain the basic integrity of the processing atmospheres therein. To provide the isolation desired between the two reactive chambers (e.g., 71A and 93), the isolation chamber 92 is subdivided into a series of alternate outlet and inlet compartments into which a non-reactive gas, such as any of those indicated above, is respectfully withdrawn and introduced. For the particular isolation obtained, the isolation chamber 92 is subdivided into an outlet compartment 92A, an inlet compartment 92B and a second outlet compartment 92C. The outlet compartment 92A is about 2½ inches in length and is defined between the flanged partition 96 and a baffle 97 in which a non-reactive atmosphere is maintained at a pressure of about 0.001 p.s.i.g.

A gas mixture is formed in the outlet compartment 92A by the in-flowing atmosphere and gas from respectively oxide depositing chamber 71A and inlet compartment 92B (of isolation chamber 92) with the gasses exhausted via an outlet 94 which exhausts the gasses under the sole impetus of the gas flows into the outlet compartment. However, as previously indicated, a positive exhaust means may be employed to assist in exhausting the gasses if desired and where the requirements of the processing system require it. It is also noted that the indicated baffle 97 extends to about 0.020 inches of the top of carriers 50 to define a clearance substantially larger than that defined by the flange 82 of partition 96. In general, the pressure and outlet compartment 92A may extend in the range from about 0 to about 0.003 p.s.i.g., and preferably from about 0 to 0.002 p.s.i.g. However, in all cases the pressure P92A in outlet compartment 92A will be lower than the pressure P71A in oxide depositing chamber 71A with a pressure differential therebetween, P_1 , of at least 0.001 p.s.i.g.

In the preferred construction, as indicated, baffle 97 extends to within 0.20 inches of the top of carriers 50 to define a restricted clearance with the carriers larger than the corresponding clearance formed under the flange 82 of partition 96. As will be understood, since the flow of the orifice equation is directly proportional to the orifice area, the flow (under like conditions) will be greater in a larger orifice than in a smaller orifice. The significance of this becomes evident upon consideration that the broad pressure range in the succeeding inlet compartment 92B, also about 1 inch in length, is of the order of about 0.002 to about 0.01 p.s.i.g., and preferably from about 0.002 to about 0.02 p.s.i.g. with a pressure differential 2 of at least 0.002 p.s.i.g. Generally, as shown in FIG. 15, the pressure differential ΔP_1 and ΔP_2 are coordinated with each other and with other pressure differentials (as described below) in the remaining compartment and chambers of reaction tube 52 so that there will be a positive flow from the oxide depositing chamber 71A into the outlet compartment 92A.

The inlet compartment 92B, aforeindicated, is defined between the baffle 97 and a second like baffle 97A wherein both define like clearances with the top of wafer carriers 50. A non-reactive gas (the same as employed in the preceding isolation chamber 70 of the tube) is introduced through the inlet nozzle 95 having the same general configuration as the previously described inlet nozzle 86, to maintain a pressure substantially higher than the pressures in the outlet compartment 92A and in the following outlet compartment 92C, as for example, about 0.005 p.s.i.g. Generally the pressure in the inlet compartment 92B will be maintained in a range of 0.002 to about 0.01 p.s.i.g., and preferably from about 0.002 to about 0.02 p.s.i.g. However, as indicated the pressure in inlet compartment will be maintained at a level substantially higher than the pressures in either of outlet compartments 92A and 92C with the latter compartment also being approximately 1½ inches in length. Conversely, the pressure in inlet compartment 92B will be at a level higher than the pressures in oxide

depositing chamber 71A and in the metal plating chamber 93, when the relationship is graphically shown in FIG. 15.

As indicated, the carrier-supported wafers on passage through the isolation chamber 92 concurrently pass within heating coil 54 which conditions the wafers to suitable processing temperature for deposition of a metal film on the wafers, e.g., the wafers 64 may be heated to a general range of about 250° to about 750° C. and preferably in the range of 300° to 550° C.

As the carriers 50 emerge from isolation chamber 92, they enter and pass through a metal plating chamber 93 which is about 8 inches in length and is defined between flanged partition 96A and flanged partition 91 of the post-cool chamber 93A. Concurrently, the wafers pass within and through the RF heating coil 54 which maintains the wafers at processing temperatures.

The metal plating chamber 93 comprises a section of processing tube of about 8 inches in length wherein the substrates or wafers 64 are subjected to a substantially quiescent flowing gaseous environment of hydrogen and a metal halide (e.g., molybdenum chloride) flowing from its inlet to its outlet, 89 to 90 respectively, at a feed rate of about 1 to about 15 liters per minute, e.g., 0.0565 to about 0.848 liters/minute/sq. cm. of the free-flow cross section. Typically, the metal plating atmosphere may comprise hydrogen and a halide of a metal having resistivity less than about 100 microhms-cm. at 18° C. As will be understood, various metal plating atmospheres such as indicated above may also be employed in the metal plating chamber 93.

In 80 preferred embodiment, 89 used in the specific examples set out below, the metal plating atmosphere comprises a two-component gaseous mixture wherein the first component is hydrogen and the second component is a halide of a metal having a resistivity less than about 100 microhms-cm., as for example, tungsten pentachloride, and specifically, molybdenum pentachloride. A typical feed mixture of this metal plating atmosphere will comprise 6 liters per minute hydrogen and 3 liters per minute argon containing about 6 volume percent molybdenum pentachloride per 9 liter volume. In the process, as indicated above the metal plating atmosphere (e.g., molybdenum pentachloride and hydrogen) may be pre-heated externally of reactor tube 52 and injected therein via the inlet nozzle 89 (of processing chamber 71A) wherein upon contact with the heated wafers 64, the metal halide is reduced by hydrogen with liberation of the metal (e.g., molybdenum) at the surface of wafer 64 whereat the liberated metal is deposited. After passage of the substrates through the metal plating chamber 93, the carrier supported wafers 64 pass through the post-cool chamber 93A of about 10 inches in length and similar in construction to the preheat chamber 71. Herein the wafers are cooled below critical or reactive temperatures, e.g., to about or below 400° C.

After cooling, the wafers pass through the isolation chamber 73 similar in construction and function to those previously discussed in greater detail with respect to isolation chamber 70 of the present and preceding examples. However, during passage through the isolation chamber 73, the carriers or wafers are allowed to further cool toward ambient temperatures as they emerge into outlet buffer chamber 77 for final exiting across a transfer table onto a conveyor for removal from the system.

To illustrate the operation of the above described system as shown in FIG. 24, the following Table 14 is set forth to illustrate the environment and results of a specific operating system for processing of surface preconditioned silicon wafers supported on carriers traveling through the system at a rate of one inch per minute. For the specific example set out below the silicon oxide depositing atmosphere comprised hydrogen containing, by volume, 0.5 percent silicon tetrachloride and 1.0 percent oxygen; and the metal depositing atmosphere comprised 6 liters/minute hydrogen and 3 liters/minute argon containing, by volume, 6 percent molybdenum pentachloride per 9 liter volume.

EXAMPLE X

Sequential Vapor Etching and Metal Deposition

This example, in conjunction with FIGS. 5, 7, 9-17 and 25 describes a continuous processing system for sequentially 25 vapor etching and depositing a metal film on semiconductor substrates.

In the same fashion described in the preceding examples, a continuous tier of wafer carriers 50 having a rectangular configuration is transported in end-to-end relationship by a feed mechanism generally indicated by the numeral 51 into a quartz processing tube 52 disposed within heating coils 53 and 54 which may be optionally enclosed in a furnace enclosure 55 of the usual construction.

Since water-cooled RF heating coils 53 and 54 are also shown and employed in this example, the carriers 50 are fabricated of suitable susceptor materials such as graphite, carbon, molybdenum, and the like. However, it is to be understood that carriers 50 may also be constructed of other suitable materials compatible with the wafers and with process requirements. In general, the material of carriers 50 will normally determine the type of heater coils employed in conjunction with reactor tube 52. Thus in a system employing quartz carriers, the heating coils can conveniently comprise resistance coils, and conversely, the use of graphite in the construction of the carriers permits the use of either resistance coils or induction heater coils in this system.

The processing tube 52 is also of rectangular configuration having an internal height of about 33 mm. and an internal 50 width of 89 mm., and an overall length of about 78 inches subdivided into appropriate chambers described below.

The carriers 50 illustrated in FIG. 6 are employed for processing of wafers having 2½-inch diameter with it being understood that other variations in carriers and wafers 55 aforesubdiscussed in conjunction with the preceding examples may also be employed where desired or required. As in the previous embodiments, the carriers 50 were fabricated in a 3.45 inch square configuration with a thickness of about 0.5 inches and having skids or rails 62 of about 0.015 inches depending from the bottom of the carriers to provide an overall height of 0.515 inches defining a free-flow cross section of 17.7 sq. cm. in the unbaffled portions of the tube.

As in the previous examples, the top surfaces of carriers 50 of this example are also recessed at 63 to a sufficient depth to seat and maintain therein a semiconductor wafer 64 of silicon, germanium and the like, for multistage processing through the tube 52. In general, the top surfaces of the wafers will be substantially flush with the top surfaces of carriers 50 while seated therein.

The feed station shown in FIG. 5 may also be employed in this example, and comprises an endless conveyor 65 which carries the carriers between the drive unit 66 which comprises two side-gripping endless belts which contact the carriers on their sides of propel them in end-to-end relationship through

processing tube 52. A transfer plate 67 is provided with side-guides 67A for guiding the carriers 50 in the indicated end-to-end relationship through the processing tube 52.

The tube shown in FIG. 25 is configured to sequentially process a pre-conditioned silicon wafer 64 for vapor etching thereof followed by deposition of a metal having a resistivity less than about 100 microhms-cm. Basically, the reactor tube of FIG. 25 is subdivided into an ambient inlet buffer chamber or zone 69, a critical isolation chamber 70, a preheat chamber 71, a vapor etch chamber 71A, a secondary three-compartmented isolation chamber 92, an intermediate cool chamber 100, a metal plating chamber 93, a post-cool chamber 93A, a critical isolation chamber 73, and an ambient outlet buffer chamber 77.

The buffer zone 69 of about 5 inches in length is defined by partition 78 and 79, with partition 78 extending toward the bottom of reactor tube 52 a distance providing about 0.25 inches clearance with the top of a tier of carriers 50. Buffer zone 69 forms a preliminary barrier with ambient atmospheres as in maintained with a non-reactor protective atmosphere of about 0.05 p.s.i.g. by introducing therein through a circumferential slot 80A of a closed end nozzle 80 (of about 5mm ID) a suitably controlled flow of an inert gas such as nitrogen, helium, argon, forming gas and the like. Generally however, for the processing system of this example, the pressure in ambient buffer chamber 69 may extend from about 0 to about 0.003 p.s.i.g. and preferably from about 0.001 p.s.i.g. to about 0.005 p.s.i.g. As indicated, nozzle 80 is a closed end structure having the configuration shown in FIG. 12.

A tier of carriers 50 traveling at a rate of 1.0 inches per minute pass out of the ambient buffer chamber 69 into and through the critical isolation chamber 70 having the same structural configuration indicated therefor in the previous examples, and accordingly, like component features are indicated by the same reference numerals.

Also, as in the preceding examples, the isolation chamber 70 is subdivided into a series of alternate inlet and outlet compartments, into which protective gasses are introduced and withdrawn. For the particular isolation obtained, the isolation chamber 70 is subdivided into an inlet compartment 70A, an outlet compartment 70B, a second inlet compartment 70C, a second outlet compartment 70D, and a third inlet compartment 70E, each about 1 inch in length. In general, the pressure relationship of the preceding examples will also be maintained within the various compartments of isolation chamber 70 and between the adjacent ambient inlet buffer chamber 69 and the preheat chamber 71, so as to maintain the same flow relationship indicated above therefor.

As the tier of carriers 50 emerges from the last inlet compartment 70E of isolation chamber 70, the carriers enter the preheat chamber 71, disposed within the heating coil 53 for heating the supported wafers 64 to processing temperatures, e.g., about 1,200° C., with it being understood that the temperatures may extend from a preferred range of about 1,175°

to about 1,250° C., to a general range of about 1,000° to about 1,300° C.

In this example, for a carrier travel rate of 1.0 inches per minute through the preheat chamber 71, this chamber has the length of about 18 inches and is defined between the flanged partitions 81 and 91.

Normally, the environment in preheat chamber 71 will be selected as indicated in Example 4 so as to be compatible with the etching atmosphere in the succeeding processing chamber 71A defined between partitions 91 and 96. For example, the protective atmosphere in preheat chamber 71 may not only comprise any of the indicated inert gasses but also preferentially includes hydrogen. A specific application, utilizing a gas mixture of hydrogen and hydrogen chloride in the etching chamber 71A, hydrogen is conveniently employed for the atmosphere in preheat chamber 71 in the general range of about 0.001 to about 0.05 p.s.i.g., and preferably from about 0.002 to about 0.005 p.s.i.g. It is to be understood that the pressure P71 in preheat chamber 71 will be maintained at a level below the pressure P70E in the preceding inlet compartments 70E (of isolation chamber 70), and coordinated therewith so that there will be either a zero flow F6 between inlet compartment 70E and preheat chamber 71, or a positive flow F6 from inlet compartment 70E into preheat chamber 71.

After the preheating stage, the moving tier of carriers 50 emerges from the preheat chamber 71 and passes through the reaction chamber 71A of about 4 inches in length in which is maintained a substantially quiescent environment of hydrogen and a hydrogen halide gas flowing from its inlet tube 89 to its outlet tube 90 at a feed rate not greater than about 25 liters per minute (e.g., 1.41 liters/minute/sq. cm. of free-flow cross section) and preferably from about 6 to about 12 liters per minute (e.g., about 0.339 to about 0.68 liters/minute/sq. cm. of free-flow cross section).

For example, the etching atmosphere may comprise, hydrogen containing from about 2 to 12 percent, by volume, of a hydrogen halide such as hydrogen chloride, hydrogen bromide, hydrogen fluoride, and hydrogen iodide.

In the preferred embodiment, as used in the specific example set out below, the halide of the etching atmosphere is hydrogen chloride. A typical mixture of this etching atmosphere will comprise, by volume, from about 92 to about 98 percent hydrogen and from about 2 to about 8 percent hydrogen chloride.

After passage through the etching chamber 71A, the carriers 50 enter and pass through a secondary three-compartmented isolation chamber 92 having the configuration previously described in conjunction with FIG. 2. In addition, the carrier supported wafers pass out of heating coil 53 and pass through an intermediate cooling chamber 100 which conditions the wafers 64 to suitable processing temperatures for deposition of a metal film on the wafers, e.g., the wafer 64 may be cooled within the general range of about 250° to about 750° C., and preferably in the range of about 300° to 550° C.

In the processing system embodied in FIG. 25, the three-compartmented isolation chamber 92 forms a buffer separating unit between the etching chamber 71A and the metal plating chamber 93 to maintain the basic integrity of the processing atmospheres therein. To provide a degree of isolation desired between the two reactive chambers (e.g., 71A and 93), the isolation chamber 92 is subdivided into a series of outlet and inlet compartments into which a non-reactive gas, such as any of those indicated above, is respectively withdrawn and introduced. For the particular isolation obtained, the isolation chamber 92 is subdivided into an outlet compartment 92A, an inlet compartment 92B, and a second outlet compartment 92C. The outlet compartment 92A is about 2½ inches in length and is defined between the flanged partitions 96 and baffle 97 in which a non-reactive atmosphere is maintained at a pressure of about 0.001 p.s.i.g.

A gas mixture is formed in the outlet compartment 92A by the inflowing atmosphere and gas from respectively etching

chamber 71A and inlet compartment 92B (of isolation chamber 92) with the gasses exhausted via an outlet 94 which exhausts the gasses under the sole impetus of the gas flows into the outlet compartment. However, it is indicated above, positive exhaust means may be employed to assist in exhausting the gasses if desired and where the requirements of a processing system require it. It is also noted that the indicated baffle 97 extends to about 0.020 inches of the top of carriers 50 to define a restricted clearance substantially larger than that defined by the flange 82 of partition 96. In general, the pressure in outlet compartment 92A may extend in a range of 0 p.s.i.g. to about 0.003 p.s.i.g., and preferably from about 0 to about 0.002 p.s.i.g. However, in all cases, the pressure P92A in outlet compartment 92A will be lower than the pressure P71A in etching chamber 71A where the pressure differential therebetween, ΔP_1 , of at least 0.001 p.s.i.g.

In the preferred construction, as indicated, baffle 97 defines a restricted clearance with the carriers larger than the corresponding clearance formed under the flanged 82 of partition 96. As will be understood, since the flow in the orifice equation is directly proportional to the orifice area, the flow (under like conditions) will be greater in a larger orifice than in a smaller orifice. The significance of this becomes evident upon consideration of the broad pressure range in the succeeding inlet compartment 92B is of the order of about 0.002 to about 0.01 p.s.i.g., and preferably from about 0.002 to about 0.02 p.s.i.g., with a pressure differential ΔP_2 of at least 0.002 p.s.i.g. Generally, as shown in FIG. 15, the pressure differential ΔP_1 and ΔP_2 are coordinated with each other and with other pressure differentials (as described below), in the remaining compartments and chambers of the reaction tube 52, so that there will be a positive flow from the etching chamber 71A into the outlet compartment 92A.

The inlet compartments 92B, aforeindicated, of about 1 inch is defined between the baffle 97 and a second like baffle 97A wherein both defined like clearances with the top of wafer carriers 50. A non-reactive gas (the same as employed in the preceding isolation chamber 70 of the tube) is introduced through the inlet nozzle 95, having the same general configuration as the previously described inlet nozzle 86, to maintain a pressure substantially higher than the pressures in the outlet compartment 92A and in the following outlet compartment 92C of about 2½ inches in length, as for example, about 0.005 p.s.i.g.

Generally the pressure in the inlet compartment 92B which is about 1 inch in length will be maintained in the range from about 0.002 to about 0.01 p.s.i.g., and preferably from about 0.002 to about 0.02 p.s.i.g. However, as indicated, the pressure in inlet compartment 92B will be maintained at a level substantially higher than the pressures in either of outlet compartments 92A and 92C. Conversely, the pressure will also be at a level higher than the pressures in etching chamber 71A and the metal plating chamber 93 wherein the relationship is graphically shown in FIG. 17.

As the carriers 50 emerge from the separation chamber 92, they enter and pass through a 14-inch intermediate cooldown chamber 77A and into a metal plating chamber 93 which is about 8 inches in length as defined between flange partition 96A and flange partition 91 of the post-cool chamber 93. Concurrently, as the wafers enter plating chamber 93 they also pass into and through the RF heating coil 54 which maintains the wafers at processing temperatures.

The metal plating chamber 93 comprises a section of the processing tube of about 8 inches in length wherein the substrates or wafers 64 are subjected to a substantially quiescent flowing gaseous environment of hydrogen and a metal halide (e.g., molybdenum chloride) flowing from its inlet to its outlet, 89 and 90, respectively, at a feed rate of about 1 to about 15 liters per minute. Typically, the metal plating atmosphere may comprise hydrogen and a halide of metal having a resistivity less than about 100 microhms-cm. at 18°C. As will be understood, various metal plating atmospheres such as indicated above may also be employed in a metal plating chamber 93.

In the preferred embodiment as used in the specific example set out below, the metal plating atmosphere comprises a two-component gaseous mixture wherein the first component is hydrogen, and the second component is a halide of a plating metal having a resistivity less than about 100 microhms-cm., as for example, tungsten pentachloride, and specifically molybdenum pentachloride. A typical mixture of this metal plating atmosphere will comprise about 6 liters/minute hydrogen and about 3 liters/minute argon, with about 6 volume percent molybdenum pentachloride per 9 liters volume. In the process as indicated, the metal plating atmosphere (e.g., molybdenum pentachloride and hydrogen) may be preheated externally of reactor tube 52 and injected therein via the inlet nozzle 89 (of processing chamber 71A) wherein upon contact with the heated wafer 64, the metal halide is reduced by hydrogen for liberation of the metal (e.g., molybdenum) at the surface of the wafer whereat the liberated metal is deposited. After passage of the substrates through the metal plating chamber 93, the carrier supported wafers 64 pass through the post-cool chamber 93A of about 10 inches in length and similar in construction to the preheat chamber 71. Herein the wafers are cooled below critical or reactive temperatures, e.g., to about or below 400°C.

After cooling, the wafers pass through the isolation chamber 70 of similar construction and function to those previously discussed in greater detail with respect to isolation chamber 70 of the present and preceding examples. However, during passage through the isolation chamber 70, the carriers or wafers are allowed to further cool toward ambient temperatures as they emerge into outlet chamber 77 for final exiting across a transfer table onto a conveyor for removal from the system.

To illustrate the operation of the above described system as shown in FIG. 25, the following Table 15 is set forth to illustrate the environments and results of a specific operating system for processing of surface pre-conditioned silicon wafers supported on carriers traveling through the system at a rate of one inch per minute. For the specific example set out below the vapor etch atmosphere comprised hydrogen containing, by volume, 6 percent hydrogen chloride; and the metal depositing atmosphere comprised 6 liters/minute hydrogen and 3 liters/minute argon containing, by volume, 6 percent molybdenum pentachloride per the 9-liter volume.

EXAMPLES XI to XIV

The following examples illustrate various embodiments of the invention directed to

- A continuous multistage processing system for sequentially vapor etching and thermally oxidizing semiconductor substrates without exposure of the substrates to ambient and intermediate the processing operations, as shown in FIG. 26;
- A continuous multistage processing system for sequentially vapor etching and depositing silicon nitride films onto semiconductor substrates without exposure of the

substrates to ambients intermediate processing operations, as shown in FIG. 27;

C. a continuous multistage processing system for sequentially depositing epitaxial films and thermal oxidation of semiconductor substrates without exposure of the substrates to ambients intermediate processing operations, and as shown in FIG. 28 and

D. a continuous multistage processing system for sequentially depositing epitaxial and silicon nitride films onto semiconductor substrates without exposure of the substrates to ambients intermediate processing operations, as shown in FIG. 29.

In view of the similarity in the tube configurations employed in each of the four examples, the various tube configurations are grouped together with the specific process parameters and chamber dimensions set forth below for each example. However, as will be understood, in the systems utilizing a vapor etch operation, the etching atmosphere may comprise

hydrogen containing from about 2 to about 12 percent, by volume, of a hydrogen halide such as hydrogen chloride, hydrogen bromide, hydrogen fluoride and hydrogen iodide. In the preferred embodiment of the etching atmosphere, as used in the specific example set out below (e.g. Example XI and XII), the halide of the etching atmosphere comprises hydrogen chloride, with a typical mixture of this etching atmosphere comprising, by volume, from about 92 to about 98 percent hydrogen and from about 2 to about 8 percent hydrogen chloride.

Similarly any of the thermal oxidizing atmospheres indicated above may also be employed for purposes of these examples. Thus, for the thermal oxidation of silicon semiconductor substrates, the oxidizing atmosphere may comprise oxygen, or oxygen in conjunction with water vapor, or a combination of the two as employed in these specific embodiments described herein. Specifically as shown in more particularity in the tables below and in FIGS. 26 and 28, a three-stage oxidation is normally employed comprising a first oxidation in dry oxygen, a second oxidation of the substrates in a gas mixture of oxygen and water vapor followed by a third-stage oxidation of the substrates in dry oxygen again.

Also, the nitriding atmospheres may also comprise any of the compositions indicated therefor above. In the preferred

embodiment as used in the specific examples set out below, the nitriding atmosphere may be comprised of silane and ammonia in conjunction with hydrogen as a carrier therefor. A typical composition of these nitriding atmospheres may comprise 10 liters/minute nitrogen, from about 0.005 to about 0.05 volume percent silane, from about 0.05 to about 0.5 volume percent ammonia per 10 liter volume and nitrogen. A specific mixture of this nitriding atmosphere, as used in the example set out below, comprises 10 liters/minute nitrogen and 0.02 percent silane and 0.2 percent ammonia per 10 liter volume.

Also, the epitaxial film-growing atmospheres may comprise any of the compositions indicated therefor above. Further, thus as will be understood, the epitaxial film-growing atmosphere may include conductivity-type determining impurities. In the preferred embodiments, as used in the specific examples, as set out below, the epitaxial film-forming atmosphere may comprise 10 liters per minute hydrogen containing from about 0.1 to about 1.0 volume percent silicon tetrachloride in combination with from about 0.01 to about 0.5 volume percent of arsine as a conductivity-type determining impurity, per 10 liter volume. In the specific epitaxial film-forming atmosphere employed in these examples, the composition of the atmosphere comprises 10 liters/minute, with 0.5 volume per cent silicon tetrachloride and 0.05 percent arsine per 10 liter volume.

The tube configurations shown in FIGS. 26-29 are employed in these examples as follows:

- A. Example XI in conjunction with FIGS. 5, 7, 9-17 and 26 describes a continuous processing system for sequentially vapor etching and thermally oxidizing semiconductor substrates;
- B. Example XII, in conjunction with FIGS. 5, 7, 9-17 and 27 describes a continuous processing system for sequentially vapor etching and depositing a silicon nitride film on semiconductor substrates;
- C. Example XIII, in conjunction with FIGS. 5, 7, 9-17 and 28 describes a continuous processing system for sequentially depositing an epitaxial film and thermally oxidizing semiconductor substrates; and
- D. Example XIV, in conjunction with FIGS. 5, 7, 9-17 and 28 describes a continuous processing system for sequentially depositing epitaxial and silicon nitride films on semiconductor substrates.

In the same fashion described in the preceding examples, in these four Examples XI to XIV taken in conjunction with their respective FIGS. 26-29, a continuous tier of wafer carriers 50 having a rectangular configuration are transported in end-to-end relationship by a feed mechanism generally indicated by the numeral 51 into a quartz processing tube 52 disposed within heating coils 53 and 54 which may be optionally enclosed in a furnace enclosure 55 of the usual construction.

Since water-cooled RF heater coils 53 and 54 are also shown and employed in these examples, the carriers 50 are fabricated of suitable susceptor material such as graphite, carbon, molybdenum and the like. However, it is to be understood that carriers 50 may also be constructed of other suitable materials compatible with the wafers and with process environments. In general, the material of carriers 50 will normally determine the type of heater coils employed in conjunction with reactor tube 52. Thus in a system employing quartz carriers, the heating coils can conveniently comprise resistance coils, and conversely the use of graphite in the construction of the carriers permits the use of either resistance coils or induction heater coils in the systems.

The processing tubes shown here are also of rectangular configuration having an internal height of about 33 mm. and an internal width of 89 mm. Each processing tube 52 is subdivided into appropriate chambers, described below, with the various processing tubes having the following overall lengths:

- FIG. 26 96 inches;
- FIG. 27 78 inches;
- FIG. 28 96 inches;
- FIG. 29 78 inches.

The carriers 50 illustrated in FIG. 6 are employed for processing wafers having 2 1/4-inch diameter with it being understood that other variations in carriers and wafers aforesubdiscussed in conjunction with the preceding examples may also be employed where desired or required. As in the previous embodiments, the carriers 50 were fabricated in a 76.8 cm. sq. configuration with a thickness of about 0.5 inches and having skids or rails 62 of about 0.015 inches depending from the bottom of the carriers to provide an overall height of 0.515 inches defining a free-flow cross section of 17.7 sq. cm. in the unbaffled portions of the tube.

As in the previous examples, the top surfaces of carriers 50 of these examples are also recessed at 63 to a sufficient depth to seat and maintain therein a semiconductor wafer 64, of silicon, germanium and the like, for multistage processing through the tubes 52. In general, the top surfaces of the wafers will be substantially flush with the top surfaces of carriers 50 while seated therein.

The feed-station shown in FIG. 5 may also be employed in these examples, and comprises an endless conveyor 65 which carries the carriers between the drive unit 66 which comprises two side-gripping endless belts which contact the carriers on their sides to propel them in end-to-end relationship through processing tubes 52. The transfer plate 67 is provided with side-guides 67A for feeding the carriers 50 in end-to-end relationship through the processing tubes 52.

Specifically the processing tube 52 shown in FIG. 26 is configured to sequentially process a pre-conditioned silicon wafer 64 by vapor etching followed by thermal oxidation of the substrates.

In turn, the processing tube 52 shown in FIG. 27 is configured to sequentially process a pre-conditioned silicon wafer 64 by a vapor etching followed by vapor state deposition of a nitrided silicon film on the substrates.

Finally the processing tube shown in FIG. 29 is configured to sequentially process a pre-conditioned silicon wafer 64 by deposition of an epitaxial film followed by vapor state deposition of a silicon nitride film on the substrates.

Basically, the reactor tubes of FIGS. 26-29 are subdivided into an ambient inlet buffer chamber or zone 69, a critical isolation chamber 70, a pre-heat chamber 71, a first environmental processing chamber 71A, a second critical isolation chamber 74, environmental processing chambers 75, 75A and 75C, and an ambient outlet buffer chamber 77 with the tube configurations of FIGS. 26 and 28 including a three-zoned isolation chamber 92 intermediate processing chambers 75A and 75C.

The buffer zone or chamber 69, of about 5 inches in length, is defined between partitions 78 and 79, with partition 78 extending toward the bottom of the reactor tube 52 a distance providing about 0.25 inch clearance with the top of a tier of carriers 50. Buffer zone 69 forms a preliminary barrier against ambient atmospheres and is maintained with a non-reactive protective atmosphere of about 0.05 p.s.i.g. by introducing therein through a circumferential slot 80A of a closed end nozzle 80 (of about 5 mm. ID) a suitably controlled flow of an inert gas such as nitrogen, helium, argon, forming gas and the like. Generally however, for this processing system the pressure in ambient chamber 69, as above, may extend from about 0 to about 0.005 p.s.i.g. and preferably from about 0.001 to about 0.003 p.s.i.g. As indicated, nozzle 80 is a closed end construction having a configuration shown and described in reference to FIG. 12.

The moving tier of carriers 50 eventually pass out of ambient buffer chamber 69 into and through the critical five-compartment isolation chamber 70 having the same structural configuration indicated therefor in the previous example, and accordingly, like component features are indicated by the same reference numerals.

Also as in the preceding examples, the isolation chamber 70 is subdivided into a series of alternate inlet and outlet compartments into which protective gasses are introduced and withdrawn. For the particular isolation obtained, the isolation chamber 70 is subdivided into an outlet compartment 70B, a second inlet compartment 70C, a second outlet compartment 70D and a third inlet compartment 70E, each about 1 inch in length. In general, the pressure relationships of the preceding examples are also maintained within and between various compartments of isolation chamber 70, and between the adjacent ambient inlet chamber 69, and the pre-heat chamber 71, so as to maintain the same flow and pressure relationships indicated therefor.

As the tier of carriers 50 emerges from the 1,000° compartment 70E, of isolation chamber 70, carriers enter into a non-reactive pre-heat chamber 71 disposed within the heating coils

53 for the supported wafers 64 to processing temperatures, e.g.,

- a. for etching, in the general range of about 1,000° to about 1,300° C. for silicon and from about 350° to about 900° C. for germanium, and
- b. for epitaxial deposition; in the general range of about 950° to about 1,350° C. for silicon and from about 600° to about 920° C. for germanium.

The preheat chamber 71 is defined between flanged partitions 81 and 91, with the specific length of the preheat chambers set out below for each example.

Normally, the environment in preheat chamber 71 will be selected so as to be compatible with the atmosphere in the succeeding processing chamber 71A defined between partitions 91 and 79B. For example, the protective atmospheres in preheat chamber 71 may not only comprise any of the indicated inert gasses but also may include hydrogen where this gas is employed as a component in the environment processing chamber 71A. Thus since each of the Examples XI-XIV employs hydrogen as a component in the processing gas within processing chamber 71A, hydrogen may also be employed as a protective atmosphere within preheat chamber 71 in view of its compatibility with the processing gasses. In general, the protective atmosphere employed in preheat chamber 71 will be maintained in the general range of about 0.001 to about 0.05 p.s.i.g. and preferably from about 0.002 to about 0.005 p.s.i.g. It is to be understood that the pressure P71 in preheat chamber 71 will be maintained at a level below the pressure P70E in the preceding inlet compartment 70E (of isolation chamber 70) and coordinated therewith so that there will be either a zero flow F6 between the inlet compartment 70E and preheat chamber 71, or a positive flow F6 from inlet compartment 70E into preheat chamber 71.

After the preheating stage, the moving tier of carriers 50 emerges from the pre-heat chamber 71 and passes through the reaction chamber 71A in which is maintained a processing gas flow therethrough via inlet tube 89 to outlet tube 90, at a feed rate not greater than about 15 liters per minute and preferably from about 5 to about 10 liters per minute. Again, the specific length of processing chamber 71A for each of the examples shown in the corresponding FIGS. 26-29 is noted in the Table below. In general, regardless the processing atmosphere employed, the pressure in processing chamber 71A may range from about 0.001 to about 0.005 p.s.i.g. and preferably from about 0.001 to about 0.003 p.s.i.g.

Specifically for Examples XI and XII, the processing chamber 71A will be provided with a vapor etching atmosphere, whereas for Examples XIII and XIV the processing chamber 71A will be provided, as shown in FIGS. 28 and 29, with an environment of hydrogen and an epitaxial film-growing gas source.

After passage through the processing chamber 71A, the carriers 50 enter and pass through a second isolation chamber 74 which is, for all practical purposes, identical to the previously described isolation chamber 70. Since these two isolation chambers 70 and 74 are identical, and since the correlation of pressures in the various inlet compartments 74A, 74C, and 74E and outlet compartments 74B and 74D are identical to the pressures in the corresponding inlet and outlet compartments of isolation chamber 70 no extended description is necessary. If required, such details may be easily ascertained by reference to the above descriptions of corresponding portions of isolation chamber 70. In general, the pressure P71A in processing chamber 71A will be correlated to the pressure in inlet compartment 74A (of isolation chamber 74) so that there will be zero flow therebetween or a positive flow from inlet compartment 74A into the processing chamber 71A. However, it will be noted that this second isolation chamber 74 is free of heating coils to permit the wafers to cool to a second processing temperature prior to entry within a second induction heater coil 54 (which also extends about chambers 75, 75A and/or 75C) which maintains wafer temperature for the subsequent stage of processing.

The basic function of isolation chamber 74 is for utilization of protective gasses to effect critical isolation between processing chamber 72 (utilizing hydrogen) and processing chamber 75 (utilizing oxygen) at elevated temperatures. The effectiveness of isolation chamber 74 is readily apparent upon consideration of its length of 5 inches in the safe separation of oxygen and hydrogen both at elevated temperatures of the order of 1,000° to 1,200° C. In Examples XI and XIII, reaction chamber 75, 75A and 75C are employed to oxidize wafers 64 in corresponding dry, wet and dry oxygen environments.

The first and third oxidation chambers in the systems shown in FIGS. 26 and 28 are each about 7 and 4 inches in length respectively with the first defined between flanged partitions 81B and 91A, and the second defined between partitions 96A and 79C where each of the partitions extend to a level of about 0.015 inches above the surfaces of the traveling tier of carriers 50 to provide the desired orifice-size clearances therewith and thereby restrict the flow of gasses therethrough.

In general, dry oxygen is circulated through the first oxy-chamber 75 via its inlet and outlet 89 and 90 to provide a flow at a feed rate of about 2 liters per minute at a pressure of about 0.003 p.s.i.g. Generally, the feed rate may range from about 1 to 5 liters per minute, and the pressure may range from about 0.001 to about 0.005 p.s.i.g. However, in all cases the pressure P75 in oxy-chamber 75 will be less than the pressure in inlet compartment 74E (of isolation chamber 74) and correlated therewith so that there will be zero flow between them, or a positive flow from inlet compartment 74E into oxy-chamber 74.

In similar fashion dry oxygen is circulated through oxy-chamber 75C (about 8 inches in length) via its inlet and outlet tubes 89 and 90, respectively, to maintain a flow at a feed rate and pressure comparable to that employed in oxy-chamber 75, e.g., about 2 liters per minute and 0.003 p.s.i.g.

In general, the length of both oxy-chambers 75 and 75C will be determined by the range of oxide thicknesses desired, as correlated directly to the through-put of carriers 50, temperatures employed, and indirectly correlated to the parameters of the primary process employed which initially determines the range of speed for the through-put of carriers 50.

As seen in FIGS. 26 and 28, the second dry oxy-chamber 75C is preceded by the three-compartment isolation chamber 92 which follows wet oxy-chamber 75A.

The wet oxy-chambers 75 in the system shown in FIGS. 26-28 are about 32 inches in length with an oxygen/water vapor mixture circulated therethrough via its inlet and outlet tubes 89 and 90. The flow of the oxidation mixture is controlled to provide a feed rate of about 1 to about 5 liters per minute at a pressure in the range of about 0.001 to about 0.005 p.s.i.g.

In Examples XII and XIV, as shown in the respective FIGS. 27 and 29, reaction chambers 75 and 75A and 75C are employed for purposes of depositing a silicon nitride film on the substrates, and for this processing operation the chambers define, respectively, an intermediate-cool chamber 75, a nitriding chamber 75A, and a post-cool chamber 75C.

Thus for the silicon nitride deposition, as the tier of carriers 50 emerge from the last inlet compartment 74E, of isolation chamber 74, the carriers enter into a cooldown chamber 75 for cooling the supported wafers 64 to a second processing temperature, e.g., about 850° C. for silicon wherein temperatures may extend from the preferred range of about 800° to about 1,100° C. to a general range of about 700° to about 1,150° C.

Normally, the environment of cooldown chamber 75 will be selected so as to be compatible with the nitriding atmosphere in the succeeding reaction or nitriding chamber 75A, defined between partitions 91A and 91B. For example, the protective atmosphere in post-heat chamber 75 may conveniently be nitrogen in a general range of about 0.001 to about 0.05 p.s.i.g. and preferably from about 0.002 to about 0.005 p.s.i.g. flowing via the chambers inlet and outlet 89 and 90, respectively, at feed rates of about 1 to about 10 liters per minute

and preferably from about 2 to about 6 liters per minute. As will be understood from the discussions above, the pressure P75 in cooldown chamber 75 will be maintained at a level below the pressure P74E in the preceding inlet compartment 74E (of isolation chamber 74) and coordinated therewith so that there will be either a zero flow F6 between inlet compartment 74E and post-heat chamber 75, or a positive flow F6 from inlet compartment 74E into cooldown chamber 75.

After the cooldown stage, the moving tier of carriers 50 emerges from the cooldown chamber 75 and passes through the nitriding chamber 75A disposed within RF heating coils 54 and in which is maintained a substantially quiescent environment of a nitriding atmosphere having any of the compositions indicated therefor above. In the specific example employed herein, the nitriding atmosphere is comprised of silane, ammonia, in conjunction with nitrogen as a carrier therefor. The reactive atmosphere is maintained in continuous flow from the chamber's inlet tube 89 and outlet tube 90 at a feed rate not greater than about 15 liters per minute and preferably from about 6 to about 14 liters per minute. In general, the flow will be maintained at a Reynold's number below 3,000 (to provide a laminar flow) and will be sufficient to maintain a substantially constant proportional concentration of the reactive gas components. A typical composition of the above nitriding atmosphere employed in these examples may comprise 10 liters/minute nitrogen containing from about 0.005 to about 0.05 percent silane and from about 0.05 to about 0.5 percent ammonia per 10-liter volume. The specific mixtures of the nitriding atmospheres in these examples is set out in the tables below.

After passage of the substrates through the nitriding chamber 75A, the carrier supported substrates enter and pass through a post-cool chamber 75B which is provided with a protective atmosphere at positive pressures and flow rates in a general range of about 0.001 to about 0.05 p.s.i.g. and from about 2 to about 10 liters per minute, and preferably from 0.002 to about 0.005 p.s.i.g. and from about 3 to about 7 liters per minute. In general, the atmospheres of post-cool chambers 75C can be comprised of the conventional inert atmospheres such as nitrogen, helium, argon, and the like and may also include hydrogen, where the gas is common with a component employed in a nitriding atmosphere of processing chamber 75A.

The following Table 16 is set forth below to show the relative dimensions of the various chambers configured in the processing tubes of Examples XI to XIV as shown in their respective FIGS. 26-29.

After passage through the chamber 75C, the carriers 50 (with the wafers 64 supported thereon) enter and pass through an outlet buffer chamber 77 to discharge across the transfer table 98 between conveyor belts 99. As shown, the outlet buffer chamber, of about 13 inches in length, is provided with a protective atmosphere (e.g. inert gasses) with discharge of the gasses effected into ambient atmospheres through the restricted openings defined by end-partition 78A and the surfaces of carriers 50.

EXAMPLES XV and XVI

The following examples illustrate the adaptation of the reactor tubes 52 of FIGS. 22 to 25 into like structurally arranged reactor tubes 52 of FIGS. 30 and 31 for use in additional embodiments of the invention, directed to, respectively,

A. a continuous processing system for sequentially vapor etching and depositing an epitaxial film on semiconductor

70 planation of the wafer transport through the reactor tube 52 of FIGS. 30 and 31 is set forth, and details thereof can be readily ascertained by reference to the above description relative to FIGS. 22-25, which description is incorporated by reference in these examples. However, to characterize the reactor tubes 75 52 of FIGS. 30 and 31 to the systems of the instant examples, the relative dimensions and functions of the various chambers are set forth in the following table:

Example XV-FIG. 30			Example XVI-FIG. 31

77	Outlet buffer	5	Outlet buffer	5	

However, it is pointed out, that in the system of Example XV (FIG. 30) utilizing a vapor etch operation, the etching atmosphere may comprise hydrogen containing from about 2 to about 12 percent, by volume, of hydrogen halide such as hydrogen chloride, hydrogen bromide, hydrogen fluoride and hydrogen iodide. In the preferred embodiments of the etching atmosphere, as used in Example XV, the halide of the etching atmosphere comprises hydrogen, with a typical mixture of this etching atmosphere comprising, a 10 liter per minute flow of hydrogen containing about 6 volume per cent hydrogen chloride.

Similarly the epitaxial film-growing atmosphere, as employed in Examples XV and XVI (FIGS. 30 and 31, respectively) may comprise any of the compositions indicated therefor above. Also, as will be understood, the epitaxial film-growing atmosphere may include conductivity-type impurities as specifically shown in FIG. 30. In the preferred embodiments, as used in a specific example, the epitaxial film-forming atmosphere may comprise hydrogen containing from about

percent arsine. Also, the atmospheres for metal deposition may also comprise any of the compositions indicated therefor above. In the preferred embodiment as used in Example XVI, the metal-plating atmosphere comprises a two-component gaseous mixture wherein the first component is hydrogen and the second component is a halide of a plating metal having a resistivity less than about 100 microhms-cm., as for example, tungsten pentachloride, and specifically molybdenum pentachloride. A typical feed mixture of this metal-plating atmosphere will comprise 6 liters/minute hydrogen and 3 liters/minute argon containing about 6 volume per cent molybdenum pentachloride per 9 liter flow.

To illustrate the operation of the system shown in FIG. 30, 40 the following Table 22 is set forth to illustrate the process parameters of a specific operating system directed to Example XV for sequentially vapor etching and depositing an epitaxial film on silicon wafer supported on carriers 50 traveling through the system at a rate of 1 inch per minute.

EXAMPLE XVII

Sequential Thermal Oxidation and Metal Film Deposition

This example in conjunction with FIGS. 5, 7, 9-17 and 32 describes a continuous processing system for sequentially thermally oxidizing and depositing a metal film on semiconductor substrates.

In the same fashion described in the preceding examples, a continuous tier of wafer carriers 50 having a rectangular configuration are transported in end-to-end relationship by a feed mechanism generally indicated by the numeral 51 into a quartz processing tube 52 disposed within heating coils 53 and 54 which may be optionally enclosed in a furnace enclosure 55 of the usual construction.

Since water-cooled RF heater coils 53 and 54 are also shown and employed in this example, the carriers 50 are fabricated of suitable susceptor materials such as graphite, carbon, molybdenum and the like. However, it is to be understood that carriers 50 may also be constructed of other suitable materials compatible with the wafers and with process environments. In general, the material of carriers 50 will normally determine the type of heater coils employed in conjunction with reactor tube 52. Thus in a system employing quartz carriers, the heating coils can conveniently comprise resistance coils, and conversely the use of graphite in the construction of the carriers permits the use of either resistance coils or induction heater coils in this system.

The processing tube 52 shown here (FIG. 32) is also of rectangular configuration having an internal height of about 33mm. and an internal width of 89 mm. with an overall length of about 96 inches subdivided into appropriate chambers described below.

The carriers 50 illustrated in FIG. 6 are employed for processing the wafers having two and one-half inch diameter with it being understood that other variations in carrier and wafers aforesubjected in conjunction with the preceding examples may also be employed where desired or required. As in the previous embodiments, the carriers 50 were fabricated in a 3.45 inch square configuration, with a thickness of about 0.5 inches and having skids or rails 62 of about 0.015 inches depending from the bottom of the carrier to provide an overall height of 0.515 inches.

As in the previous examples, the top surfaces of carriers 50 of this Example XVII are also recessed at 63 to a sufficient depth to seat and maintain the rein a semiconductor wafer 64 of silicon and the like for multistage processing through the

25 reactor tube 52. In general, the top surfaces of the wafers will be substantially flush with the top surfaces of the carriers while seated therein.

The feed station shown in FIG. 5 may also be employed in this example, and comprises an endless conveyor 65 which carries the carriers between the drive unit 66 which comprises two side-gripping endless belts which contact the carriers on their sides to propel them in end-to-end relationship through processing tube 52. A transfer plate 67 is provided with side-guides 67A for feeding the carriers 50 in end-to-end relationship through the processing tube 52.

The reactor tube 52 of this example, as shown in FIG. 32, is configured to sequentially process a pre-conditioned silicon 40 wafer 64 for thermal oxidation of the substrates to form a film of silicon oxide thereon followed by deposition of a film of metal having a resistivity less than about 100 microhms-cm. at 18° C. Basically, the reactor tube of FIG. 32 is subdivided into an ambient inlet buffer chamber or zone 69, a first dry oxidation chamber 69A, a wet oxidation chamber 69B, an isolation or 45 buffer chamber 69C and isolation chamber 74, an inter-cool chamber 100, a metal-plating chamber 71A, a post-cool chamber 71B, a critical isolation chamber 73, and an ambient outlet buffer chamber 50 77.

The inlet buffer chamber 69 is about 10 inches in length and is defined between partitions 78 and 79 with partition 78 extending toward the bottom of reactor tube 52, a distance 55 providing about 0.25 inch clearance with the top of the tier of carriers 50. Inlet buffer chamber 69 forms a preliminary barrier with ambient atmospheres and is maintained with either an oxygen or a non-reactive gaseous environment of about 0.001 p.s.i.g. by introducing therein, through a circumferential slot 60 80A of a closed end nozzle 80 (of about 5 mm. ID), a suitably controlled flow of gas such as nitrogen, helium, argon forming gas or other gas which is compatible with ambient atmospheres and oxygen. Generally, however, for the instant processing system, the gas selected is oxygen which can be 65 maintained at a pressure which may extend from about 0.001 to about 0.005 p.s.i.g. and preferably from about 0.001 to about 0.003 p.s.i.g.

As indicated, nozzle 80 is a closed end structure having the 70 configuration shown and described in reference to FIG. 12.

The tier of carriers 50 traveling at a rate of 1 inch per minute passes out of the ambient inlet buffer chamber 69 into and through three oxidation chambers 69A, 69B, and 69C.

The reaction chambers 69A, 69B and 69C are employed to oxidize the wafers 64 in corresponding dry, wet and dry environments. The first dry-oxidation chamber 69A, of about 7 inches, in the system shown in FIG. 32 is defined between flanged partitions 79 and 79A, each of which extends to a level of about 0.015 inches above the surfaces of the traveling tier of carriers 50 to provide an orifice-sized clearance therewith and thereby restrict flow of gasses.

The second dry-oxidation chamber 69C in the system is about four inches in length and is defined between partitions 96A and 79B, both of which also extend to a level of about 0.015 inches above the surfaces of the traveling tier of carriers 50 to define the indicated orifice-sized clearance therewith and likewise restrict the flow of gasses therethrough. In general, dry oxidation is circulated through the first oxy-chamber via its inlet and outlets 89 and 90, respectively, to provide a flow at a feed rate of 2 liters per minute and a pressure of about 0.003 p.s.i.g. Generally, the feed rate may range from about 1 to 10 liters per minute, and the pressure may range from about 0.001 to about 0.03 p.s.i.g.

In similar fashion, dry-oxygen is circulated through dry oxy-chamber 69C via its inlet and outlet tubes 89 and 90, respectively, to again maintain a flow at a feed rate and pressure comparable to that employed in the first dry oxy-chamber 69A, e.g., about 2 liters per minute and 0.003 p.s.i.g.

The wet oxy-chamber 69B in the system, as shown in FIG. 32, is about 32 inches in length with an oxygen/water vapor mixture circulated therethrough via its respective inlet and outlet tubes 89 and 90. The flow of the oxidizing mixture is again controlled to provide a rate of about 2 to about 4 liters per minute which defines a substantially quiescent environment at a pressure in the range of about 0.002 to about 0.004 p.s.i.g.

In operation, as the tier of carriers 50 traveling at the indicated rate of 1 inch per minute emerges from ambient buffer chamber 69, and pass through dry oxy-chamber 69A, the surface of wafer 64 is converted into a relatively dense adherent oxide film ranging from about 250 to about 600 angstroms prior to entry in the following wet oxidation chamber 69B. On passage through the wet oxy-chamber 69B, the wafers are further oxidized by an additional thickness of about 3,000 to about 4,500 angstroms of relatively less dense oxide. From chambers 69B, the carrier supported wafers pass through the isolation chamber 92 into the dry oxygen chamber 69C for a final oxidation wherein the wafers 64 are further oxidized to form an additional film thickness of about 50 to about 150 angstroms.

In order to maintain the integrity of the oxidizing atmosphere in the wet oxy-chamber 69B and the oxidizing atmosphere in the second dry oxy-chamber 69C, a three-compartmented isolation chamber 92 (having the construction previously described above for this three-compartmented configuration, each of one inch in length) is interposed between the two oxy-chambers 69B and 69C. Upon emerging from the final oxidation in dry oxy-chamber 69C, the carriers enter and pass through a five-compartmented isolation chamber 74 having the same structural configuration indicated for like 1-inch, five-compartmented chambers described above.

Isolation chamber 74 also functions, in this example, as a buffer feed zone between the final oxidation chamber 69C and the metal plating chamber 71A to maintain the integrity of processing atmospheres therein. Also, as in the preceding examples, the carrier-supported wafers on passage through the isolation chamber 74 concurrently pass out of heating coil 54 which permits the wafers to cool toward processing temperatures for deposition of a metal film on the wafers, e.g., silicon wafers 64 may be heated to a general range of about 250° to about 750° C. and preferably in the range of about 300° to about 550° C.

Inlet compartments 74, 74C and 74E of isolation chamber 74 are provided with protective atmospheres which may com-

prise any of the inert gasses such as nitrogen, argon, helium and the like. In general, the pressure relationships, of the preceding five-compartmented isolation chambers will be maintained within the various compartments of isolation chamber 74 and between the adjacent second oxy-chamber 69C and the metal-plating chamber 71A, so as to maintain the same flow relationships indicated above.

As the carriers 50 emerge from the isolation chamber 74, they enter and pass through a 9-inch inter-cool chamber and into the metal-plating chamber 71A which is about 8 inches in length and is defined between flanged partitions 81B and 91 of the post-cool chamber 71B. Concurrently with passage through metal deposition chamber 71A, the wafers enter a second RF heating coil 54 which maintains the wafers at processing temperatures.

The metal-plating chamber 93 comprises a section of the processing tube of about 8 inches in length wherein the substrates or wafers 64 are subjected to a substantially quiescent flowing gaseous environment of hydrogen and a metal halide (e.g., molybdenum pentachloride) flowing from its inlet to its outlet, 89 to 90, respectively, at a feed rate of about 1 to about 15 liters per minute. Typically, the metal-plating atmospheres may comprise hydrogen and a halide of a metal having a resistivity less than about 100 microhms-cm. at 18° C. As will be understood, various metal-plating atmospheres such as indicated above may also be employed in the metal-plating chamber 93.

In the preferred embodiment, as used in this example, the metal-plating atmosphere comprises a two-component gaseous mixture wherein the first component is hydrogen and the second component is a halide of a metal having a resistivity less than about 100 microhms-cm. as for example, tungsten pentachloride, and specifically molybdenum pentachloride. A typical feed mixture of this metal-plating atmosphere will comprise 6 liters per minute hydrogen and 3 liters per minute argon containing about 6 volume per cent molybdenum pentachloride per 9-liter flow. In the process, as indicated, above the metal-plating atmosphere (e.g., molybdenum pentachloride and hydrogen) may be pre-heated externally of reactor tube 52 and injected therein via the inlet nozzle 89 (of processing chamber 71A) wherein upon contact with the heated wafers 64, the metal halide is reduced by hydrogen for liberation of the metal (e.g., molybdenum) at the surface of wafers 64 whereat the liberated metal is deposited. After passage of the substrates through the metal-plating chamber 93, the carrier-supported wafers 64 pass through the post-cool chamber 71B of about 8 inches in length and similar in construction to like chambers described above. Herein the wafers are cooled below critical or reactive temperatures (e.g., to about or below 400° C.).

After cooling, the wafers pass through the isolation chamber 73 similar in construction and function to those previously discussed in greater detail with respect to the 1-inch, five-compartmented chambers described above and in the preceding examples. However, during passage through the isolation chamber 73, the carriers and the wafers thereon are allowed to further cool toward ambient atmospheres as they emerge into a 5-inch outlet buffer chamber 77 for final exiting across a transfer table onto a conveyor for removal from the system.

To illustrate the operation of the system of this example as shown in FIG. 32, the following Table 24 is set forth to illustrate the environment and results of a specific operating system for processing of surface pre-condition silicon wafers supported on the carriers traveling through the system at a rate of 1 inch per minute. For the specific example set out below the wet oxidizing atmosphere comprised 0.92 mole fraction of water in oxygen; and the metal depositing atmosphere comprised 6 liters/minute hydrogen in combination with 3 liters/minute argon containing, by volume, 6 percent molybdenum pentachloride per the 9-liter volume.

EXAMPLES XVIII TO XXIII

The following examples illustrate various embodiments of this application directed to:

- A. a continuous multistage processing system for sequentially vapor etching and depositing consecutive layers of epitaxial and metal films on semiconductor substrates without exposure of the substrates to ambients intermediate the processing operations, as shown in FIG. 33;
- B. a continuous multistage processing system for sequentially vapor etching and depositing consecutive superposed layers of epitaxial and nitride films on semiconductor substrates without exposure of the substrates to ambients intermediate processing operations, as shown in FIG. 34;
- C. a continuous multistage processing system for sequentially vapor etching and depositing superposed consecutive layers of epitaxial and oxide films on substrates without exposure of the substrates to ambients intermediate processing operations, as shown in FIG. 35;
- D. a continuous multistage processing system for sequentially vapor etching and depositing successive nitride and metal films on semiconductor substrates without exposure of the substrates to ambients intermediate processing operations, as shown in FIG. 36;
- E. a continuous multistage processing system for sequentially vapor etching and depositing consecutive oxide and metal films on semiconductor substrates without exposure of the substrates to ambients intermediate processing operations, as shown in FIG. 37; and
- F. a continuous multistage processing system for sequentially depositing superposed and consecutive epitaxial, oxide and metal films on semiconductor substrates without exposure of the substrates to ambients intermediate processing operations, as shown in FIG. 38.

As above, in view of the similarity of the tube configurations employed in each of the four Examples (XVIII to XXIII), only a single tube configuration will be described with the specific process parameters and chamber dimensions set forth below for each example. However, as will be understood, in the systems utilizing a vapor etching operation (Examples XVIII to XXIII), the etching atmosphere may comprise hydrogen containing a hydrogen halide, such as hydrogen chloride, hydrogen bromide, hydrogen fluoride, and hydrogen iodide. In a preferred embodiment of the etching atmosphere, as used in the specific examples set out (e.g., Examples XVIII to XXII), the halide of the etching atmosphere comprises hydrogen chloride, with a typical mixture of this etching atmosphere comprising a 6 to 12 liter/minute flow of hydrogen containing from about 2 to about 12 volume per cent hydrogen chloride. For the specific example set out below the vapor etch atmosphere comprised hydrogen containing, by volume, 6 percent hydrogen chloride.

Similarly, in systems incorporating an epitaxial film deposition (e.g., Examples XVIII, XIX, XX and XXIII), the epitaxial film-growing atmospheres may comprise any of the compositions indicated therefor above. Further, as will be understood, the epitaxial film-growing atmosphere may include conductivity-type determining impurities. In the preferred embodiments, (as used in the specific example below), the epitaxial film-forming atmosphere may comprise hydrogen containing from about 0.1 to about 1.0 percent, by volume, silicon tetrachloride in combination with from about 0.01 to about 0.5 percent, by volume, of arsine as a conductivity-type determining impurity. In a specific epitaxial film-forming atmosphere employed in these examples, the composition of the atmosphere comprises hydrogen containing, by volume, 0.5 percent silicon tetrachloride, and 0.05 percent arsine.

Also, any of the metal-plating atmospheres indicated above may also be employed for purposes of these examples (particularly Examples XVIII and XXIII). Typically, the metal-plating atmosphere may comprise hydrogen and a halide of a metal having a resistivity less than about 100 microhms-cm. at 18° C. In the preferred embodiment, as used in this Example, the metal-plating atmosphere comprises a two-component gaseous mixture wherein the first component is hydrogen and the second component is a halide of a metal having a resistivity less than about 100 microhms-cm., as for example, tungsten pentachloride, and specifically molybdenum pentachloride.

As used in the specific examples below, the mixture of this metal-plating atmosphere will comprise 6 liters/minute of hydrogen and 3 liters/minute argon containing, by volume, about 6 percent molybdenum pentachloride per 9-liter flow.

Also, the nitriding atmospheres may also comprise any of the compositions indicated therefor above. In a preferred embodiment as used in the specific examples (e.g., Examples XIX and XXI) set out below, the nitriding atmosphere may be comprised of silane and ammonia in conjunction with hydrogen as a carrier therefor. A typical composition of these nitriding atmospheres may comprise 10 liters of hydrogen containing, by volume, from about 0.005 to about 0.05 percent silane and from about 0.05 to about 0.5 percent ammonia. A specific mixture of this nitriding atmosphere, as used in the Examples set out below comprised 10 liters of hydrogen containing, by volume, 0.02 percent silane and 0.2 percent ammonia.

Also for vapor state oxide deposition, the oxide-forming composition may also comprise any of those previously indicated above therefor. In the preferred embodiments, as used in the specific examples set out below (Examples XX, XXII and XXIII), the oxide-forming atmosphere can comprise a three-component mixture wherein the first component is hydrogen, the second component may be either oxygen or carbon dioxide, and the third component may be either an organic silicate, a silicon halide, or an alkoxy silane. A typical

mixture of this film-forming atmosphere will comprise, by volume, about 92 to about 99 percent hydrogen, about 0.92 to about 1.2 percent silicon tetrachloride and about 0.4 to about 0.6 percent oxygen. In the specific examples below the oxide-forming atmosphere comprised hydrogen containing, by volume, 0.5 percent silicon tetrachloride and 1.0 percent oxygen.

The tube configuration shown in FIGS. 33-38 are employed in these Examples as follows:

- A. Example XVIII in conjunction with FIGS. 5,7,9-17 and 33 describes a continuous processing system for sequentially vapor etching and depositing superposed contiguous layers of epitaxial and metal films on semiconductor substrates;
- B. Example XIX in conjunction with FIGS. 5,7,9-17 and 34 describes a continuous processing system for sequentially vapor etching and depositing superposed consecutive layers of epitaxial and nitride films on semiconductor substrates;
- C. Example XX in conjunction with FIGS. 5,7,9-17 and 35 describes a continuous processing system for sequentially vapor etching and depositing superposed consecutive layers of epitaxial and oxide films on semiconductor substrates;
- D. Example XXI in conjunction with FIGS. 5,7,9-17 and 36 describes a continuous processing system for sequentially vapor etching and depositing superposed consecutive nitride and metal films on semiconductor substrates;
- E. Example XXII in conjunction with FIGS. 5,7,9-17 and 37 describes a continuous processing system for sequentially vapor etching and depositing oxide and metal films on semiconductor substrates; and
- F. Example XXIII in conjunction with FIGS. 5,7,9-17 and 38 describes a continuous processing system for sequentially depositing consecutive epitaxial oxide and metal films on semiconductor substrates.

In the same fashion described in the preceding examples, in these six Examples, XVIII to XXIII taken in conjunction with their respective FIGS. 33-38, a continuous tier of carriers 50 having a rectangular configuration are transported in end-to-end relationship by a feed mechanism generally indicated by the numeral 51 into a quartz processing tube 52 disposed within heating coils 53, 53A and 53B which may be optionally enclosed in a furnace enclosure 55 of the usual construction.

Since water-cooled RF heater coils 53, 53A and 53B are also shown and employed in these Examples, the carriers 50 are fabricated of suitable susceptor materials such as graphite, carbon, molybdenum and the like. However, it is to be understood that carriers 50 may also be constructed of other suitable materials compatible with the wafers and with process environments. In general, the material of carriers 50 will normally determine the type of heater coils employed in conjunction with reactor tube 52. Thus in a system employing quartz carriers, the heating coils can conveniently comprise resistance coils, and conversely the use of graphite in the construction of the carriers permits the use of either resistance coils or induction heater coils in the systems.

The processing tubes shown here are also of rectangular configuration having an internal height of about 33 mm. and an internal width of 89 mm. Each processing tube 52 is subdivided into appropriate chambers, described below, with the various processing tubes having the following overall lengths:

FIGURE 33	90 inches
FIGURE 34	90 inches
FIGURE 35	90 inches
FIGURE 36	96 inches
FIGURE 37	90 inches
FIGURE 38	90 inches

The carriers 50 illustrate in FIG. 6 are employed for processing the wafers having two and one half inch diameter with it being understood that other variations in carriers and wafers aforesubjected in conjunction with the preceding Examples may also be employed where desired or required. As in the previous embodiments, the carriers 50 were fabricated in a

3.45-inch-square configuration with a thickness of about 0.5 inches and having skids or rails 62 of about 0.015 inches depending from the bottom of the carriers to provide an overall height of 0.515 inches, defining a free-flow cross section of 17.7 sq. cm. in the unbaffled portion of the tubes.

As in the previous examples, the top surfaces of carriers 50 of these examples are also recessed at 63 to a sufficient depth to seat and maintain therein a semiconductor wafer 64, of silicon, germanium, and the like, for multistage processing through the tubes 52. In general, the top surfaces of the wafers will be substantially flush with the top surfaces of carriers 50 while seated therein.

The feed station shown in FIG. 5, may also be employed in these examples, and comprises an endless conveyor 65 which carries the carriers between the drive-unit 66 which comprises two-side gripping endless belts which contact the carriers on their sides to propel them in end-to-end relationship through processing tubes 52. The transfer plate 67 is provided with side-guides 67A for feeding the carriers 50 in end-to-end relationship through the processing tubes 52.

Specifically the processing tube shown in FIG. 33 is configured to sequentially process a pre-conditioned silicon wafer 64 by vapor etching the substrates and sequentially depositing epitaxial and metal films on the substrates.

In turn, the processing tube 52 shown in FIG. 34 is configured to sequentially process a pre-conditioned silicon wafer 64 by vapor etching of the wafer followed by vapor state deposition of an epitaxial and nitride film on the substrates.

Similarly, the processing tube shown in FIG. 35 is configured to sequentially process a pre-conditioned silicon wafer 64 by vapor etching of the wafer followed by successive depositions of epitaxial and oxide films on the substrates.

Also the processing tube 52 shown in FIG. 36 is configured to sequentially process a pre-conditioned silicon wafer 64 by vapor etching of the wafers followed by successive depositions of nitride in metal films on the substrates.

Also the processing tube 52 shown in FIG. 37 is configured to sequentially process a pre-conditioned silicon wafer 64 by vapor etching of the wafer followed by successive vapor state deposition of oxide and metal films on the substrates.

Finally, the processing tube shown in FIG. 38 is configured to sequentially process a pre-conditioned silicon wafer 64 by sequential vapor state deposition of epitaxial, oxide and metal films on the substrates.

Basically, the reactor tubes of FIGS. 33-38 are subdivided into an ambient inlet buffer chamber or zone 69, a critical five-compartmented isolation chamber 70, a pre-heat chamber 71, a first reaction chamber 71A, a three-compartmented isolation chamber 101, a second processing chamber 71B, a second three-compartmented isolation chamber 92, a third processing chamber 93, a cooldown chamber 93A, a third five-compartmented isolation chamber 73, and an ambient outlet buffer chamber 77 with intermediate cooling chambers 100 positioned in the processing tube as shown in FIGS. 33 to 38.

The buffer zone or chamber 69 is defined between partitions 78 and 79, with partition 78 extending toward the bottom of reactor tube 52, a distance providing about 0.25-inch clearance with the top of a tier of carriers 50. Buffer zone 69 forms a preliminary barrier against ambient atmospheres and is maintained with a non-reactive protective atmosphere of about 0.05 p.s.i.g. by introducing therein through a circumferential slot 80A of the closed end nozzle 80 (of about 5 mm.

65 ID) a suitably controlled flow of an inert gas such as nitrogen, helium, argon, forming gas and the like. Generally however, for these processing systems the pressure in ambient chamber 69, as above, may extend from about 0 to about 0.003 p.s.i.g. and preferably from about 0.001 to about 0.005 p.s.i.g. As indicated nozzle 80 is a closed end construction having a configuration shown and described in reference to FIG. 12.

The moving tier of carriers eventually passes out of ambient buffer chamber 69 into and through the critical five-compartmented isolation chamber 70 having the same structural configuration indicated therefor in the previous examples; and ac-

cordingly, like component features are indicated by the same reference numerals.

Also as in the preceding examples, the isolation chamber 70 is subdivided into a series of alternate inlet and outlet compartments into which protective gasses are introduced and withdrawn. For the particular isolation obtained, the isolation chamber 70 is subdivided into an inlet compartment 70A, an outlet compartment 70B, a second inlet compartment 70C, a second outlet compartment 70D, and a third inlet compartment 70E, each about 1 inch in length. In general, the pressure relationships of the preceding examples are also maintained within and between various compartments of isolation chamber 70 and between the adjacent inlet chamber 69, and the pre-heat chamber 71, so as to maintain the same flow and pressure relationship indicated above therefor.

As the tier of carriers 50 emerges from the last compartment 70E, of isolation chamber 70, the carriers enter into a non-reactive pre-heat chamber 71, dispose within the heating coils 53 for heating the supported wafers 64 to processing temperatures, e.g., (a) for etching, in the general range of about 1,000° to about 1,300° C. for silicon, and from about 350° to about 900° C. for germanium and (b) for epitaxial deposition, in the general range of about 950° to about 1,350° C. for silicon, and from about 600° to about 920° C. for germanium.

The pre-heat chamber 71 is defined between flanged partitions 81 and 91, with the specific length of the pre-heat chamber 71 set out below for each example.

Normally, the environment in pre-heat chamber 71 will be selected so as to be compatible with the atmospheres in a succeeding processing chamber 71A defined between partitions 91 and 79B. For example, the protective atmospheres in pre-heat chamber 71 may not only comprise any of the indicated inert gasses but also may include hydrogen where this gas is employed as a component in the environment in processing chamber 71A. Thus, since each of Examples XVIII-XXIII employs hydrogen as a component in the processing gas within processing chamber 71A, hydrogen may also be employed as a protective atmosphere within pre-heat chamber 71 in view of its compatibility with the processing gasses. In general, the protective atmosphere employed in pre-heat chamber 71 will be maintained in the general range of about 0.001 to about 0.05 p.s.i.g. and preferably from about 0.002 to about 0.005 p.s.i.g. It is to be understood that the pressure P_{71} in pre-heat chamber 71 will be maintained at the level below the pressure P_{70E} in the preceding inlet compartment 70E (of isolation chamber 70) and coordinated therewith so that there will be either a zero flow F6 between the inlet compartment 70E and pre-heat chamber 71, or a positive flow F6 from inlet compartment 70E into pre-heat chamber 71.

After the pre-heating stage, the moving tier of carriers 50 emerges from the pre-heat chamber 71 and passes through the reaction chamber 71A in which is maintained a processing gas flowing therethrough via its inlet tube 89 to outlet tube 90, at a feed rate not greater than about 15 liters per minute and preferably from about 5 to 10 liters per minute. Again, the specific length of processing chamber 71A for each of the examples shown in the corresponding FIGS. 33-38 is noted in the Table below. In general, regardless the processing atmosphere employed, the pressure in processing chamber 71A may range from about 0.001 to about 0.05 p.s.i.g., and preferably from about 0.002 to about 0.005 p.s.i.g.

Specifically, for Examples XVIII-XXII, the processing chamber will be provided with a vapor etching atmosphere, whereas for Example XXIII to processing chamber 71A will be provided, as shown in FIG. 38, with an environment of hydrogen and an epitaxial film-growing gas source.

After passage through the processing chamber 71A, the carriers 50 enter and pass through a three-compartmented isolation chamber 101 which is, for all practical purposes, identical to the below described isolation chamber 92. Since these isolation chambers 101 and 92 are identical, and since the correlation of pressures in the various outlet compartments 101A and 101C and inlet compartment 101B are identical to the

pressures in the corresponding inlet and outlet compartments of isolation chamber 92 no extended description is necessary. If required, such details may be easily ascertained by reference to the below descriptions of corresponding portions of isolation chamber 92. In general, the pressure P_{71A} in processing chamber 71A will be correlated to the pressure in outlet compartment 101A (of isolation chamber 101) so that there will be a positive flow therebetween or positive flow from processing chamber 71A into outlet compartment 101A, and the pressure in inlet compartment 101B will at all events be at a level higher than the pressure levels in chambers 71A and 71B so that there will be a positive gas flow a) from compartment 101B into outlet compartments 101A and 101C, and b) a positive gas flow from processing chambers 71A and 71B into respective outlet compartments 101A and 101B. However, it will be noted that this second isolation chamber 101 is positioned within a second induction heater coil 53A (which also extends around chamber 71B) to temperature condition the wafers for a subsequent stage of processing.

The basic function of isolation chamber 101 is for utilization of protective gasses to effect critical isolation between processing chambers 71A and 71B to maintain the integrity of the processing atmospheres therein.

As the carriers 50 emerge from isolation chamber 74, they enter and pass through the second processing chamber 71B in which is also maintained a substantially quiescent environment of a processing gas flowing therethrough, via inlet tube 89 to outlet tube 90 of the chamber, at a feed rate not greater than about 15 liters per minute and preferably from about 5 to about 10 liters per minute and preferably from about 5 to about 10 liters per minute. Again, the specific length of processing chambers 71B for issue and the examples shown in corresponding FIGS. 33-38 are noted in the Table below. In general, regardless of the processing atmosphere employed, the pressure in processing chamber 71B may range from about 0.001 to about 0.05 p.s.i.g., and preferably from about 0.002 to about 0.005 p.s.i.g.

Specifically, for Examples XVII-XX, the processing chamber 71B will be provided (as shown in FIGS. 33-35) with an environment of hydrogen and an epitaxial film-growing gas source. As regards Example XXI, the processing chamber 71B will be provided (as shown in FIG. 36) with an atmosphere forming a nitrided silicon. With respect to Examples XXII and XXIII, the processing chamber 72B will be provided (as shown in FIGS. 37 and 38) with an oxide-forming gaseous environment.

After passage through the processing chamber 71B, the carriers enter and pass through a three-compartmented isolation chamber 92 having identical configured chambers of the preceding examples the description of which is incorporated herein by reference thereto.

Also, as the carrier-supported wafers pass through isolation chamber 92, they concurrently pass out of heating coil 53A and through an inter-cool chamber 100 which permits the wafers to cool to suitable processing temperature for subsequent processing in the third processing chamber 93.

Basically, the three-compartmented isolation chamber 92 functions as a buffer between the two processing chambers 71B and 93 while maintaining the integrity of the processing atmospheres therein.

As previously noted, the three-compartmented isolation chamber 92, is subdivided into a series of alternate outlet and inlet compartments in which protective gasses are introduced and withdrawn. For the particular isolation obtained, the isolation chamber 92 is subdivided into an outlet compartment 92A, and inlet compartment 92B and an outlet compartment 92C. In general, the pressure relationships of the preceding examples are also maintained within and between various compartments of isolation chamber 70 and between the adjacent processing chambers 71B and 93 so as to maintain the same flow and pressure relationships indicated above therefor. Basically, the pressure in inlet compartment 92B will at all events be at a level higher than the pressure levels in

processing chamber 71B and 93 so that there will be a positive gas flow (a) from compartment 92B into outlet compartment 92A and (b) a positive flow from processing chamber 71B into outlet compartment 92A. Conversely, there will be positive gas flows into outlet compartments 92C from each of compartment 92B and processing chamber 93.

As the carriers 50 emerge from the isolation chamber 92, they pass through the inter-cool chamber 100 and enter into the third processing chamber 93 surrounded by an RF coil 53B and in which is maintained a substantially quiescent environment of another processing gas flowing therethrough via its inlet tube 89 and outlet tube 90 at a feed rate not greater than about 15 liters per minute, and preferably from about 5 to about 10 liters per minute. As will be noted in FIGS. 37 and 38, the inter-cool chamber 100 is omitted intermediate chambers 92 and 93, with an inter-cool chamber 102 positioned intermediate chambers 101 and 71B as well as in FIG. 36. Again the specific length of processing chamber 93 is noted in the Table below. In general, regardless the processing atmospheres employed, the pressure processing chamber 93 will range from about 0.0001 to about 0.05 p.s.i.g. and preferably

Conversely with respect to Example XX, the processing chamber 93 will be provided (as shown in FIG. 35) with an oxide-forming atmosphere.

After passage of the substrates through the processing chamber 93, the carrier supported wafer 64 passes through the post-cool chamber 93A similar in construction to like chambers described above. Herein the wafers are cooled below critical or reactive temperatures.

After cooling, the wafers pass through the isolation chamber 73 similar in construction and function to those previously discussed in greater detail with respect to the five-compartmented chambers described in the preceding examples. However, during passage through the isolation chamber 73 the carriers and wafers thereon are allowed to further cool toward ambient atmospheres as they emerge into outlet buffer chamber 77 for final exiting across a transfer table onto a conveyor for removal from the system.

The following Table 25 is set forth below to show the relative dimensions of the various chambers and compartments configured in the processing tubes of Examples XVIII-XXIII, as shown in their respective FIGS. 33-38.

TABLE 25.—Length of chambers or compartment, inches

from about 0.002 to about 0.005 p.s.i.g.

Specifically in Examples XVIII and XXI-XXIII, the processing chamber 93 will be provided a metal film-forming atmosphere as shown in FIGS. 33 and 36-38. As regards Example XIX, the processing chamber 93 will be provided, as shown in FIG. 34, with a silicon nitride-forming atmosphere.

To illustrate the operation of the system of Example XVIII, as shown in its FIG. 33, the following Table 26 is set forth to illustrate the process parameters of a specific operating system for vapor etching, epitaxial deposition followed by metal-film deposition on silicon wafers supported on carriers 50 traveling through the system at a rate of 1 inch per minute.

EXAMPLES XXIV AND XXV

The following examples illustrate various embodiments of the invention directed to

- A. a continuous method for sequentially vapor etching, thermally oxidizing and depositing a metal film on semiconductor substrates without exposure of the substrates to ambients in intermediate processing operations, as shown in FIG. 39;
 B. a continuous multistage processing system for sequentially depositing an epitaxial film, thermally oxidizing a metal film on semiconductor substrates without exposure of the substrates to ambients intermediate processing operations, as shown in FIG. 40.

In view of the similarity in the tube configurations employed in each of the two Examples, only a single tube configuration will be described for the specific process parameters and chamber dimensions set forth below for each example. However, as will be understood, in the system utilizing a vapor etch operation, the etching atmosphere may comprise hydrogen containing a hydrogen halide such as hydrogen chloride, hydrogen bromide, hydrogen fluoride and hydrogen iodide. In a preferred embodiment of the etching atmosphere, it is used in the specific examples set out below (e.g., Example XXIV) the halide of the etching atmosphere comprises hydrogen chloride, with a typical mixture of this etching atmosphere comprising a 6 to 12 liters per minute flow of hydrogen containing from about 2 to about 12 volume per cent hydrogen chloride. For the specific example set out below the vapor etch atmosphere comprised hydrogen containing, by volume, 6 percent hydrogen chloride.

Similarly any of the thermal oxidizing atmospheres indicated above may also be employed for purposes of these examples. Thus, for the thermal oxidation of silicon semiconductor substrates, the oxidizing atmosphere may comprise oxygen in conjunction with water vapor, or a combination of the two as employed in these specific embodiments described herein. Specifically as shown in more particularity in the Tables below and in FIGS. 39 and 40, a three-stage oxidation is normally employed comprising a first oxidation in dry-oxygen, a second oxidation of the substrates in a gaseous mixture of oxygen and water vapor followed by a third oxidation of the substrates in dry-oxygen. For the specific example set out below the wet oxidizing atmosphere oxygen containing 0.92 mole fraction water.

Also, the atmospheres for metal deposition may also comprise any of the compositions indicated therefor above. In the preferred embodiments as used in Examples XXIV and XXV, the metal-plating atmosphere comprises a two-component gaseous mixture wherein the first component is hydrogen and the second component is a halide of a plating metal having a resistivity less than about 100 microhms-cm. at 18° C., for ex-

ample tungsten pentachloride, and specifically molybdenum pentachloride. A typical mixture of this metal-plating atmosphere will comprise 3 liters per minute argon and 6 liters per minute hydrogen containing about 6 volume per cent molybdenum pentachloride. Further, the epitaxial film-growing atmosphere as employed in Example XXV may comprise any of the compositions indicated therefor above. As will be understood, the epitaxial film-growing atmosphere may also include conductivity-type determining impurities. In the preferred embodiments, as used in the specific examples, as set out below, the epitaxial film-growing atmosphere may comprise hydrogen containing from about 0.1 to about 1.0 percent by volume, silicon tetrachloride in combination with from about 0.01 to about 0.5 percent of arsine as a conductivity-type determining impurity. In a specific epitaxial film-forming atmosphere employed in Example XXV, the composition of the atmosphere comprised hydrogen containing 0.5 percent, by volume, silicon tetrachloride and 0.05 volume per cent arsine.

The tube configurations shown in FIGS. 39 and 40 are employed in these examples as follows:

- A. Example XXIV in conjunction with FIGS. 5, 7, 9-17 and 39 describes a continuous processing system for sequentially vapor etching, thermally oxidizing and depositing a metal film on semiconductor substrates; and
 B. Example XXV in conjunction with FIGS. 5, 7, 9-17 and 40 describes a continuous processing system for sequentially depositing an epitaxial film, thermally oxidizing and depositing a metal film on semiconductor substrates.
 50 In the same fashion described in the preceding examples, in the present two Examples XXIV and XXV taken in conjunction with their respective FIGS. 39 and 40, a continuous tier of wafer carriers 50 having a rectangular configuration are transported in end-to-end relationship by a feed mechanism generally indicated by the numeral 51 into a quartz processing tube 52 disposed within heating coils 53, 53A, and 53B which may be optionally enclosed in a furnace enclosure 55 of the usual construction.

Since water-cooled RF heater coils 53, 53A and 53B are also shown and employed in these examples, the carriers 50 are fabricated of suitable susceptor material such as graphite, carbon, molybdenum and the like. However, it is to be understood that carriers 50 may also be constructed of other suitable materials compatible with the wafers and with processing environments. In general, the material of carriers 50 will normally determine the type of heater coils employed in conjunction with reactor tube 52. Thus in a system employing quartz carriers, the heating coils can conveniently comprise resistance coils and, conversely, the use of graphite in the construction of the carriers permits the use of either resistance coils or induction heater coils in the systems.

The processing tube shown here is also of rectangular configuration having an internal height of about 33 mm. and an internal width of 89 mm. Each processing tube 52 is subdivided into appropriate chambers, described below, with the various processing tubes having the following overall lengths:

FIGURE 39
FIGURE 40

124 inches
124 inches

The carriers 50 illustrated in FIG. 6 are employed for processing the wafers having two and one-half inch diameter with it being understood that other variations in carriers and wafers aforesubjected in conjunction with the preceding examples may also be employed where desired or required. As in the previous embodiments, the carriers 50 were fabricated in a 76.8 cm. sq. configuration with a thickness of about 0.5 inches and having skids or rails 62 to about 0.015 inches depending from the bottom of the carriers to provide an overall height of 0.515 inches which defines a free-flow cross section of 17.7 sq. cm. in the unbaffled portions of the tubes.

As in the previous examples, the top surfaces of carriers 50 of these examples are also recessed at 63 to a sufficient depth to seat and maintain therein a semiconductor wafer 64, of silicon, germanium and the like, for multistage processing through the tubes 52. In general, the top surfaces of the wafers will be substantially flush with the top surfaces of carriers 50 while seated therein.

The feed-station shown in FIG. 5 may also be employed in these examples, and comprises an endless conveyor 65 which carries the carriers between the drive-unit 66 which comprises two side-gripping endless belts which contact the carriers on their sides to propel them in end-to-end relationship through processing tube 52. The transfer plate 67 is provided with side-guide 67A for feeding the carriers 50 in end-to-end relationship through the processing tubes 52.

Specifically the processing tube shown in FIG. 39 is configured to sequentially process a pre-condition silicon wafer 64 by vapor etching followed by thermal oxidation of the substrates and deposition of a metal film thereon.

In turn the processing tube 52 shown in FIG. 40 is configured to sequentially process a pre-condition silicon wafer 64 by deposition of an epitaxial film followed by thermal oxidation of the substrates and subsequent deposition of a metal film thereon.

Basically, the reactor tube of FIGS. 39 and 40 are subdivided into an ambient inlet buffer chamber or zone 69, a critical isolation chamber 70, a pre-heat chamber 71, a first environmental processing chamber 71A, a second critical five-compartmented isolation chamber 74, a first oxidation chamber 71B, a second oxidation chamber 71C, a three-zone isolation chamber 101, a third oxidation chamber 71D, a five-compartmented isolation chamber 75, an inter-cool chamber 100, a third environmental processing chamber 71E, a post-cool chamber 71F, a five-compartmented isolation chamber 73, and an ambient outlet buffer chamber 77.

The buffer zone or chamber 69, of about 5 inches in length, is defined between partition 78 and 79, with partition 78 extending to the bottom of the reactor tube 52 a distance providing about 0.25 inches clearance with the top of a tier of carriers 50. Buffer zone 69 forms a preliminary barrier against ambient atmospheres and is maintained with a non-reactive protective atmosphere of about 0.003 p.s.i.g. by introducing therein through a circumferential slot 80A of a closed end nozzle 80 (of about 5 mm. ID) a suitably controlled flow of an inert gas such as nitrogen, helium, argon, forming gas and the like. Generally, however, for this processing system the pressure in ambient chamber 69, as above, may extend from 0.001 to about 0.005 p.s.i.g. and preferably from about 0.001 to about 0.003 p.s.i.g. As indicated, nozzle 80 is a closed end construction having a configuration shown and described in reference to FIG. 12.

The moving tier of carriers 50 eventually passes out of ambient buffer chamber 69 into and through the critical five-

compartmented isolation chamber 70 having the same structural configuration indicated therefor in the previous examples; and accordingly, like component features are indicated by the same reference numerals.

5 Also as in the preceding examples, the isolation chamber 70 is subdivided into a series of alternate inlet and outlet compartments into which protective gasses are introduced and withdrawn. For the particular isolation obtained, the isolation chamber 70 is subdivided into an inlet compartment 70A, an outlet compartment 70B, a second inlet compartment 70C, a second outlet compartment 70D, and a third inlet compartment 70E, each about 1 inch in length. In general, the pressure relationships of the preceding examples are also maintained within and between various compartments of isolation chamber 70, and between the adjacent ambient inlet buffer chamber 69 and, the pre-heat chamber 71, so as to maintain the same flow and pressure relationship indicated above therefor.

10 As the tier of carriers 50 emerges from the last compartment 70E, of isolation chamber 70, the carriers enter into a non-reactive pre-heat chamber 71 disposed within the heating coils 53 for heating the supported wafers 64 to processing temperatures, e.g., (a) for etching, in a general range of about 1,000° to 1,300° C. for silicon, and from about 350° to about 900° C. for germanium, and (b) for epitaxial deposition, in a general range of about 950° to about 1,350° C. for silicon, and from about 600° to about 920° C. for germanium.

15 The pre-heat chamber 71 is defined between the flanged partitions 81 and 91 with the specific length of the pre-heat chamber 71 set out below for each example. Normally, the environment in pre-heat chamber will be selected so as to be compatible with the atmosphere in the succeeding processing chamber 71A defined between partitions 91 and 79B. For example, the protective atmospheres in pre-heat chamber 71 may not only comprise any of the indicated inert gasses but also may include hydrogen where this gas is employed as a component in the environment in processing chamber 71A. Thus, since each of Examples XXIV and XXV employs

20 hydrogen as a component in the processing gas within processing chamber 71A, hydrogen may also be employed as a protective atmosphere within pre-heat chamber 71 in view of its compatibility with the processing gasses. In general, the protective atmosphere employed in pre-heat chamber 71 will be maintained in the general range of about 0.001 to about 0.05 p.s.i.g., and preferably from about 0.002 to about 0.005 p.s.i.g. It is to be understood that the pressure P_{71} in pre-heat chamber 71 will be maintained at a level below the pressure P_{70E} in the preceding inlet compartment 70E (of isolation chamber 70) and coordinated therewith so that there will be either a zero flow F_6 between the inlet compartment 70E into pre-heat chamber 71.

25 After the pre-heating stage, the moving tier of carriers 50 emerges from the pre-heat chamber 71 and passes through the reaction chamber 71A in which is maintained a substantially quiescent environment of a processing gas flowing therethrough via inlet tube 89 to outlet tube 90, at a feed rate not greater than about 15 liters per minute and preferably from about 5 to 10 liters per minute. Again, the specific length of processing chamber 71A for each of the examples shown in their corresponding FIGS. 39 and 40 is noted in the table below. In general, regardless the processing atmosphere employed, the pressure in processing chamber 71A may range 30 from about 0.001 to about 0.05 p.s.i.g., and preferably from about 0.001 to about 0.003 p.s.i.g.

35 30 Specifically, for Example XXIV, the processing chamber 71A will be provided with a vapor etching atmosphere, whereas for Example XXV, the processing chamber 71A will be provided, as shown in FIG. 39 with an environment of hydrogen and an epitaxial film-growing gas source.

40 After passage through the processing chamber 71A, the carriers 50 enter and pass through a second isolation chamber 74 which is, for all practical purposes, structurally identical to the 45 previously described isolation chamber 70 since these two

50 50

55 55

isolation chambers 70 and 74, as well as a subsequent isolation chamber 75, are identical and since the correlation of pressures in the various inlet compartments 74A, 74C and 74E, and outlet compartment 74B and 74D are identical to the pressures in the corresponding inlet and outlet compartments of isolation chambers 70 no extended description is necessary. If required, such details may be easily ascertained by reference to the above description of corresponding portions of isolation chamber 70. In general, the pressure $P71A$ in processing chamber 71A will be correlated to the pressure in inlet compartment 74A (of isolation chamber 74) so that there will be zero flow therebetween or a positive flow from inlet compartment 74A into processing chamber 71A. However, it will be noted that this second isolation chamber is positioned within a second induction heater coil 54 (which also extends about chambers 71B, 71C and 71D) to temperature condition the wafers for a subsequent stage of processing.

The basic function of isolation chamber 74 is for utilization of protective gasses to effect critical isolation between processing chambers 72 (utilizing hydrogen) and processing chamber 71B (utilizing oxygen) at elevated temperatures. The effectiveness of isolation chamber 74 is readily apparent upon consideration of its length of 5 inches in the safe separation of oxygen and hydrogen both at elevated temperatures of the order of 1,000° to 1,200° C. In these Examples XXIV and XXV, reaction chambers 71B, 71C and 71D are employed to oxidize wafer 64 in corresponding dry-wet and dry oxygen.

The first and third oxidation chambers 71B and 71D in the system shown in FIGS. 39 and 40 are respectively about 7 and 4 inches in length with the first defined between flanged partitions 81B and 81D and a second defined between partitions 81D and 96 for each of the partitions extending to a level of about 0.015 inches above the surfaces of the traveling tier of carriers 50 to provide the desired orifice-sized clearance therewith and thereby restrict the flow of gasses therethrough. In general, dry-oxygen is circulated through the first oxy-chamber 71B via its inlets and outlets 89 and 90 at a feed rate of about 4 liters per minute at a pressure of about 0.003 p.s.i.g. Generally, the feed rate may range from about 1 to 5 liters per minute, and the pressure may range from about 0.001 to about 0.005 p.s.i.g. However, in all cases the pressure $P71B$ in oxy-chamber 71B will be less than the pressure in inlet compartment 74E (of isolation chamber 74) and correlated therewith so that there will be zero flow between them, or a positive flow from inlet compartment 74E into oxygen chamber 71B.

In a similar fashion dry-oxygen is circulated through dry oxy-chamber 71D (about 4 inches in length) via its inlet and outlet tubes 89 and 90, respectively to maintain a flow rate and pressure comparable to that employed in oxy-chamber 75, e.g., about 1 liter per minute and 0.003 p.s.i.g. In general, the length of both dry oxy-chambers 71B and 71D will be determined by the range of oxide thicknesses desired, as correlated directly by the through-put of carriers 50, temperatures employed, and indirectly correlated to the parameters of the primary processes employed in the various stages which determine the range of speed for the through-put of carriers 50.

The wet oxy-chambers 71C in the system shown in FIGS. 39 and 40 are about 32 inches in length with an oxygen/water vapor mixture circulated therethrough via its inlet and outlet tubes 89 and 90. The flow of the oxidation mixture is controlled at a feed rate of about 1 to about 5 liters per minute at a pressure in the range of about 0.001 to about 0.005 p.s.i.g. After wet-oxidation the wafers pass through a three-compartmented isolation chamber 101 for final oxidation in dry oxy-chamber 71D after which the tier of carriers 50 pass through a five-compartmented isolation chamber 75 having the construction previously described above for this three-compartmented configuration. As in the preceding examples, the three-compartmented isolation chamber 101 is subdivided into a series of alternate outlet and inlet compartments in which protective gasses are introduced and withdrawn. For example, for the particular isolation obtained, the three-com-

partmented isolation chamber 101 is subdivided into an outlet compartment 101A, an inlet compartment 101B and a second outlet compartment 101C, each about 1 inch in length. In general, the pressure relationship of the three-compartmented isolation chambers of the preceding examples are also maintained within and between the various compartments of isolation chamber 101 and between the final oxy-chamber 71D and wet oxy-chamber 71C so as to maintain the same flow and pressure relationships indicated above therefor. As will be understood from the discussions above, the pressures $P71D$ (in final oxy-chamber 71D) and the pressure $P71C$ (in processing chamber 71C) will be maintained at a level substantially higher than the pressure levels in their adjacent outlet compartments 101A and 101C, respectively, and coordinated therewith so that there will be a positive pressure flow from the processing chambers into their adjacent outlet compartments of isolation chamber 101. In addition, the pressure $P101B$ in inlet compartment 101B (of isolation chamber 101) will be maintained at a pressure level $P101B$ substantially higher than the pressure levels $P71B$ and $P71C$ (in final oxy-chamber 71D and processing chamber 71C respectively) and thus, conversely, higher than the pressure levels $P101A$ and $P101C$ in inlet compartments 101A and 101C respectively with a positive gas flow flowing from compartment 101B into each of outlet compartments 101A and 101C.

Conversely, the five-compartmented isolation chamber 75 will have comparable structural and flow relationships indicated previously for this type of chamber.

Also, as in the preceding examples concurrently with passage through the isolation chamber 75, the carrier supported wafers also pass out of heating coil 53A which conditions the wafers to suitable processing temperatures for deposition of a metal film on the wafers within processing chamber 71E, e.g., silicon wafers 64 may be cooled in conjunction with inter-cool chamber 100 to a general range of about 250° to about 750° C. and preferably in the range of about 300° to about 550° C.

As the carriers 50 emerge from the isolation chamber 75, they pass through an inter-cool chamber 100 and enter the metal-plating chambers 71E which is within RF heating coil 53B and also defined between flanged partitions 96A and 91 of the post-cool chamber 71F. The metal-plating chamber 71E comprises a section of the processing tube of about 8 inches in length wherein the substrates 64 are subjected to a substantially flowing gaseous environment of hydrogen, argon and a metal halide (molybdenum pentachloride) flowing from its inlet to its outlet, 89-90 respectively, at a feed rate of about 9 liters per minute. Typically, the metal-plating atmosphere may comprise hydrogen and a halide of a metal having a resistivity less than about 100 microhms-cm. at 18° C. As will be understood, various metal-plating atmospheres such as indicated above may also be employed in the metal-plating chamber 71E.

In the preferred embodiments as used in these examples, the metal-plating atmosphere comprises a three-component gaseous mixture wherein the first component is hydrogen, the second is argon and the third component is a halide of a metal having the indicated resistivity less than about 100 microhms-cm. as for example, tungsten pentachloride and specifically molybdenum pentachloride. A typical feed mixture of this metal-plating atmosphere will comprise 6 liters per minute hydrogen and 3 liters per minute argon containing about 6 volume per cent molybdenum pentachloride per 9-liter flow. In the process, as indicated above, the metal-plating atmosphere (e.g., molybdenum pentachloride and hydrogen) may be pre-heated externally in reactor tubes 52 and injected therein via the inlet nozzles 89 (of processing chamber 71E) wherein upon contact with the heated wafers 64, the metal halide is reduced by hydrogen for liberation of the metal (e.g., molybdenum) at the surface of wafers 64 whereat the liberated metal is deposited. After passage of the substrates through the metal-plating chamber 71E, the carrier-supported wafers 64 pass through the post-cool chamber 71F of about 10

inches in length and similar in construction to like chambers described above. Herein the wafers are cooled below critical or reactive temperatures (e.g., to about or below 400°C.).

After cooling, the wafers pass through the isolation chamber 73 similar in construction and function to those previously discussed in greater detail with respect to the five-compartmented chambers described above and in the preceding examples. However, during passage through the isolation chamber 73, the carriers and wafers thereon are allowed to further cool toward ambient atmospheres as they emerge into outlet buffer chamber 77 for final exiting across a transfer table onto a conveyor for removal from the system. As shown, the outlet buffer chamber of about 5 inches in length is provided with a protective atmosphere (e.g., inert gas) with discharge of the gasses effected into ambient atmospheres through the restricted openings defined by end partitions 78 and the services of carriers 50.

EXAMPLE XXVI

Sequential Vapor Etching, Epitaxial Deposition and Thermal Oxidation

This example in conjunction with FIGS. 5, 7, 9-17 and 41 describes a continuous processing system for sequentially vapor etching and depositing of an epitaxial film on semiconductor substrates followed by thermal oxidation thereof.

In the same fashion described in preceding examples, in conjunction with FIG. 41 of this example, a continuous tier of wafers supported on carriers 50 having a rectangular configuration are transported in end-to-end relationship by a feed mechanism generally indicated by the numeral 51 into a quartz processing tube 52 disposed within heating coils 53, 53A and 53B which may be optionally enclosed in a furnace enclosure 55 of the usual construction.

Since water-cooled RF heater coils 53, 53A and 53B are also shown and employed in this example, the carriers 50 are fabricated of suitable susceptor materials such as graphite, carbon, molybdenum and the like. However, it is to be understood that carriers 50 may also be constructed of other suitable materials compatible with the wafers and with process environments. In general, the material of carriers 50 will normally determine the type of heater coils employed in conjunction with reactor tube 52. Thus, in a system employing quartz carriers, the heating coils can conveniently comprise resistance coils, and conversely the use of graphite in the construction of the carriers permits the use of either resistance coils or induction heater coils in the system.

The carriers 50 illustrated in FIG. 6 are employed for processing wafers having two and one-half inch diameter with it being understood that other variations in carriers and wafers aforesdiscussed in conjunction with the preceding examples may also be employed where desired or required. As in the previous embodiments, the carriers 50 were fabricated in a 3.45-inch-square configuration with a thickness of about 0.5 inches and having skids or rails 62 of about 0.015 inches depending from the bottom of the carriers to provide an overall height of 0.515 inches defining a free-flow cross section of 17.7 sq. cm. in the unobstructed portions of the tube.

As in the previous examples, the top surfaces of carriers 50 of this example are also recessed at 63 to a sufficient depth to seat and maintain therein a semiconductor wafer 64, of silicon, germanium, and the like, for multistage processing through the tube 52. In general, the top surfaces of the wafers

will be substantially flush with the top surfaces of carriers 50 while seated therein.

The feed station shown in FIG. 5 may also be employed in this example, and comprises an endless conveyor 65 which carries the carriers between the drive unit which comprises two side-gripping endless belts which contact the carriers on their sides to propel them in end-to-end relationship through processing tube 52. A transfer plate 67 is provided with side-guides 67A for feeding the carriers 50 in end-to-end relationship through the processing tube 52.

Specifically, the processing tube shown in FIG. 41 is configured to sequentially process a pre-conditioned silicon wafer 64 by vapor etching followed by deposition of an epitaxial film on the wafers with subsequent thermal oxidation thereof.

Basically of reactor tube 52 of 104 inches as shown in FIG. 41 is subdivided into an ambient inlet buffer chamber, a five-compartmented isolation chamber 70, a pre-heat chamber 71, a first environmental processing chamber 71A, a three-compartmented isolation chamber 101, a second environmental processing chamber 71B, a second five-compartmented isolation chamber 73, two environmental processing chambers 71C and 71D, a second three-compartmented isolation chamber 103, a processing chamber 71E, and an ambient outlet buffer chamber 77.

The buffer zone or chamber 69, of about 5 inches in length, is defined between partitions 78 and 79 with partition 78 extending toward the bottom of reactor tube 52, a distance providing about 0.25-inch clearance with the top of a tier of carriers 50. Buffer zone 69 forms a preliminary barrier against ambient and is maintained with a non-reactive atmosphere, of about 0.05 p.s.i.g. by introducing therein through a circumferential slot 80A of a closed end nozzle 80 (of about 5 mm. ID) a suitably controlled flow of an inert gas such as nitrogen, helium, argon and the like. Generally, however, for this processing system the pressure in ambient chamber 69 as above, may extend from about 0.001 to about 0.005 p.s.i.g., and preferably from about 0.001 to about 0.003 p.s.i.g. As indicated, nozzle 80 is a closed end construction having the configuration shown and described in reference to FIG. 12.

The moving tier of carriers 50 eventually passes out of ambient buffer chamber 69 into and through the critical five-compartmented isolation chamber 70 having the same structural configuration indicated therefor in the previous examples, and accordingly like component features are indicated by the same reference numerals.

Also as in the preceding examples, the isolation chamber 70 is subdivided into a series of alternate inlet and outlet compartments each of 1 inch in length and into which protective gasses are introduced and withdrawn. With the particular isolation obtained, the isolation chamber 70 is subdivided into an inlet compartment 70A, an outlet compartment 70B, a second inlet compartment 70C, a second outlet compartment 70D, and a third inlet compartment 70E, each about 1 inch in length. In general the pressure relationships of the preceding examples are also maintained within and between various compartments of isolation chamber 70, and between the adjacent ambient inlet chamber 69, and the pre-heat chamber 71 so as to maintain the same flow and pressure relationship indicated above therefor.

As the tier of carriers 50 emerges from the last compartment 70E, of isolation chamber 70, the carriers enter into a non-reactive pre-heat chamber 71 disposed within the heating coils 53 for heat-conditioning the supported wafers 64 to processing temperatures, e.g., in the general range of about 950° to about 1,350° C. for silicon and about 350 to about 900° C. for germanium.

The pre-heat chamber 71 is defined between flanged partitions 81 and 91, and is of about 14 inches in length. Normally, the environment in pre-heat chamber 71 will be selected so as to be compatible with the atmosphere in the succeeding processing chamber 71A, of about 4 inches in length, defined between partitions 91 and 79B. For example, the protective atmosphere in pre-heat chamber 71 may not only comprise any of the indicated inert gasses but may also include hydrogen where this gas is employed as a component in the environment in processing chamber 71A. Thus, since hydrogen is employed as a component in the processing gas within processing chamber 71A, hydrogen may also be employed as a protective atmosphere within pre-heat chamber 71 in view of its compatibility with the processing gas in processing chamber 71A. In general, the protective atmosphere in pre-heat chamber 71 is maintained at a pressure in the general range of about 0.001 to about 0.05 p.s.i.g. and preferably from about 0.002 to about 0.005 p.s.i.g. As will be understood, the pressure P_{71} in pre-heat chamber 71 will be maintained at a level below the pressure P_{70E} in the preceding inlet compartment 70E (of isolation chamber 70) and coordinated therewith so that there will be either a zero flow F_6 between the inlet compartment 70E and pre-heat chamber 71, or a positive flow F_6 from inlet compartment 70E into pre-heat chamber 71.

After the pre-heating stage, the moving tier of carriers 50 emerges from the pre-heat chamber 71 and passes through the reaction chamber 71A in which is maintained a flowing environment of a processing gas flowing therethrough via inlet tubes 89 to outlet tube 90, at a feed rate not greater than about 15 liters per minute and preferably from about 5 to 10 liters per minute.

In general, the pressure of the processing atmosphere employed in chamber 71A may range from about 0.001 to about 0.05 p.s.i.g. and preferably from about 0.001 to about 0.003 p.s.i.g.

The processing chamber 71A comprises a section of the processing tube of about 4 inches in length wherein the substrates or wafers 64 are subjected to an etching atmosphere flowing from its inlet to its outlet, 89 to 90 respectively, at a feed rate of about 4 to about 25 liters per minute. The etching atmosphere employed may comprise a 6 to 12 liter per minute flow of hydrogen containing from about 2 to about 12 percent, by volume, of a hydrogen halide such as hydrogen chloride, hydrogen bromide, hydrogen fluoride, and hydrogen iodide. In this example the etching atmosphere comprised about 94 percent hydrogen and about 6 percent hydrogen chloride.

After passage through the processing chamber 71A, the carriers 50 enter and pass through a three-compartmented isolation chamber 74 (of 3-inch total length) which is, for all practical purposes, identical to the previously described isolation chambers of this type. In view of such similarity no extended

description is necessary. If required, such details may be easily ascertained by reference to the above description of corresponding portions of such three-compartmented isolation chambers. As shown, isolation chamber 101 is positioned within a second induction heater coil 53A (which also extends about processing chambers 71B) to provide proper temperature conditioning of the wafers for a subsequent stage of processing.

The basic function of isolation chamber 101 is for utilization of protective gasses to effect isolation between processing chamber 71A (involving a vapor etching operation) and processing chamber 71B (involving epitaxial deposition).

As the carriers 50 emerge from the isolation chamber 101, they enter and pass through the epitaxial deposition chamber 71B which is about 8 inches in length and is defined between flanged partitions 81B and 79A. Epi-chamber 71B comprises a section of processing tube of about 8 inches in length wherein the substrates or wafers 64 are subjected to a gaseous environment of an epitaxial film-forming atmosphere flowing from its inlet to its outlet, 89 to 90 respectively, at a feed rate of about 4 to about 25 liters per minute. Typically, the epitaxial film-growing atmospheres may comprise any of the compositions indicated therefor above. Also, as will be understood 25 the epitaxial film-growing atmospheres may also include conductivity-type determining impurities. In the preferred embodiment as used in this example, the epitaxial film-forming atmosphere comprises hydrogen containing from about 0.1 to about 1.0 percent, by volume, a silicon tetrachloride in combination with from about 0.01 to about 0.5 percent, by volume, of arsine as a conductivity-type determining impurity. In the specific epitaxial film-forming atmosphere employed in this example the composition of the atmosphere comprised hydrogen containing, by volume, 0.5 percent silicon tetrachloride, and 0.05 percent arsine.

After epitaxial deposition, the tier of carriers (with the wafers 64 supported thereon) emerge from the processing chamber 71B and pass through a second five-compartmented isolation chamber 73 which is also, for all practical purposes, identical to the previously described isolation chambers 70. Since these two isolation chambers 70 and 73 are identical, and since the correlation of pressure in the various inlet compartments 73A, 73C and 73E and outlet compartments 73B and 73D are identical to the pressures in the corresponding inlet and outlet compartments of isolation chambers 70 and 74 no extended description is necessary. Similarly, if required, such details may also be ascertained by reference to the above description of corresponding portions of isolation chambers 50 70 and 74. In general, the pressure P_{71B} in processing chamber 71B will be correlated to the pressure in inlet compartment 73A (of isolation chamber 73) so that there will be zero flow therebetween or positive flow from inlet compartment 73A into processing chamber 71B. However, it will be noted that this third isolation chamber 74 is positioned within a third induction heater 53B (which also extends about chambers 71C, 71D, and 71A (to temperature condition the wafers for a subsequent stage of processing.)

The basic function of isolation chamber 73 is for utilization of protective gas to effect critical isolation between processing chamber 71B (utilizing hydrogen) in processing chamber 71C (utilizing oxygen) at elevated temperatures. The effectiveness of isolation chamber 73 is readily apparent upon consideration of its length of 5 inches in the safe separation of oxygen and hydrogen, both in elevated temperatures of the order of 1,000° to 1,200° C. In this example, reaction chambers 71C, 71D and 71E are employed to oxidize wafers in corresponding dry, wet and dry-oxygen environments.

As will be seen in FIG. 41B, as the wafers emerge from epi-chamber 71B they also pass out of RF coil 53A for cooling in isolation chamber 73 prior to entry within RF coil 53B extending over processing chambers 71C, 71D and 71E and over isolation chamber 103.

75 The first and third oxidation chambers in the systems shown in FIG. 40 are respectively about 7 and 4 inches in length. The

first chamber 71C is defined between flanged partitions 81A and 91A, and the second chamber 71E is defined between partitions 91B and 91C with each of the partitions extending to a level of about 0.015 inches above the surfaces of the traveling tier of carriers 50 to provide the desired orifice clearances therewith and thereby restrict the flow of gasses therethrough. In general, dry oxygen is circulated through the first oxy-chamber 71C via its inlet and outlet 89 and 90 at a feed rate of about 4 liters per minute at a pressure of about 0.003 p.s.i.g. Generally, the feed rate may range from about 1 to 10 liters per minute, and the pressure may range from about 0.001 to about 0.05 p.s.i.g. However, in all cases the pressure

various process parameters of a specific operating system for sequentially vapor etching followed by deposition of an epitaxial silicon film on the silicon wafers and subsequent thermal oxidation thereof, with the wafers supported on carriers 50 traveling through the system at a rate of 1 inch per minute.

For this example the following gas compositions were employed: (a) vapor etch—94 percent hydrogen and 6 percent hydrogen chloride; (b) epitaxial deposition—hydrogen containing, by volume, 0.5 percent silicon tetrachloride and 0.05 percent arsine; (c) first and second dry oxidation—oxygen; and (d) wet oxidation—0.92 mole fraction water in oxygen.

77	Output buffer	O ₂	2	300	

P71C in oxy-chamber 71C will be less than the pressure in inlet compartment 73E (of isolation chamber 73) and correlated therewith so that there will be zero flow between them, or a positive flow from inlet compartment 73E into oxy- 40 chamber 71C.

In similar fashion, dry-oxygen is circulated through oxy-chamber 71E (of about 4 inches in length) via its inlet and outlet tubes 89 and 90, respectively, to maintain a flow at a feed rate and pressure comparable to that employed in oxy-chamber 71C, e.g., about 2 liters per minute and 0.003 p.s.i.g.

In general, the length of both dry oxy-chambers 71C and 71E will be determined by the range of oxide thicknesses desired, as correlated directly to the throughput of carriers 50, the temperatures employed, and indirectly correlated to the 50 parameters of the primary processes employed in preceding stages of the tube which initially determine the rate of the throughput of carriers 50.

The wet oxy-chamber 71D in the system shown in FIG. 41 is about 32 inches in length with an oxygen/water vapor mixture 55 circulated therethrough via its inlet and outlet tubes 89 and 90, respectively. The flow of the wet oxidation mixture is controlled to provide a flow rate of about 1 to about 5 liters per minute of oxygen containing 0.92 mole fraction of water maintained at a pressure in the range of 0.001 to about 0.005 p.s.i.g. Following wet oxidation in chamber 71D the wafers pass through a three-compartment isolation chamber 103 (of 60 3-inch total length) for final oxidation in dry oxy-chamber 71E.

After passage through the final dry oxy-chamber 71E, the carriers 50 (with the wafer 64 supported thereon) enter and pass through an ambient outlet buffer chamber 77 to discharge across the transfer table 98 between conveyor belts 99. As shown, the outlet buffer chamber of about 14 inches in length is provided with a protective atmosphere, (e.g., inert gasses) with discharge of the gasses effected into ambient atmospheres through the restricted openings defined by end partition 78A and the surfaces of carriers 50.

To illustrate the operation of this example as shown in its 75 FIG. 41, the following Table 35 is set forth to illustrate the

EXAMPLES XXVII AND XXVIII

The following examples illustrate additional embodiments of the invention directed to:

- A. a continuous multistage processing system for sequentially vapor etching and depositing consecutive superposed layers of epitaxial, nitride and metal films on semiconductor substrates without exposure of the substrates to ambient intermediate the processing operations, as shown in FIG. 42, and
- B. a continuous multistage processing system for sequentially vapor etching and depositing consecutive superposed layers of epitaxial, silicon oxide and metal films on semiconductor substrates without exposure of the substrates to ambient intermediate processing operations, as shown in FIG. 43.

In view of the similarity in the tube configuration employed in these two examples, only a single tube configuration will be described with the specific process parameters in chamber dimensions set forth below for each example. However, as will be understood, in these systems utilizing a vapor etch operation, the etching atmosphere may comprise hydrogen containing from about 2 to about 12 percent, by volume, of a hydrogen halide, such as hydrogen chloride, hydrogen bromide, hydrogen fluoride and hydrogen iodide. In the preferred embodiment of the etching atmosphere, as used in the specific examples set out below (e.g., Examples XXVII and XXVIII), the halide of the etching atmosphere comprises hydrogen chloride in a composition comprising hydrogen containing about 6 percent hydrogen chloride.

Similarly, the epitaxial film-growing atmospheres may comprise any of the compositions indicated therefore above. Further, as will be understood, the epitaxial film-growing atmosphere may include conductivity type determining impurities. In the preferred embodiments as used in these specific examples, as set out below, the epitaxial film-forming atmosphere may comprise hydrogen containing from about 0.1 to about 1.0 percent, by volume, silicon tetrachloride in combination with from about 0.01 to about 0.5 percent, by volume, of arsine as a conductivity type determining impurity.

In the specific epitaxial film-forming atmosphere employed in these examples, the composition of the atmosphere comprised hydrogen containing, by volume, 0.5 percent silicon tetrachloride, and 0.05 percent arsine.

Also, the nitriding atmospheres may also comprise any of the compositions indicated therefor above. In the preferred embodiment as used in the specific example (e.g., Example XXVII) set out below, the nitriding atmosphere may be comprised of silane and ammonia in conjunction with hydrogen as a carrier therefor. A typical composition of these nitriding atmospheres may comprise hydrogen containing, by volume, from about 0.005 to about 0.05 percent silane and from about 0.05 to about 0.05 percent ammonia. A specific mixture of this nitriding atmosphere, as used in the example set out below, comprised hydrogen, containing, by volume, 0.02 percent silane and 0.2 percent ammonia.

Also for the vapor state oxide deposition, the oxide-forming composition may also comprise any of those previously indicated above therefor. In the preferred embodiments, as used in the specific example (e.g., Example XVIII) set out below, the oxide-forming atmosphere can comprise a three-component mixture wherein the first component is hydrogen, the second component may be either oxygen or carbon dioxide, and the third component may be either an organic silicate, a silicon halide or an alkoxy silane. A typical mixture of this film-forming atmosphere will comprise hydrogen containing, by volume, about 0.92 to about 1.2 percent silicon tetrachloride, and about 0.4 to about 0.6 percent oxygen. For the specific example below the oxide-forming atmosphere comprised hydrogen containing, by volume, about 0.5 percent silicon tetrachloride and about 1.0 percent oxygen.

The tube configurations shown in FIGS. 42 and 43 are employed in these examples as follows:

- A. Example XXVII, in conjunction with FIGS. 5, 7, 9-17 and 42 describes a continuous processing system for sequentially vapor etching and depositing consecutive superposed layers of epitaxial, nitride and metal films on semiconductor substrates, and
- B. Example XXVII, in conjunction with FIGS. 5, 7, 9-17 and 43 describes a continuous processing system for sequentially vapor etching and depositing consecutive superposed layers of epitaxial, oxide and metal films on semiconductor substrates.

In the same fashion described in the preceding examples, in these two Examples XXVII and XXVIII, taken in conjunction with their respective FIGS. 42 and 43, a continuous tier of carriers 50 having a rectangular configuration are transported in end-to-end relationship by a feed mechanism generally indicated by the numeral 51 into and through a quartz processing tube 52 disposed within heating coils 53, 53A, 53B and 53C which may be optionally enclosed in a furnace enclosure 55 of the usual construction.

Since water-cooled RF heater coils, 53, 53A, 53B and 53C are also shown and employed in these examples, the carriers 50 are fabricated of suitable susceptor material such as graphite, carbon, molybdenum and the like. However, it is to be understood that carriers 50 may also be constructed of other suitable materials compatible with the wafers and with process environments. In general, the material of carriers 50 will normally determine the type of heater coils employed in conjunction with reactor tube 52. Thus in a system employing quartz carriers, the heating coils can conveniently comprise resistance coils, and conversely the use of graphite in the construction of the carriers permits the use of either resistance coils or induction heater coils in the system.

The processing tubes shown here are also of rectangular configuration having an internal height of about 33 mm. and an internal width of 89 mm. Each processing tube 52 is subdivided into appropriate chambers, as described below, with the various processing tubes having the following overall lengths:

FIG. 42
FIG. 43

104 inches; and
104 inches

The carriers 50 illustrated in FIG. 6 are employed for processing wafers having two one-half inch diameter with it being understood that other variations in carriers or wafers aforesubdivided in conjunction with the preceding examples may also be employed where desired or required. As in the previous embodiments, the carriers 50 were fabricated in a 76.8 cm. sq. configuration with a thickness of about 0.5 inches and having skids or rails 62 of about 0.015 inches depending from the bottom of the carriers to provide an overall height of 0.515 inches defining a free-flow cross section of 17.7 sq. cm. in the unbaffled portions of the tube.

As in the previous examples, the top surfaces of carriers 50 employed in these two examples are also recessed at 63 to a sufficient depth to seat and maintain therein a semiconductor wafer 64 of silicon, germanium and the like for multistage processing through the tubes 52. In general, the top surfaces of the wafers will be substantially flush with the top surfaces of carriers 50 while seated therein.

20 The feed station shown in FIG. 5 may also be employed in these examples, and comprises an endless conveyor 65 which carries the carriers between the drive unit 66 which comprises two side-gripping endless belts which contact the carriers on their sides to propel them in end-to-end relationship through

25 the processing tubes 52.

Specifically the processing tube 52, shown in FIG. 42, is configured to sequentially process a pre-conditioned silicon wafer 64 by vapor etching followed by sequential depositions of epitaxial, oxide and metal films on the substrate.

30 In turn, the processing tube 52 shown in FIG. 43 is configured to sequentially process a pre-conditioned silicon wafer 64 by vapor etching followed by sequential vapor state depositions of epitaxial, nitride, and metal films on the substrates.

Basically, the reactor tubes of FIGS. 42 and 43 are subdivided into an ambient inlet buffer chamber or zone 69, a five-compartmented isolation chamber 70, a pre-heat chamber 71, a first environmental processing chamber 71A, a three-compartmented isolation chamber 101, a second environmental processing chamber 71B, a second three-compartmented isolation chamber 103, an inter-cool chamber 100, a third environmental processing chamber 71C, a third three-compartmented isolation chamber 104, an inter-cool chamber 102, a fourth environmental processing chamber 71D, a second five-compartmented isolation chamber 73, and an ambient outlet buffer chamber 77.

The buffer zone or chamber 69 of about 5 inches in length, is defined between partitions 78 and 79, with partitions 78 extending toward the bottom of the reactor tube 52, a distance providing about 0.25 inch clearance with the top of a tier of carriers 50. Buffer zone 69 forms a preliminary barrier against ambient atmosphere, and is maintained with a non-reactive protective atmosphere of about 0.001 p.s.i.g. by introducing therein through a circumferential slot 80A of a closed end nozzle 80 (of about 5 mm. ID), a suitably controlled flow of an inert gas such as nitrogen, helium, argon forming gas and the like. Generally however, for this processing system the pressure in ambient chamber 69, as above, may extend from about 0.001 to about 0.005 p.s.i.g. and preferably from about 0.001 to about 0.003 p.s.i.g. As indicated, nozzle 80 is a closed end construction having a configuration shown and described in reference to FIG. 12.

65 The moving tier of carriers 50 eventually passes out of ambient buffer chamber 69 into and through the critical five-compartmented isolation chamber 70 having the same structural configuration indicated therefor in the previous examples, and accordingly, like component features are indicated by the same reference numerals.

Also as in the preceding examples, the isolation chamber 70 is subdivided into a series of alternate inlet and outlet compartments into which protective gasses are introduced and withdrawn. For the particular isolation obtained, the isolation chamber is subdivided into an inlet compartment 70A, an outlet compartment 70B, a second inlet compartment 70C, a second outlet compartment 70D and a third inlet compartment

ment 70E, each about 1 inch in length. In general, the pressure relationship in the preceding examples are also maintained within and between various compartments of isolation chamber 70, and between the adjacent ambient inlet chamber 69, and the preheat chamber 71, so as to maintain the same flow and pressure relationships indicated above therefor.

As the tier of carriers 50 emerges from the last compartment 70E of isolation chamber 70, the carriers enter into a non-reactive preheat chamber 71 disposed within heating coils 53 for heating the supported wafer 64 to processing temperatures, e.g., in the general range of about 1,000° to about 1,300° C. for silicon, and from about 350° to about 900° C. for germanium. The preheat chamber 71 is defined between flanged partitions 81 and 91, with the specific length of the preheat chamber set out below for each example.

Normally, the environment in preheat chamber 71 will be selected so as to be compatible with the atmosphere in the succeeding processing chamber which is 71A defined between partitions 91 and 79B. For example, the protective atmospheres in preheat chamber 71 may not only comprise any of the indicated inert gasses but also may include hydrogen when this gas is employed as a component in the environment in processing chamber 71A. Thus since each of Examples XXVII and XXVIII employs hydrogen as a component in the processing gas within processing chamber 71A, hydrogen may also be employed as a protective atmosphere within preheat chamber 71 in view of its compatibility with the processing gasses. In operation, the protective gasses within preheat chamber 71A are maintained in flow via the chamber's inlets and outlets 89 and 90. In general, the protective atmosphere employed in preheat chamber 71 will be maintained in a general range of about 0.001 to about 0.05 p.s.i.g. and preferably from about 0.002 to 0.005 p.s.i.g. It is to be understood that the pressure P_{71} in preheat chamber 71 will be maintained at a level below the pressure P_{70E} in the preceding inlet compartment 70E (of isolation chamber 70) and coordinated therewith so that there will be either a zero flow F_6 between the inlet compartments 70E and preheat chamber 71, or positive flow F_6 from inlet compartments 70E into preheat chamber 71.

After the pre-heating stage, the moving tier of carriers 50 emerges from the preheat chamber 71 and passes through the reaction chamber 71 in which is maintained a substantially quiescent environment of processing gas flowing therethrough via inlet tube 89 and outlet tube 90, at a feed rate not greater than about 15 liters per minute and preferably from about 5 to about 10 liters per minute. Again, the specific length of processing chamber 71A for each of the examples shown in the corresponding FIGS. 42 and 43 are noted in the table below. In general, the pressure in processing chambers 71A may range from about 0.001 to about 0.005 p.s.i.g.

Specifically in each of these Examples XXVII and XXVIII, the processing chamber 71A is provided, as shown in FIGS. 42 and 43, with a vapor etching atmosphere such as described above.

After passage through the processing chamber 71A, the carriers 50 enter and pass through a three-compartmented isolation chamber 74 which is for all practical purposes, identical to the previously described like isolation chambers in the preceding examples. If required, details of this isolation chamber may be easily ascertained by the reference to the description in preceding examples of corresponding portions of isolation chamber 101. However, it will be noted that this isolation chamber 101 is positioned within a second induction heater coil 53A (which also extends about chamber 71B) to temperature-condition the wafers for a subsequent stage of processing. It is noted that although a three-compartmented isolation chamber 101 is shown it is to be understood that a five-compartmented chamber as described above may also be employed for separating the processing chamber 71A and 71B.

Also, as in the preceding examples, the carrier supported wafers on passage through isolation chamber 101 concur-

rently pass within heating coil 53A which conditions the wafers to processing temperatures for epitaxial deposition, e.g., the silicon wafers 64 are maintained a general range of about 950° to about 1,350° C. and preferably in the range of about 1,050° to about 1,250° C.; and conversely, the temperature of germanium wafers may be maintained in the general range of about 600° to about 920° C. and preferably from about 890° to about 910° C.

As the carriers 50 emerge from isolation chamber 101 they enter and pass through the reaction chamber 71B which is defined between flanged partitions 81B and 79C. Reaction chamber 71B comprises a section of the processing tube of about 8 inches in length wherein the substrates or wafers 64 are subjected to a substantial quiescent flowing epitaxial film-forming atmosphere flowing from its inlet to its outlet, 89 to 90, respectively, at a feed rate of about 4 to about 25 liters per minute. Typically, the epitaxial film-forming atmosphere may comprise any of the compositions indicated above therefor.

After passage through processing chamber 71B, the carriers 50 (with the wafers 64 supported thereon) enter and pass through another three-compartmented isolation chamber 103 which is, for all practical purposes, again identical to the previously described three-compartmented isolation chambers of the preceding examples. However, it will be noted that on entry of the wafers into this isolation chamber, the wafers pass out of the RF heater coil 53A which permits the wafers to cool (in conjunction with an inter-cool chamber) to temperatures employed in a subsequent stage of processing.

As the carriers 50 emerge from inter-cool chamber, they pass through an RF heater coil 53B as they enter the processing chamber 71C wherein is maintained a substantially quiescent environment of a processing gas flowing therethrough via inlet tube 89 and through outlet tube 90, at a feed rate not greater than about 15 liters per minute and preferably from about 6 to about 14 liters per minute. Again, the specific length of processing chamber 71C, for each of the examples shown in the corresponding FIGS. 42 and 43, is noted in the table below. In general, regardless the processing atmosphere employed, the pressure in processing chamber 71C may range from 0.001 to about 0.05 p.s.i.g. and preferably from about 0.002 to about 0.005 p.s.i.g.

Specifically for Example XXVII, the processing chamber 71C will be provided with a nitrided silicon film-forming atmosphere, whereas for Example XXVIII, the processing chamber 71C will be provided, as shown in FIG. 43, with a silicon oxide film-forming atmosphere.

After passage through the processing chamber 71C, the carriers 50 again enter and pass through another three-compartmented isolation chamber 104 which is, for all practical purposes, identical to the previously described three-compartmented isolation chambers. Also, as in the preceding examples, the carrier-supported wafers on passage through the isolation chamber 104 concurrently pass out of heating coil 53B which permits the wafers to cool toward processing temperatures which on additional passage through a second inter-cool chamber 102 conditions the wafers for deposition of a metal film on the wafers, e.g., silicon wafer 64 may be heated to a general range of about 250° to about 750° C., and preferably in the range of about 300° to about 550° C.

As the carriers 50 emerge from the inter-cool chamber 102 they pass through another RF heater coil 53C as they enter the metal-plating chamber 71D which is defined between flanged partitions 79A and 81A. The metal-plating chamber 71D comprises a section of the processing tube of about 8 inches in length wherein the substrates or wafers 64 are subjected to a substantially quiescent flowing gaseous environment of hydrogen and a metal halide (e.g., molybdenum pentachloride) flowing from its inlet to its outlet 89 to 90 respectively, at a feed rate of about 1 to about 15 liters per minute.

Typically, the metal-plating atmosphere may comprise hydrogen and a halide of a metal having a resistivity less than about 100 microhms-cm. at 18° C. As will be understood, various metal-plating atmospheres such as indicated above may

also be employed in the metal-plating chamber 71D. For the specific examples set out below the metal depositing atmosphere comprised 6 liters per minute hydrogen in combination with 3 liters per minute argon containing, by volume, 6 percent molybdenum pentachloride per 9-liter volume.

After passage of the substrates through the metal-plating chamber 71D, the carrier-supported wafers pass through the isolation chamber 73 again similar in construction compared to those previously discussed in greater detail with respect to like five-compartmented chambers described above and in the preceding examples. However, during passage through the isolation chamber 73, the carriers and wafers thereon are

To illustrate the operation of the system of Example XXVII as shown in its FIG. 42, the following Table 37 is set forth to illustrate the various process parameters of a specific operating system for vapor etching followed by sequential deposition of 10 consecutive layers of epitaxial, nitride and metal films on silicon wafers supported on carriers 50 traveling through the system at a rate of 1 inch per minute.

To illustrate the operation of the system of Example XXVII as shown in its FIG. 43, the following Table 38 is set forth to illustrate the various parameters of a specific operating system for vapor etching followed by sequential deposition of 45 consecutive layers of epitaxial, oxide and metal film on silicon wafers or carriers 50 traveling through the system at a rate of 1 inch per minute.

EXAMPLE XXIX

50 Continuous Process for Four-Stage Processing of Semiconductor Substrates, e.g., Vapor Etching, Epitaxial Deposition, Thermal Oxidation and Metal Film Deposition

This example, in conjunction with FIGS. 5, 7, 9-17 and 44 describes a continuous multistage processing system for sequentially vapor etching semiconductor substrates followed by deposition of epitaxial film, thermal oxidation and deposition of metal film on semiconductor substrates.

In the same fashion described in the preceding examples, a continuous tier of wafer carriers 50 having a rectangular configuration are transported in end-to-end relationship by feed mechanism generally indicated by the numeral 51 into a quartz processing tube 52 disposed within heating coils 53, 53A, 53B and 53C which may be optionally enclosed in a furnace enclosure 55.

Since water-cooled RF heater coils 53 to 53C are also shown and employed in this example, the carriers 50 are fabricated of suitable susceptor materials such as graphite, carbon, molybdenum and the like. However, it will be understood that carriers 50 may also be constructed of other suitable materials compatible with the wafers and with process environments. In general, the material of carriers 50 will normally determine the type of heater coils employed in conjunction with reactor tube 52. Thus in a system employing quartz carriers, the heating coils can conveniently comprise resistance coils, and conversely the use of graphite in the con-

struction of the carriers permits the use of either resistance coils or induction heater coils in this system.

The processing tube 52 shown here (FIG. 44) is also of rectangular configuration having an internal height of about 33 mm. and an internal width of 89 mm. with an overall length of about 130 inches subdivided into appropriate chambers described below.

The carriers 50 illustrated in FIG. 6 are employed for processing the wafers having two one-half inch diameter with it being understood that other variations in carriers and wafers aforescribed in conjunction with the preceding examples may also be employed where desired or required. As in the previous embodiments, the carriers 50 were fabricated in a 76.8 cm. square configuration, with a thickness of about 0.5 inches and having skids or rails 62 of about 0.015 inches depending from the bottom of the carriers to provide an overall height of 0.515 inches which defines a free-flow cross section of 17.7 sq. cm. in the unbaffled portions of the tube.

As in the previous examples, the top surfaces of carriers 50 of this Example XXIX are also recessed at 63 to a sufficient depth to seat and maintain therein a semiconductor wafer 64 of silicon and the like for multistage processing to the reactor tube 52. In general, the top surfaces of the wafers will be substantially flush with the top surfaces of the carriers while seated therein.

The feed station shown in FIG. 5 may also be employed in this example and comprises an endless conveyor 65 which carries the carriers between the drive unit 66 which comprises two side-gripping endless belts which contact the carriers on their sides to propel them in end-to-end relationship through processing tube 52. A transfer plate 67 is provided with side-guides 67A for feeding the carriers 50 in end-to-end relationship through the processing tube 52.

The reactor tube of this example as shown in FIG. 44 is configured to sequentially process a preconditioned silicon wafer 64 by vapor etching thereof followed by deposition of an epitaxial film, with subsequent thermal oxidation thereof and deposition of a metal film where the metal has a resistivity less than about 100 microhms-cm. at 18°C. Basically, the reactor tube of FIG. 44 is subdivided into an ambient inlet buffer chamber 69, a first five-compartmented isolation chamber 70, a preheat chamber 71, a vapor etching chamber 71A, a three-compartmented isolation chamber 101, an epitaxial deposition chamber 71B, a five-compartmented isolation chamber 75, a dry-oxidizing chamber 71C, a wet-oxidizing chamber 71D, a three-compartmented isolation chamber 103, a second dry-oxidizing chamber 71E, a five-compartmented isolation chamber 76, an intermediate-cool chambers 100, a metal

deposition chamber 71F, a post-cool chamber 102, a five-compartmented isolation chamber 73, and an ambient outlet buffer chamber 77.

30 The inlet buffer chamber 69 is about 5 inches in length and is defined between partitions 78 and 79 with partition 78 extending toward the bottom of reactor tube 52 a distance providing about 0.25-inch clearance with the top of a tier of carriers 50. Inlet buffer chamber 69 also forms a preliminary barrier with ambient atmospheres and is maintained with a non-reactive gaseous environment of about 0.001 p.s.i.g. by introducing therein, through a circumferential slot 80A of a closed end nozzle 80 (of about 5 mm. ID), a suitably controlled flow of inert gasses such as nitrogen, helium, argon, 35 forming gas and the like. Generally however, for the instant processing system, the gas selected is argon which could be maintained at a pressure which may extend from about 0.0001 to about 0.005 p.s.i.g. and preferably about 0.001 p.s.i.g. The 40 indicator on nozzle 80 is a closed end structure having a configuration shown and described in reference to FIG. 12.

45 The tier of carriers 50 traveling at a rate of 1 inch per minute passes out of ambient inlet buffer chamber 69 into and through a five-compartmented isolation chamber 70 having the same structural configuration indicated therefor in the previous examples and accordingly, like component features are indicated by the same reference numerals. It is noted that 50 each of the five-compartmented isolation chambers 70, 75, 76 and 73 have the same pressure relationship maintained within the compartments of these isolation chambers and between adjacent processing or control chambers, (e.g., ambient buffer chambers and preheat chamber). As in the preceding examples, each of these five-compartmented isolation chambers are 55 subdivided into a series of alternate inlet and outlet 1-inch compartments into which protective gasses are introduced and withdrawn. For example, for the particular isolation obtained with the isolation chambers 70, this isolation chamber is subdivided into an inlet compartment 70A, an outlet compartment 70B, an inlet compartment 70C, an outlet compartment 70D, and a third inlet compartment 70E, each about 1 inch in length. In general, the pressure relationships of the preceding examples are also maintained within and between the various compartments of the five-compartmented isolation chambers, and between the indicated processing and control chambers.

70 As the tier of carriers 50 emerges from the last compartment 70E of isolation chamber 70, the carriers enter into a non-reactive preheat chamber 71 disposed within the heating coils 53 for heating the supported wafers 64 to processing

temperatures, e.g., in the general range of about 1,000° to about 1,300° C. for silicon and about 350° to about 900° C. for germanium. The preheat chamber 71 is defined between flanged partitions 81 and 91, of about 14 inches in length; and normally a substantially quiescent environment is maintained in preheat chamber 71 having a slight laminar flow between its inlet and outlet tubes 89 and 90 respectively, which provides a Reynold's number not exceeding 3,000.

In general, the environment in preheat chamber 71 will be selected so as to be compatible with the atmosphere in the succeeding processing chamber 71A defined between flanged partitions 91 and 79B. For example, the protective atmospheres in preheat chamber 71 may not only comprise any of the indicated inert gasses but also may include hydrogen where this gas is employed as a component in the environment in processing chamber 71A. Thus since in this example hydrogen is employed as a component in the processing gas within processing chamber 71A, hydrogen may also be employed as a protective atmosphere within the preheat chamber 71 in view of its compatibility with the processing gasses. In general, the protective atmosphere employed in preheat chamber 71 will be maintained in the general range of about 0.001 to about 0.05 p.s.i.g. and preferably from about 0.002 to about 0.005 p.s.i.g. It is to be understood that the pressure P_{71} in preheat chamber 71 will be maintained at a level below the pressure P_{70E} in the preceding inlet compartment 70E (of isolation chamber 70) and coordinated therewith so that there will be either a zero flow F_6 between the inlet compartment 70E and preheat chamber 71, or a positive flow F_6 from inlet compartment 70E into preheat chamber 71.

After the preheating stage, the moving tier of carriers 50 emerges from preheat chamber 71 and passes through the reaction chamber 71A (of about 4 inches in length) in which is maintained a substantially quiescent environment of a processing gas flowing therethrough via its inlet and outlet tubes 89 and 90, respectively, at a feed rate not greater than about 15 liters per minute and preferably from about 5 to 10 liters per minute. As in the previous embodiments, the vapor etching atmosphere in processing chamber 71A comprises hydrogen containing from about 2 to about 12 percent, by volume, of a hydrogen halide such as hydrogen chloride, hydrogen bromide, hydrogen fluoride and hydrogen iodide. In the preferred embodiment of the etching atmosphere used in this example, the halide of the etching atmosphere comprised hydrogen containing, by volume about 6 percent hydrogen chloride.

After passage through the processing chamber 71A, the carriers 50 enter and pass through a three-compartmented isolation chamber 101 which, as indicated above, is for all practical purposes identical to like isolation chambers of the preceding examples.

Also, as in the preceding example, the carrier-supported wafers on passage through isolation chamber 101 concurrently pass within heating coil 53A which maintains the wafers at proper processing temperatures for epitaxial film depositions on the wafers, e.g., silicon wafer 64 may be heated to a general range of about 950 to about 1,300° C.

Thus as the carriers 50 emerge from isolation chamber 101, they enter and pass through the epichamber 71B which is about 8 inches in length and is defined between flanged partitions 81B and 79C. In the epichamber, the substrates or wafers 64 are subjected to a substantially quiescent flowing gaseous environment of an epitaxial film-forming atmosphere having any of the compositions indicated therefor above. In accordance with this invention, the epifilm-forming atmosphere flows in epichamber 71B, flows from the chambers inlet and outlet tubes 89 and 90 respectively at a feed rate of about 4 to about 25 liters per minute.

As indicated, the epitaxial film-forming atmospheres may comprise any of the compositions indicated therefor. Further, as will be understood, the epitaxial film-growing atmosphere may include conductivity-type determining impurities. In preferred embodiments as used in the specific example, the

epitaxial film-forming atmosphere may comprise hydrogen containing from about 0.1 to about 1.0 percent, by volume, silicon tetrachloride in combination with from about 0.01 to about 0.5 percent, by volume, of arsine as a conductivity-type determining impurity. In the specific epitaxial film-forming atmosphere employed, the composition of the atmosphere comprised hydrogen containing, by volume, 0.5 percent silicon tetrachloride and 0.05 percent arsine.

After passage of the carrier-supported substrates through the epichamber 71B, they enter and pass through a five-compartmented isolation chamber 75 which, as indicated above, is for all practical purposes structurally identical to the preceding like isolation chambers, e.g., isolation chamber 70. In general, the pressure P_{71B} in epichamber 71B will be correlated to the pressure in inlet compartment 75A (of isolation chamber 75) so that there will be zero flow therebetween or a positive flow from inlet compartment 75A into epichamber 71B.

Conversely, the pressure P_{71D} (in dry oxy-chamber 71C) will be correlated to the pressure P_{70E} in inlet compartment 75E (of isolation chamber 75) so that there will be zero flow therebetween or a positive flow from inlet compartment 75E into dry oxy-chamber 71C. Also, it will be noted that isolation chamber 75 is positioned within a third induction heater coil 53B (which also extends about chamber 71C, 71D and 71E) to temperature condition the wafers for a subsequent stage of processing.

The basic function of isolation chamber 75 is for utilization of protective gasses to effect critical isolation between processing chamber 71B (utilizing hydrogen) and processing chamber 71C (utilizing oxygen) at elevated temperatures. The effectiveness of isolation chamber 75 (and like five-compartmented isolation chambers) is really apparent upon consideration of its length to 5 inches in a safe separation of oxygen and hydrogen, both at elevated temperatures of the order of 1,000° to 1,200° C.

In this example, reaction chambers 71C, 71D and 71E are employed to oxidize wafer 64 in corresponding dry, wet and dry oxygen environments.

The first and third oxidation chambers in the system shown in FIG. 44 of this example are about 7 and 4 inches, respectively, in length with the first defined between flanged partitions 81B and 91A, and a second defined between flanged partitions 91B and 79D where each of the partitions extends to a level of about 0.15 inches above the surfaces of the traveling tier of carriers 50 to provide the desired orifice-size clearances therewith and thereby restrict flow of gasses therethrough. In general, dry oxygen is circulated through the first oxy-chamber 71C via its inlet and outlet tubes 89 and 90, respectively, to provide a flow rate of about 4 liters per minute at a pressure of about 0.003 p.s.i.g. Generally, the flow rate will be maintained to range from about 1 to 5 liters per minute with the pressure ranging from about 0.001 to about 0.05 p.s.i.g. However, in all cases the pressure P_{71C} in dry oxy-chamber 71C will be less than the pressure in inlet compartment 75E (of isolation chamber 75), and correlated therewith as indicated above, so that there will be zero flow between them or a positive flow from inlet compartment 75E into dry oxy-chamber 71C. Conversely, in all cases the pressure P_{71E} (in dry oxy-chamber 71E) will be less than the pressure in inlet compartment 76A (of isolation chamber 76) so that there likewise will be zero flow between them or a positive flow from inlet compartment 76A into the second dry oxy-chambers 71E.

In similar fashion, dry oxygen is circulated through the second dry oxy-chamber 71E (of about 4 inches in length) via its inlet and outlet tubes 89 and 90, respectively, to maintain a pressure comparable to that employed in the first dry oxy-chamber 71C, e.g., about 0.003 p.s.i.g. and a feed rate of 1 liter per minute.

The wet oxy-chamber 71D of the system as shown in FIG. 43, is about 32 inches in length with an oxygen/water vapor mixture (e.g., oxygen containing 0.92 mole fraction water), circulated therethrough via its inlet and outlet tubes 89 and

90, respectively. The flow of the oxidation mixture is controlled to provide a flow at a feed rate of about 0.5 to about 5 liters per minute with the environment maintained at a pressure in the range of about 0.002 to about 0.004 p.s.i.g.

In operation, as the tier of carriers 50 traveling at the indicated rate of 1 inch per minute emerges from the isolation chamber 74 and passes through dry oxy-chamber 71B, the surface of wafer 64 is converted by thermal oxidation into a relatively dense adherent oxide film ranging from 250 to about 600 angstroms in thickness prior to entry in the following wet oxy-chamber 71B. On passage through the wet oxy-chamber 71B the wafers are further oxidized by an additional thickness of 3,500 to about 4,500 angstroms of relatively less dense oxide. From wet oxy chamber 71D, the carrier supported wafers pass a three-compartmented isolation chamber 103 and through the dry oxy chamber 71E for a final thermal oxidation wherein the wafers 64 are further thermally oxidized to form an additional film thickness of about 50 to about 150 angstroms.

Upon emerging from the final oxidation and dry oxy-chamber 71E, the carriers enter and pass through another five-compartmented isolation chamber 76 having the same structural configuration indicated for like five-compartmented isolation chambers described and indicated above.

Isolation chamber 74 also a function of this example, as a transition feed zone between a final oxidation chamber 71E and the metal-plating chamber 71F to maintain the integrity of the respective processing atmospheres therein. Also, as in the preceding examples, the carrier supported wafers on passage through isolation chamber 76 and an intermediate-cool chamber 100 of about 8 inches which cools the wafers to processing temperatures for deposition of a metal film on the wafers, e.g., silicon wafer may be heated to a general range of about 250° to about 750° C.

As in the preceding five-compartmented isolation chambers, inlet compartments 76A, 76C and 76E of isolation chamber 76 are provided with protective atmospheres which may comprise any of the inert gasses such as nitrogen, argon, helium, and the like. In general, the pressure relationship of the preceding five-compartmented isolation chambers will be maintained within the various compartments of isolation chamber 76 and between the adjacent second dry oxy-chamber 71E (as indicated above) and between the metal-plating chamber 71F so as to maintain the same flow relationships indicated above. In addition, the pressure P_{71F} in plating chamber 71F will be correlated to the pressure in inlet compartment 76E so that there will be zero flow therebetween or positive flow from inlet compartment 76E into the plating chamber 71F.

As the carriers 50 emerge from the intermediate-cool

chamber 100 they enter and pass through the metal-plating chamber 71F which is defined between flanged partitions 81D and 79A. The metal-plating chamber comprises a section of the processing tube of about 8 inches in length wherein the substrates or wafers 64 are subjected to a substantially quiescent flowing gaseous environment of hydrogen and a metal halide (e.g., molybdenum pentachloride) flowing from its inlet to its outlet tubes, 89 and 90 respectively, at a feed rate of about 1 to about 15 liters per minute. Typically, the metal-plating atmosphere may comprise hydrogen and a halide of a metal having a resistivity less than about 100 microhms-cm. at 18° C. As will be understood, various metal-plating atmospheres such as indicated above may also be employed in a metal-plating chamber 71F.

In the preferred embodiment, as used in this example, the metal-plating atmosphere comprises a two-component gaseous mixture wherein the first component is hydrogen and the second component is a halide of a metal having a resistivity less than about 100 microhms-cm., as for example, tungsten pentachloride, and specifically molybdenum pentachloride. In this example the mixture of this metal-plating atmosphere comprised 6 liters per minute hydrogen in combination with a 3 liter per minute flow of argon, and containing, by volume, about 6 percent molybdenum pentachloride per 9-liter flow.

In the process, the metal-plating atmosphere (e.g., molybdenum pentachloride and hydrogen) may be preheated externally of reactor tube 52 and injected therein via the inlet nozzle 89 (of processing chamber 71F) wherein upon contact with the heated wafers 64, the metal halide is reduced by hydrogen for liberation of the metal (e.g., molybdenum) at the surface of the wafers 64 whereat the liberated metal is deposited. After passage of the substrates through the metal-plating chamber 71F, the carrier-supported wafers 64 enter

into and pass through a post-cool chamber 102 of about 10 inches and into the five-compartmented isolation chamber 73 similar in construction and function to those previously discussed in greater detail with respect to like five-compartmented chambers described above and in the preceding examples. However, during passage through the post-cool chamber 102 and the isolation chamber 73, the carriers and wafers thereon are allowed to cool toward ambient atmospheres as they emerge into outlet buffer chamber 77 for final exiting across the transfer table onto a conveyor for removal from the system.

To illustrate the operation of the system of this example, as shown in FIG. 44, the following Table 39 is set forth to illustrate the environment and results of a specific operating system for processing surface pre-conditioned silicon wafers supported on carriers traveling through the system at a rate of 1 inch per minute.

While the invention has been particularly shown and described with reference to particular embodiments thereof, it will be understood by those skilled in the art that the foregoing and other changes in form and details may be made therein without departing from the spirit and scope of the invention.

What is claimed is:

1. In a system for continuous processing of a work throughput transported in a substantially continuous tier therethrough between two isolated atmospheres: a transition zone for interconnecting said two isolated atmospheres having a substantially constant composition comprising
  - a series of alternate inlet and outlet compartments having openings for
    - a non-contact passage of said workpieces therethrough,
    - b. having a cross section substantially complementary to the cross section of said workpieces to define a restricted orifice-size clearance therebetween; and
    - c. said series comprising a minimum of three said compartments;
  - b. inlet means adapted for providing a non-reactive gas in said inlet compartments at a pressure at least as high as the pressures of said atmospheres and having progressively increased pressures from opposite ends of said transition zone toward the interior thereof;
  - c. outlet means adapted for exhausting gases from said outlet compartments; and
  - d. means for transporting said workpieces in said tier from one of said atmospheres through said compartments to the other of said atmospheres.
2. The system of claim 1 wherein the openings between each of adjacent compartments is progressively increased from the opposite end of said transition zone toward the interior thereof while maintaining orifice-size clearance with said workpieces.
3. The system of claim 1 wherein the openings to the ones of said compartments at opposite ends of said transition zone adjacent corresponding ones of said atmospheres comprise an extended passageway defining said opening having said complementary cross section.
4. The system of claim 3 wherein the openings between each of adjacent compartments is progressively increased from opposite ends of said transition zone toward the interior thereof while maintaining orifice-size clearance with said workpieces.
5. The system of claim 1 wherein said transition zone comprises three of said compartments defining two of said outlet compartments and one of said inlet compartments with said outlet compartments disposed adjacent corresponding ones of said atmospheres and with the remaining third compartment
  - A. defining a said inlet compartment, disposed intermediate said outlet compartments; and
  - B. provided with said non-reactive gas therein at a pressure substantially greater than the pressures of said atmospheres, with said pressures in said outlet compartments being substantially lower than the pressures of said atmosphere and the pressure in said third compartment.
6. The system of claim 5 including
  - A. means to provide the pressures of said atmospheres at a level which do not exceed about 0.1 p.s.i.g.; and
  - B. wherein said inlet means provides the pressure in said inlet compartment in the range of about 0.004 p.s.i.g. to
7. The system of claim 1 where said transition zone comprises five compartments defining two of said outlet compartments and three of said inlet compartments with two of said inlet compartments disposed at opposite ends of said transition zone adjacent corresponding ones of said atmospheres, with
  - A. said inlet means adapted to provide the pressure in said two inlet compartments at least equal to the pressures of adjacent ones of said atmospheres;
  - B. the inlet means of the third of said inlet compartments being adapted to maintain the pressure therein at a level substantially greater than the pressures in said two inlet compartments; and
  - C. the said outlet means adapted to maintain the pressure in said outlet compartments substantially lower than the pressures in adjacent ones of said inlet compartments.
8. The system of claim 7 including
  - A. means adapted to maintain the pressures of said atmospheres at a level which does not exceed about 0.1 p.s.i.g.;
  - B. means adapted to provide the pressure in said two inlet compartments in the range of about 0.001 p.s.i.g. to about 0.5 p.s.i.g.;
  - C. means adapted to provide the pressure in said third inlet compartment in the range of about 0.002 p.s.i.g. to about 0.5 p.s.i.g.;
  - D. means to maintain the pressure in said outlet compartments lower than the pressures of said atmospheres and the pressures in adjacent ones of said inlet compartments.
9. In a system for continuous processing of work throughput transported in a substantially continuous tier therethrough between two atmospheres,
  - A. a transition zone interconnecting two atmospheres and comprising an alternate series of inlet and outlet compartments for a non-reactive gas; with said series comprising a minimum of three said compartments;
  - B. means adapted for providing a non-reactive gas in said inlet compartments at a positive pressure at least as high as said pressures of said atmospheres;
  - C. gas exhaust means for withdrawing gases from said outlet compartments to maintain pressures therein below the said pressures in said inlet compartments and of said atmospheres with said positive pressures being progressively increased from the opposite ends of said transition zone toward the interior thereof; and
  - D. means for non-contact transport of said workpiece in said tier from one of said atmospheres through said compartments to the other of said atmospheres.
10. In a processing system for continuous processing of workpieces transported in a substantial tier therethrough between two isolated distinct atmospheres at a pressure at least as high as ambient pressures and having a substantially constant concentration, an isolation chamber interconnected with said atmospheres and comprising
  - A. spaced end walls defining said chamber and having openings for non-contact transport of said tier of said workpieces therethrough from one of said atmospheres to the other of said atmospheres with said openings having a cross section complementary to the cross section of said tier to form a restricted orifice-size clearance

- therebetween;
- B. baffle means in said isolation chamber extending transversely thereof and subdividing said chamber into at least three alternate inlet and outlet zones and defining a series of non-contact openings aligned with the openings defined in said end walls;
- C. means for providing a non-reactive atmosphere in said inlet zones at a positive pressure; and
- D. means for withdrawing gases from said outlet zones with
- a. the pressure in said outlet zone adjacent a said end wall maintained lower than the pressure of an adjacent one of said atmospheres, and
  - b. with the pressure in a said inlet zone adjacent a said inlet wall maintained at a level at least equal to the pressure of an adjacent atmosphere, and
  - c. with the positive pressures progressively increasing from adjacent said opposite end walls toward the interior of said isolation chamber.
11. A reactor for continuous processing of workpieces transported in a substantially continuous tier therethrough comprising an open ended tube with the opposite ends thereof exposed to ambient atmosphere, partitions within said tube extending transversely thereof and defining at least three consecutive chambers comprising
- A. a first reactive chamber;
  - B. an intermediate isolation chamber, and
  - C. a second reactive chamber with said partitions provided with passageways having a cross section substantially complementary to the cross section of said tier to define a restricted orifice-type non-contact clearance therebetween providing resistance to flow of gases therethrough, and interconnecting said chambers;
  - D. a first gas flow means for providing a flow of a reactive gas
    - a. at a first positive pressure level at least as high as ambient pressures, and
    - b. at a substantially constant concentration in a first of said reaction chambers; - E. second gas flow means for providing a flow of a second reactive gas
    - a. at a substantially constant concentration, and
    - b. at a second positive pressure at least as high as ambient pressure in a second of said reactive chambers; - F. baffle means in said isolation chamber defining therein at least three compartments comprising alternate inlet and outlet compartments for a non-reactive gas;
  - G. third gas flow means for injecting and withdrawing a non-reactive gas in, respectively, said inlet and outlet compartments to provide
    - a. the gas pressure in a said outlet compartment adjacent a said atmosphere lower than the gas pressure in said inlet compartments and at least equal to both said reactive chambers, and
    - b. the gas pressure in said inlet compartments at a positive pressure greater than the gas pressures in both said reactive chambers with the said pressures progressively increasing from adjacent ends of said isolation chamber toward the interior thereof.
12. The reactor of claim 11 including flanges on said end walls at the openings therethrough defining an elongated tubular passage having the said complementary cross section defining said restricted orifice-size clearance with said tier of workpieces.
13. The reactor of claim 11 wherein said baffles provide progressively increased clearance diverging from said tier inwardly of said isolation chamber.
14. The reactor of claim 13 including flanges on said end walls at the openings thereof defining an extended tubular passageway having the said complementary cross section defining said restricted orifice-size clearance with said tier of workpieces.
15. The reactor of claim 11 wherein said baffles define three consecutive compartments comprising, sequentially
- 5
- 10
- 15
- 20
- 25
- 30
- 35
- 40
- 45
- 50
- 55
- 60
- 65
- 70
- 75

- A. a first outlet compartment adjacent said first reactive chamber;
- B. an intermediate inlet compartment;
- C. a second outlet compartment adjacent the second said reactive chamber;
- D. means for introducing a non-reactive atmosphere in said inlet compartments at a pressure greater than the pressures in said first and second reactive chambers;
- E. means for withdrawing gas from said first and second outlet compartments to maintain pressure therein less than the pressures in said inlet compartment and in said first and second reactive chambers; and
- F. means for transporting said tier of workpieces from said first reactive chamber through said isolation chamber into said second reactive chamber.
16. The reactor of claim 15 wherein said baffles are provided with progressively increased clearances diverging from said tier inwardly of said isolation chamber.
17. The reactor of claim 16 including flanges on the end walls of said isolation chamber about the openings therein defining an elongated tubular passageway having the said cross section defining said restricted orifice-type clearance with said tier of workpieces.
18. The reactor of claim 11 wherein said workpieces comprise planar substrates and including a plurality of carriers therefor adapted for end-to-end transport in said tier from said first reactive chamber, through said isolation chamber and into said second reactive chamber and having
- A. complementary end configurations to define said continuous tier;
  - B. a recess for mounting said substrates therein; and
  - C. a cross section complementary to the openings in said end walls and said baffles to define said restricted orifice-size clearance therewith.
19. The reactor of claim 18 wherein said baffles are provided with progressively increased clearances with said tier of workpieces diverging from said tier inwardly of said isolation chamber.
20. The reactor of claim 18 including flanges on said end walls at the openings thereof defining an elongated tubular passageway having the said complementary cross section defining said restricted orifice-size clearance with said carriers.
21. The reactor of claim 20 wherein said baffles are provided with progressively increased clearance with said carriers diverging from said tier inwardly of said isolation chamber.
22. The reactor of claim 18 including means for transporting said carriers in said end-to-end relationship from said first reaction chamber through said isolation chamber into said second reactive chamber.
23. A system for processing a moving tier of workpieces comprising
- A. a reactive chamber;
  - B. means for maintaining a substantially constant reactive first atmosphere in said chamber;
  - C. means for isolating said chamber from a second atmosphere comprising an isolation chamber having
    - a. a first opening communicating with said reactive chamber and having a cross section complementary to said tier of workpieces to form a non-contact restricted orifice-size clearance therebetween, non-contact
    - b. a second opening communicating with said second atmosphere with said first and second openings having a cross section corresponding to said tier of workpieces to form a non-contact restricted orifice-size clearance therebetween; - D. baffle means in said isolation chamber extending transversely thereof and subdividing said isolation chamber into a series of alternate inlet and outlet compartments for a non-reactive atmosphere with said series comprising a minimum of three said compartments;
  - E. means for providing a non-reactive atmosphere in said inlet compartments at a positive pressure at least equal to

- the pressure in said reactive chambers;
- F. means for withdrawing gases from said outlet compartments to maintain pressures therein at a level substantially lower than the pressures in said inlet compartments and in said reactive chambers; and
- G. means for moving said tier of workpieces from said first reactive chamber through said isolation chamber into said second reactive chamber.
24. The system of claim 23 wherein said compartments comprise, sequentially, a first outlet compartment adjacent said first reactive chamber, an inlet compartment and a second outlet compartment adjacent the said second atmosphere chamber with the pressure of said non-reactive gas in said inlet compartment maintained at a level substantially greater than the pressure of said first and second atmospheres and with the pressure in said outlet compartments maintained substantially lower than the pressures of adjacent atmospheres.
25. The system of claim 23 wherein said baffle means subdivide said chamber into five compartments comprising, sequentially,
- A. a first inlet compartment adjacent said first reactive chamber;
  - B. a first outlet compartment;
  - C. a second inlet compartment;
  - D. a second outlet compartment;
  - E. a third inlet compartment adjacent the said second atmosphere;
  - F. means for providing a non-reactive atmosphere in said first and third inlet compartments at a pressure at least equal to the pressure of said first and second atmospheres;
  - G. means for providing a non-reactive atmosphere in said second inlet compartment at a pressure substantially greater than the pressure in said first and third inlet compartments; and
  - H. means for withdrawing gases from said outlet compartments to maintain a pressure therein substantially lower than the pressure in adjacent ones of said inlet compartments.
26. The system of claim 24 wherein adjacent ones of said pressures conform to the generalized orifice equation flow = $K \Delta P$ and wherein
- A. the flow F_1 between the first atmosphere at a pressure P_1 and the first said adjacent outlet compartment at a pressure P_{42} conforms to the equation $F_1 = K_1 \sqrt{P_1 - P_2}$ where P_1 is selected to maintain a flow selected from the group consisting of
    - a. zero flow between P_1 and P_2 and
    - b. positive flow from P_1 to P_2
  - B. the flow F_2 between the first said outlet compartment at said pressure P_2 and said inlet compartment at a pressure P_3 is greater than said flow F_1 and conforms to the equation $F_2 = K_2 \sqrt{P_3 - P_2}$ where P_3 is greater than P_2 and selected to maintain a positive flow from P_3 to P_2
  - C. the flow F_3 between said inlet compartment at its said pressure P_3 and the second said outlet compartment at a pressure P_4 conforms to the equation $F_3 = K_3 \sqrt{P_3 - P_4}$ where P_4 is less than P_3 and selected to maintain a positive flow from P_3 to P_4
  - D. the flow F_4 between said outlet compartment at a said pressure P_4 and said second atmosphere adjacent thereto at a pressure P_5 is less than the said flow F_3 and conforms to the equation $F_4 = K_4 \sqrt{P_5 - P_4}$ where P_5 is selected to maintain a flow selected from the group consisting of
    - a. zero flow between P_5 and P_4 and
    - b. positive flow from P_5 to P_4 .
27. The system of claim 25 wherein adjacent said pressures conform to the generalized orifice equation flow = $K \sqrt{\Delta P}$ and wherein
- A. the flow F_1 between the first atmosphere at a pressure P_1 and the first said inlet compartment adjacent thereto at a

- pressure P_2 conforms to the equation $F_1 = K_1 \sqrt{P_2 - P_1}$ where P_2 is selected to maintain a gas flow selected from the groups consisting of
  - a. zero flow between P_2 and P_1 and
  - b. positive flow from P_2 to P_1
- B. the flow F_2 between the first said inlet compartment at said pressure P_2 and the first said outlet adjacent the compartment at a pressure P_3 conforms to the equation $F_2 = K_2 \sqrt{P_2 - P_3}$ where
  - a. F_2 is greater than F_1
  - b. P_3 is smaller than P_2 and
  - c. P_3 is selected to maintain positive flow from P_2 to P_3
- C. where the flow F_3 between said first outlet compartment at said pressure P_3 and the adjacent said second inlet compartment thereto at a pressure P_4 conforms to the equation $F_3 = K_3 \sqrt{P_4 - P_3}$ where
  - a. P_4 is greater than P_3 and P_2 and
  - b. P_3 is selected to maintain a positive flow F_3 from P_4 to P_3
- D. the flow F_4 between the second said inlet compartment at said pressure P_4 and the adjacent second said outlet compartment at a pressure P_5 conforms to the equation $F_4 = K_4 \sqrt{P_4 - P_5}$ where P_4 is greater than P_5 and selected to maintain a positive flow F_4 from P_4 to P_5
- E. the flow F_5 between the second said outlet compartment at said pressure P_5 and the next succeeding third said inlet compartment at a pressure P_6 conforms to the orifice equation $F_5 = K_5 \sqrt{P_6 - P_5}$ where
  - a. P_6 is greater than P_5
  - b. P_6 is lower than P_4 and
  - c. P_6 is selected to maintain a positive flow from P_6 to P_5 and
- E. the flow F_6 between the third said inlet compartment at its said pressure P_6 and the adjacent second of said atmosphere at a pressure P_7 conforms to the generalized orifice equation $F_6 = K_6 \sqrt{P_6 - P_7}$ where
  - a. P_6 is greater than P_7 and
  - b. P_6 is selected to maintain said flow F_6 selected from the group consisting of
    - 1. zero flow between P_7 and P_6 and
    - 2. a positive flow from P_6 to P_7 , said isolation
28. The system of claim 23 wherein said workpieces comprise planar semiconductor substrates and including a plurality of carriers therefor adapted for end-to-end non-contact transport in said tier from said first reactive chamber, through said isolation chamber and into said second reactive chamber and having
- A. complementary end configurations to define said continuous tier;
  - B. a recess for mounting said substrates therein; and
  - C. a cross section complementary to the openings in said end walls and said baffles to define said restricted orifice-size clearance therewith.
29. The system of claim 25 wherein said workpieces comprise planar semiconductor substrates and including a plurality of carriers therefor adapted for non-contact end-to-end transport in said tier through said isolation chamber between said reactive chamber and said second atmosphere and having
- A. complementary end configurations to define said continuous tier;
  - B. a recess for mounting said substrates therein; and
  - C. a cross section complementary to the openings in said end walls and said baffles to define said restricted orifice-size clearance therewith.
30. The system of claim 1 wherein said workpieces comprise planar semiconductor substrates and including a plurality of carriers therefor adapted for end-to-end non-contact transport in said tier from said first reactive chamber, through said isolation chamber and into said second reactive chamber and having
- A. complementary end configurations to define said continuous tier;
  - B. a recess for mounting said substrates therein; and

C. a cross section complementary to the openings in said end walls and said baffles to define said restricted orifice-size clearance therewith.

31. The system of claim 4 wherein said workpieces comprise planar semiconductor substrates and including a plurality of carriers therefor adapted for end-to-end non-contact transport in said tier from said first reactive chamber, through said isolation chamber and into said second reactive chamber and having

- A. complementary end configurations to define said continuous tier;
- B. a recess for mounting said substrates therein; and
- C. a cross section complementary to the openings in said end walls and said baffles to define said restricted orifice-size clearance therewith.

32. The system of claim 5 wherein said workpieces comprise planar semiconductor substrates and including a plurality of carriers therefor adapted for end-to-end non-contact transport in said tier from said first reactive chamber, through said isolation chamber and into said second reactive chamber and having

- A. complementary end configurations to define said continuous tier;
- B. a recess for mounting said substrates therein; and
- C. a cross section complementary to the openings in said end walls and said baffles to define said restricted orifice-size clearance therewith.

33. The system of claim 7 wherein said workpieces comprise planar semiconductor substrates and including a plurality of carriers therefor adapted for end-to-end non-contact transport in said tier from said first reactive chamber, through said isolation chamber and into said second reactive chamber and having

- A. complementary end configurations to define said continuous tier;
- B. a recess for mounting said substrates therein; and
- C. a cross section complementary to the openings in said end walls and said baffles to define said restricted orifice-size clearance therewith.

34. The system of claim 9 wherein said workpieces comprise planar semiconductor substrates and including a plurality of carriers therefor adapted for end-to-end non-contact transport in said tier from said first reactive chamber, through said isolation chamber and into said second reactive chamber and having

- A. complementary end configurations to define said continuous tier;
- B. a recess for mounting said substrates therein; and
- C. a cross section complementary to the openings in said

50

end walls and said baffles to define said restricted orifice-size clearance therewith.

35. The system of claim 10 wherein said workpieces comprise planar semiconductor substrates and including a plurality of carriers therefor adapted for end-to-end non-contact transport in said tier from said first reactive chamber, through said isolation chamber and into said second reactive chamber and having

- A. complementary end configurations to define said continuous tier;
- B. a recess for mounting said substrates therein; and
- C. a cross section complementary to the openings in said end walls and said baffles to define said restricted orifice-size clearance therewith.

36. The system of claim 11 wherein said workpieces comprise planar semiconductor substrates and including a plurality of carriers therefor adapted for end-to-end non-contact transport in said tier from said first reactive chamber, through said isolation chamber and into said second reactive chamber and having

- A. complementary end configurations to define said continuous tier;
- B. a recess for mounting said substrates therein; and
- C. a cross section complementary to the openings in said end walls and said baffles to define said restricted orifice-size clearance therewith.

37. The system of claim 13 wherein said workpieces comprise planar semiconductor substrates and including a plurality of carriers therefor adapted for end-to-end non-contact transport in said tier from said first reactive chamber, through said isolation chamber and into said second reactive chamber and having

- A. complementary end configurations to define said continuous tier;
- B. a recess for mounting said substrates therein; and
- C. a cross section complementary to the openings in said end walls and said baffles to define said restricted orifice-size clearance therewith.

38. The system of claim 15 wherein said workpieces comprise planar semiconductor substrates and including a plurality of carriers therefor adapted end-to-end non-contact transport in said tier from said first reactive chamber, through said isolation chamber and into said second reactive chamber and having

- A. complementary end configurations define said continuous tier;
- B. a recess for mounting said substrates therein; and
- C. a cross section complementary to the openings in said end walls and said baffles to define said restricted orifice-size clearance therewith.
